UNITED STATES PATENT OFFICE.

WILLIAM S. GUBELMANN, OF ROCHESTER, NEW YORK.

CALCULATING-MACHINE.

1,160,071.

Specification of Letters Patent.

Patented Nov. 9, 1915.

Application filed July 2, 1889. Serial No. 316,811.

To all whom it may concern:

Be it known that I, WILLIAM S. GUBELMANN, a citizen of the United States, residing at Rochester, in the county of Monroe 5 and State of New York, have invented new and useful Improvements in Calculating-Machines, of which the following is a specification.

This invention relates to that class of calculating machines which are provided with a series of registering wheels and in which the registering wheels are actuated by key levers.

The object of my invention is to produce 15 a machine of this character whereby the various operations of adding, subtracting, multiplying, and dividing are mechanically performed in a simple and expeditious manner.

20 The invention consists of the improvements which will be hereinafter fully set forth and pointed out in the claims.

In the accompanying drawings consisting 25 of six sheets, Figure 1 is a front elevation of my improved calculating machine showing a number of transverse stop bars broken away and the indicating dials and dial casing removed. Fig. 2 is a horizontal section in line 2—2, Fig. 1. Fig. 3 is a longitudinal 30 sectional elevation. Fig. 4 is a fragmentary cross section of the lower portion of the machine partly in line 4—4, Fig. 3, looking toward the rear. Fig. 5 is a fragmentary cross section of the rear portion of the machine in line 5—5, Fig. 3 looking from the rear. Fig. 6 is a fragmentary longitudinal sectional elevation of the registering mechanism and connecting parts in line 6—6, Fig. 1, on an enlarged scale, showing the 35 dials, movable sight plate, and dial casing attached. Fig. 7 is a fragmentary transverse section in line 7—7, Fig. 6, showing the dial casing and sight plate removed. Fig. 8 is a fragmentary transverse section of the 40 dial casing, dials, and connecting parts. Fig. 9 is a top plan view of the same. Fig. 45 10 is a fragmentary longitudinal sectional elevation similar to Fig. 6, showing the mechanism whereby the movement of one registering wheel is transmitted to the next

higher wheel, in a locked position. Fig. 11 is a similar view showing the transmitting mechanism in an unlocked position.

Like letters of reference refer to like parts in the several figures.

A A' represent the side frames of the machine which are connected at their front ends by an end frame *a* and at their rear ends by cross bars *a'*.

B see Figs. 1, 3, 6, and 7 represents a series of registering wheels arranged side by side in the upper portion of the machine and mounted upon a transverse shaft *b* so as to rotate independently of each other. The shaft *b* is held against turning by disks C Fig. 3 secured to the side frames A A'. The wheels B are held against retrograde movement by detents *b'* suspended from a cross bar *b* secured between the disks C.

c represents a gear rim secured to one side of each registering wheel B. Each registering wheel B is preferably provided with one hundred teeth, and its gear rim *c* is also provided with the same number of teeth.

c' represents a cam disk secured to the opposite side of each registering wheel B and each provided with ten abrupt inclines or cams *c*², there being one cam or incline *c*² for every ten teeth on the registering wheel.

*c*³ represents gear pinions one of which 80 engages with the gear rim *c* of each registering wheel B.

The gear pinions *c*³ are each provided with ten teeth and are secured to the lower ends of forwardly inclined spindles *c*⁴. The latter are journaled at their upper ends in a cross bar *c*⁵ and at their lower ends in bearings formed in arms *c*⁶ depending from the cross bar *c*⁵.

D represents the dials secured to the upper 90 ends of the spindles *c*⁴. The number of dials D corresponds with the number of registering wheels B. Each dial is connected with a registering wheel B by a gear rim *c*, a gear pinion *c*³, and spindle *c*⁴. The 95 dials D are inclosed in a casing *d* arranged above the registering wheels between the side frames A A'.

Each dial is provided on its upper face, near its periphery, with two annular rows 100

of figures or numerals ranging from 0 to 9, one row being arranged within the other and having the value of its numerals increasing in a direction opposite to those of the other row, whereby the numerals are arranged in complementary pairs. The dials D are arranged side by side one above each registering wheel, and represent units, tens, hundreds, thousands, and so on, up to ten hundred millions. The dial nearest to the right registers the units, the next adjacent dial the tens, and so on to the last dial which registers the hundred millions.

D represents a movable sight plate arranged above the dials D in grooves or ways d' formed in the upper ends of the casing d and provided with as many sight openings d² as there are dials D.

d³ represents a thumb piece formed on the outer end of the sight plate D' whereby the latter can be shifted.

d⁴ represents a spring detent which engages against one of two notches d⁵ d⁶ on the top of the plate D' whereby the latter is held in position to expose either the numbers in the outer row of the dials, or the numbers of the inner row of the dials. The sight openings d² are of the proper size and so arranged as to expose only one of the outer figures on each dial when the plate is moved inwardly, and only one of the figures on the inner row of each dial when the plate is moved outwardly; so that when the plate is in its first mentioned position, the figures exposed to view will increase in value from 0 to 9 as the dials are rotated, and when the plate is in the last mentioned position, the exposed figures will decrease in value from 9 to 0, as the dials are rotated.

E represents a yoke or U-shaped frame mounted on the cross bar b² between each pair of detents b'. As shown in Figs. 6 and 7, each frame E consists of a forwardly and downwardly projecting cam finger e, a forwardly projecting pawl carrying arm e' having a pawl e² and a connecting sleeve e³. The cam finger e is arranged to engage with the cam disk c' of one of the registering wheels B, and the pawl arm and the pawl e² to engage with the teeth of the adjacent or next succeeding registering wheel.

e⁴ represents a wire spring whereby the cam finger e is moved inwardly when released from one of the cams. The spring e⁴ surrounds the sleeve e³ and bears with one end against the cam finger e and its opposite end against the cross bar c⁵.

E' represents a curved arm forming a rearwardly continuation of the cam finger e and carrying at its free end a friction roller E². This arm is so arranged with reference to the finger e that when the latter is raised, or moved outwardly, the finger E' will be moved inwardly, in front of the inclined advancing face of a succeeding cam c². This

construction compels the cam finger e to move inwardly when released from the cam, and assists the spring e⁴ in actuating the cam finger at a time when the wheel B is rotated a distance sufficient to cause a number 70 of cam faces to pass by the cam finger in quick succession.

e⁵ represents a stop pin secured to the free end of each pawl arm e' and which projects over the teeth of the adjacent registering wheel (Figs. 6, 7, 10, and 11) and also serving as a pivot for the pawl e².

e⁶ represents a similar pin secured to the free end of the pawl e² and which rides over the advancing inclined face of one of the 80 teeth of the adjacent registering wheel so as to engage against the abrupt back of the next succeeding tooth, when the arm e' is elevated by the cam finger e as shown in Fig. 6, and which moves said wheel the distance of one tooth each time the cam finger is released and depressed by the spring e⁴. The range of movement of the arm e' is just sufficient to cause the pawl to move the wheel B but one tooth at a time. The movement 90 of the arm e' is such that the speed of the forward movement of the pawl will decrease as the arm and pawl assume a straight line as shown in Fig. 10. The possibility of imparting a movement to the wheel B, sufficient to cause it to move more than one tooth at a time is thus practically avoided; but as an additional safeguard I permit the arm e' to descend sufficiently, momentarily, to cause the pin e⁵ to strike against the inclined advancing face of one of the teeth of the registering wheel B at the same time that the pawl e² has reached the limit of its forward movement, whereby the wheel B is practically locked against further rotation. 100

At the same moment that the pin e⁵ engages between the teeth of wheel B, as shown in Fig. 10, the rear arm E' strikes against a recoil spring e⁷, secured to the rear side of the cross bar c⁵, and deflects the spring sufficiently to allow the pin e⁵ of the arm e' to strike against the front side of one of the advancing teeth of the wheel B and thereby retard its further movement. This engagement of the pin is but momentary as the reaction of the spring e⁷ moves the arm E', cam finger e, and pawl arm e' to the position shown in Fig. 11, in which position the pin e⁵ clears the teeth of the wheel B. 110

The termination or highest point of each 120 cam is arranged in a radial line with the tooth of the wheel B which indicates zero on the dial D, so that in moving the wheel B a distance of one tooth when its dial indicates 9, the cam finger e, will drop or 125 move inwardly and advance the next succeeding wheel one tooth at the same time that the first mentioned wheel is moving from 9 to 0.

F represents the key levers arranged hori- 130

zontally side by side in the lower portion of the machine, and provided at their front ends with the usual keys f' . The latter are numbered 1, 2, 3, 4, 5, 6, 7, 8, and 9, respectively. The zero or 0 key is arranged at the left hand side of the machine as shown at W, Figs. 1 and 2. Each key lever is supported near its front end by a light spring f^2 and bears with its rear end against the lower curved side of a cross bar g secured to the rear end of a U-shaped carriage frame G. The side arms G' of the latter are arranged on opposite sides of the key levers F and are pivoted at their front ends at g' to the inner side of the side frames A A', and rest with their rear ends upon stops or pins g^2 .

H represents a transversely and vertically movable slide or carriage, moving on guides or ways h h' which latter are arranged one above the other and are secured at their ends to the side bars G' of the frame G.

H' represents a horizontal shifting lever arranged underneath the key levers F and engaging at its rear end with a depending stud h^2 formed on the lower side of the carriage H and attached near its front end by a vertical pivot bolt to the lower side of the front frame a of the machine.

h^3 represents a coiled spring attached at one end to the shifting lever H' and at its opposite end to the front frame a of the machine. A vertical movement is imparted to the carriage frame and the carriage H supported thereon by depressing the key levers. The carriage is moved transversely from right to left by the shifting lever H' and spring h^3 .

The shifting lever H' is composed of two sections h^4 h^5 which are connected by a hinged joint h^6 so as to allow the inner arm h^4 of the lever to take part in the vertical movement of the carriage. The outer arm h^5 is provided at its free end with a thumb piece h^7 whereby the carriage can be moved transversely to the right-hand side of the machine. If desired the shifting lever may be constructed of a single piece of spring metal having sufficient elasticity to permit the upward movement of the carriage.

I represents a T-shaped pawl or detent pivoted in an opening in the upper portion of the carriage H and adapted to engage with its rear leg i against one of a series of stops i' arranged on a transverse bar i^2 , and with its front leg i^3 against one of a series of teeth i^4 formed on the upper side of the cross bar g of the carriage frame as shown in Figs. 3 and 5. The rear leg of the pawl I engages against one of the stops i' when the carriage is in its lowest position as shown in Figs. 3, 4 and 5, and the front leg i^3 of the pawl engages with a tooth i^4 of the cross bar g , when the carriage is raised and its rear leg disengaged from the stop i' .

The stops i' are provided with backwardly inclined top faces and the teeth i^4 on the cross bar g are arranged slightly in rear or to the left of the stops i' . Upon depressing a key lever so as to move the carriage upwardly, the pawl I will be released from the stop i' , by the upward movement of the carriage and will engage immediately against the next tooth i^4 on the bar g and hold the carriage against further transverse movement to the left while the key lever is depressed. Upon releasing the key lever the carriage descends and the leg i of the pawl I during the downward movement of the carriage strikes against the inclined face of the stop i' below the pawl, whereby the downward movement of the pawl is arrested until the pawl is released from the tooth i^4 . When the pawl has been released from the tooth i^4 the carriage is permitted to be moved to the left by the shifting lever H' until the pawl engages against the next succeeding stop i' . The carriage H is fed in this manner intermittently from one stop to another. The carriage is returned to its point of beginning by the operator swinging the lever H' on its pivot by means of the thumb piece h^7 . The transverse bar i^2 is movably secured to two laterally projecting ears j^4 on the frames A A' by screws j^6 . These screws pass through elongated openings j^6 Figs. 4 and 5 in the bar i^2 and are secured to the ears j^2 . j^7 represents a dog or catch which engages with a nose j^8 on the bar i^2 and whereby the latter is held in a locked position. j^9 represents a spring whereby the bar i^2 is moved to the left when released from said catch j^7 . When the bar i^2 is released from the catch j^7 and moved to the left by the spring j^9 the stops i' will be arranged in rear of the teeth i^4 , so that the pawl I will clear the stops i' when the carriage descends, and will not be released from the teeth on the bar g of the carriage frame. In this position of the bar i^2 the carriage is held from moving transversely upon depressing and releasing a key lever by the pawl I remaining engaged with one of the teeth i^4 on the bar g of the carriage frame.

I' represents a space bar arranged in rear of the shifting bar i^2 and secured at its opposite ends to vertical guide rods i^8 , which are guided at their lower ends in lugs secured to the side frames. The upper ends of these guide rods are attached to the inner ends of rock levers i^7 which latter are secured at their outer ends to a transverse rock shaft i^9 mounted in bearings secured to the rear of the machine. I² represents a space lever arranged above the key levers F and pivoted to the side frame A'. The space lever I² is connected with the rock shaft i^9 by a longitudinal rod i^9

secured to the short arm of the space lever, and a vertical arm i^{10} secured to the rock shaft i^s .

The space bar I' is held in a depressed position by springs surrounding the lower portion of the rods, and interposed between the lower side of the guide lugs, and heads formed on the lower ends of the guide rods. The space bar I' is provided with a series 16 of blunt teeth or projections i^{12} having flat upper faces, and straight or vertical front sides. The vertical front sides of these teeth are arranged to the right of the stops i' , and the pawl arm when in engagement 15 against a stop i' rests above the upper flat face of one of the teeth on the space bar. Upon depressing the space lever I^2 , the space bar I' is raised and carries with it the pawl I of the carriage H, until the pawl is released from the stop i' when the shifting 20 lever H' will cause the carriage to move to the left until the pawl I strikes against the front vertical side of the next adjacent tooth i^{12} on the space bar I' . Upon releasing the 25 space lever I^2 the space bar I' is allowed to descend, which movement releases the pawl I and the carriage H, and permits the pawl to engage against the next stop i' . When the stop bar i^2 has been moved to the left 30 so that the pawl engages against the teeth i^s of the bar g as before described, and it is desired to shift the carriage, the space lever I^2 is depressed and the space bar I' raised so as to disengage the pawl I from the tooth 35 i^s of the bar g , when the carriage is moved to the left by the shifting bar H' as before and the pawl I engages against the next tooth i^s upon releasing the space lever.

J Figs. 1, 2, 3 and 4 represents a series of 40 forwardly inclined spring levers arranged side by side, on the rear side of the machine. These spring levers are preferably secured at their lower ends to blocks or sleeves k which are mounted upon a cross bar k' arranged above the space bar I' . Each sleeve k carries a spring lever J and is provided with a forwardly and downwardly curved finger k^2 . The finger k^2 of each spring lever J projects over the path of the carriage H, 45 so that the latter will stand below said fingers as it is moved from one stop i' to another. As the carriage is raised upon depressing a key lever the finger k^2 immediately above the carriage will be raised and 50 its spring lever J deflected or swung backwardly. The spring levers J bear with their upper ends against the upper cross bar a' of the frame of the machine when at rest.

J' represents a series of pawl arms 60 mounted on the shaft b and each provided at its outer end with a pawl J^2 . The pawl arms J' are each arranged adjacent to the cam disk c of each registering wheel B as shown in Figs. 1, 3, 6, and 7, so that its 65 pawl J^2 engages with a tooth on the adja-

cent wheel B. The hub k^3 of each pawl arm J' is preferably made hollow as shown in Figs. 6 and 7, so as to form a casing for a coiled return spring k^4 which surrounds the cross bar b , and has one end secured to the cross bar b and the other end to the arm J' . 70

k^5 represents a cord or chain secured at one end to the upper free end of each spring lever J and at its opposite end to the hub k^3 of each pawl arm J' . The cord passes 75 around the hub k^3 and upwardly to the lever J, so that when the lever is swung backwardly it causes the pawl arm to move downwardly and turn the registering wheel B in the direction of the arrow in Figs. 3 80 and 6. The pawl arm J' and its spring lever J are returned to their normal position by the spring k^4 after each forward stroke of the pawl arm.

L Figs. 1, 3, and 6 represents a fixed transverse stop bar secured at opposite ends to the inner sides of the disks C. The backward stroke of each pawl arm J' is arrested by a nose l formed on the arm J' , striking 85 against the stop bar L. 90

m Figs. 1, 3 and 6 represents a series of transversely movable stop bars arranged radially around the peripheries of the registering wheels with their ends projecting through radial grooves m' formed in the 95 end disks C. The ends of the stop bars m project through openings m^2 formed in the end frames A A' as shown in Figs. 4 and 6 whereby they are held against radial displacement in the disks C. The stop bars 100 m increase in value in the direction of the arrow m^3 in Fig. 3, and are numbered so as to embrace the units 0, 1, 2, 3, 4, 5, 6, 7, 8, and 9, and also all the products of any two as 10—12 etc., there being thirty-seven stop 105 bars which embrace all the units as well as the entire unit multiplication system, as shown in Fig. 3.

As shown in Figs. 1, 3, 4, and 6 each stop bar m is provided on its inner edge opposite the path of the pawl arms J' with recesses or notches m^4 so as to allow the pawl arms J' to move freely past the same, when the stop bars are in their normal position as shown in the above figures of the drawings, and with projecting portions m^5 arranged between each two adjacent notches or recesses m^4 whereby the movement of the pawl arms J' is arrested when the stop bars are moved in the path of the pawl arms. When 110 a stop bar intercepts a pawl arm the latter will have moved its registering wheel B a number of teeth corresponding with the number represented by the stop bar so moved. 115

As shown in Figs. 1, 2, and 4 each stop bar m is connected at one end with a vertical lever N by a link n . These levers N are fulcrumed between their ends upon a longitudinal rod n' which is supported in brackets 120 125 130

*n*² secured to the side frame A' of the machine. The opposite end of each stop bar *m* is provided with a coiled spring *n*³ which surrounds a finger *n*⁴ formed on the end of 5 the bar *m*. The springs *n*³ are connected at their outer ends to said fingers and bear with their inner ends against the side frame A, whereby the stop bars *m* are held in their normal position, with their recesses *m*⁴ in the 10 path of the pawl arms J'.

As shown in Figs. 6 and 7, each pawl J² is 15 provided with a tooth *n*⁵, having an abrupt front or actuating face and an inclined or retreating back, and is held in engagement with the teeth of the registering wheel by a suitable spring *n*⁶. The outer face *n*⁷ of the pawl J² is arranged close to the inner longitudinal edge of the projecting portions *m*⁵ of the stop bars *m*, so that when one of said 20 stop bars is moved across the path of said pawl, to arrest the movement of the arm J', the pawl J² will be held against the tooth of the wheel B with which it is in engagement, by the projecting portion *m*⁶. The stop bar 25 *m* bears against the outer side of said pawl and locks the wheel B against rotation. The pawl in this manner will be held against forward or backward movement until the stop bar *m* has again returned to its normal position, with one of its notches *m*⁴ opposite the pawl J², when the latter is released and returned to its normal position by the 30 spring *k*⁴.

P represents a series of transversely movable slides arranged side by side, one in rear of the other as shown in Figs. 1, 2, and 3. These slides are preferably arranged obliquely. The ends *p* of the slides P are rectangular and are arranged in openings 35 formed in the side frames A A'. *p*' are shoulders formed near the opposite ends of the slides P, and adapted to bear against the side frames A A' whereby the movement of the slides P is limited in either direction. Each slide P is provided at its end adjacent to the side frame A with a key or thumb piece *p*² which is numbered to correspond with the number of a key lever as 40 shown in Figs. 2 and 4, and with a spring *p*³ 45 whereby the slides P are moved outwardly when released.

P' represents a rock shaft mounted in brackets *p*⁴. The rock shaft P' is arranged above the outer ends of the slides P and is 50 provided with a series of laterally projecting catches *p*⁵ one for each slide P. These catches *p*⁵ bear with their lower inclined faces upon the top of the slides P and engage with a spur or nose *p*⁶, formed on the 55 top of each slide, when said slides are moved inwardly. These spurs *p*⁶ have inclined front faces and abrupt backs so that upon moving the slide P inwardly the catches *p*⁵ and the rock shaft P' are swung upwardly 60 until the catch above the slide P drops back 65

of the incline and locks the slides in this innermost position. The catches *p*⁵ are arranged in line so that a slide P which has been previously moved in and locked by its catch, will be released at the same moment 70 that another slide is moved inwardly. This construction prevents the possibility of more than one slide P being held in an innermost or locked position at one time. The catches *p*⁵ are held in a locked position by a spring 75 *p*⁷ secured to one end of the rock shaft P'.

Each slide P is provided with a row of vertical pins R, there being nine of said pins for each slide. The pins R move in vertical openings arranged in top and bottom flanges 80 *r* *r*' formed in each slide P and are held in an elevated position by springs *r*² which surround the pins R and are interposed between the lower flange *r*' and transverse pins *r*³ secured in the upper portion of each pin R. 85 The pins *r*³ also serve to limit the upward movement of the pins R. The pins R on each slide P increase in value from left to right. As for example: In the first slide P No. 1 its pins represent in value from one to 90 9, the first pin to the left being 1 and the last pin to the right 9. The pins on slide P No. 2 begin with the value of 2, and this number is added to itself eight times successively so that the value of the last pin on this slide 95 is 18. The pins on slide P No. 3 begin with the value of 3 and this number is added to itself on each succeeding pin in the same manner as on slide No. 2 so that the value of its last pin represents 27. The pins of each 100 of the succeeding slides Nos. 4, 5, 6, 7, 8, and 9 begin at the left with the value of 4, 5, 6, 7, 8, and 9 respectively, and the remaining pins of these slides increase in value in the same manner by adding the number of 105 the first pin to itself eight times successively. As clearly shown in Fig. 2 the numbers on the pins R increase from the front to the rear of the machine in the same manner as they increase from left to right of the machine on each slide P.

S represents nine narrow horizontal open wings or swinging frames arranged side by side as shown in Figs. 2, and 4, and pivoted lengthwise of the machine in the upper portion of two oblique bars or frames S' S² by pivots *s*. Each wing S is connected at opposite ends in front of its pivots *s* by vertical rods *s*' *s*², with the opposite ends of a horizontal equalizing bar *s*³. The bar *s*³ of each 115 wing is pivoted between its ends to the key lever F arranged below said wing, so that upon depressing a key lever the wing S connected therewith will also be depressed or swung downwardly on its pivots. As shown 120 in Fig. 3 the wings S are held in an elevated position by springs *s*⁴ surrounding the rods *s*' *s*² and bearing with their upper ends against the lower sides of the projecting ends of the wings S, and with their lower 130

ends against the upper side of a flange formed on the lower end of each frame $S' S^2$. Each wing S consists of a bar s' , a second bar parallel therewith, and a pair of relatively short bars which connect the bar s' with the second bar, forming a longitudinal opening s^6 through each wing-plate S , see Figs 2 and 4. When the slides P are in their normal or forward position the pins R will be arranged below the open portion s^6 of the wings. When a slide has been moved inwardly and is locked by its catch p^5 the pins R attached to this slide will stand immediately below the longitudinal bars s' of the wings, so that upon depressing any one of the wings by means of its key lever the pin R below the bar s' of this wing will also be depressed.

As represented in Figs. 1, 3, and 4, T represents elbow levers arranged below the pins R , there being one elbow lever for each pin R . These levers are arranged side by side upon longitudinal bars t secured at opposite ends to the lower portion of the oblique frames $S' S^2$. The upper arm of each elbow lever T is provided with a flat bearing face t' and the lower long arm t^2 of each elbow lever is connected by a rod or wire t^3 , with the lower end of one of the vertical levers N , which is connected as before described with a movable stop bar m . The pins R correspond in value with the stop bars m and each pin R having a given value is connected by means of its lever T , rod t^3 and lever N with a stop bar m having the same value, so that upon depressing a pin R by a wing S , and key lever F the stop bar m corresponding in value with the depressed pin will be actuated by the lever T , rod t^3 and lever N connected therewith.

As shown in Fig. 4 the upper end of each elbow lever T is arranged a slight distance in advance of the lower projecting ends of the pins R , when the slides P are in their normal or forward position, but will stand immediately below the pins R of a slide that has been moved inwardly and locked by its catch p^5 . Upon depressing a key lever when a slide is in this last mentioned position the bar s' of the wing S attached to said key lever, will swing downwardly and depress the pin R below the same, and the pin R in turn will move the lever T so that the lower arm t^2 of the same will swing backwardly toward the left hand side of the machine, Fig. 4. This movement of the lever T , causes the lever N connected therewith to swing on its pivot n' and move outwardly to the right a stop bar m corresponding in value to the depressed pin R . This outward movement of the stop bar m allows the registering wheel to move a number of teeth corresponding with the value of the depressed pin R as above described. When the key lever F is released the stop bar m and the levers N and

T are returned to their normal position by the spring n^3 of the stop bar m , and the wing S and the pin R are again elevated by their respective springs $s^4 r^1$.

As shown in Figs. 1 and 2 of the drawings 70 the slide P No. 1 is in a locked position; the pins, being arranged underneath the bars s' of the wings S , are shown in dotted lines.

As represented in Fig. 3, U represents two bell-crank levers one of which is pivoted to 75 the inner side of each side bar G' of the carriage frame G . The levers U are provided at their depending ends with hooks u which engage under noses or hooks u' secured to the adjacent side frames $A A'$, when the carriage 80 frame G is in its lowermost position. u^2 is a cross bar arranged a short distance below the key levers F and secured at its ends to the horizontal arms u^3 of each lever U . u^4 represents a spring whereby each lever U is 85 held in engagement with the nose u' . The upward movement of the rod u^2 is limited by a stop pin u^5 . The lever U serves to lock the carriage frame in a depressed position and hold the same against vertical movement. 90

It will be observed that the first part of the downward movement of a key lever F tends to move its wing S , the pin R arranged below the same, the bell crank T , lever N and stop m as above described, the 95 cross bar g acting as a fulcrum for the key lever. As this downward movement of the key lever continues, its lower side strikes the upper side of the cross bar u^2 , and releases the hook u from the nose or projection u' . 100 During the balance of the downward stroke of the key lever F its point of fulcrum is transferred to the pivot of the equalizing bar s^3 , and the rear end of the carriage frame G is raised so as to cause the carriage H to 105 strike against one of the curved fingers k^2 of a spring arm J , and swing the latter backwardly. This movement of the spring arm causes the pawl arm J' and the wheel B with which it is in engagement to rotate 110 until the nose l of the pawl arm strikes against the shifted stop bar m . Upon releasing the key lever F the stop m is returned to its normal position, thereby releasing the pawl arm J' and lever J . The 115 pawl arm J' and lever J are returned to their normal position by the spring k^4 ; the carriage, by gravity; the key lever F , by the spring f^2 ; and the wing S and connections by their springs as above described. The 120 distance of the upward movement of the carriage H and the lower inner ends k^2 of the springs bars J is the same at each upward stroke, while the backward movement of the upper end of the spring bars J varies according to the distance of the movement of the registering wheel B with which its pawl arm J' is in engagement. This difference of movement is compensated for, by the elasticity of the spring bars J . 125 130

W represents the zero key lever arranged at the extreme left of the machine. The rear end of this key lever rests against the bar *g* of the carriage frame, and is supported near 5 its center by a rod *w*³ secured to the inner end of a rock lever *w*⁴. The latter is secured to one end of a rock shaft *w*⁵ which is supported in bearings secured to the outer side of the side frame A. *w*⁶ is an outwardly 10 projecting arm secured to the rear end of the rock shaft *w*⁵, and *w*⁷ is a lifting bar pivoted at its upper end to the arm *w*⁶. The lower end of the lifting bar *w*⁷ is attached to the stop bar *i*² by a screw engaging in an 15 elongated opening *w*⁸ formed in the lifting bar. The lower end of the lifting bar *w*⁷ is provided with a lip or projection *w*⁹ which engages against the lower side of a nose *w*¹⁰ formed on the space bar I' when the stop bar 20 *i*² is in an inward or locked position, whereby the space bar is raised upon depressing the zero lever W. The lower end of the lifting bar *w*⁷ is disengaged from the space bar I' when the stop bar *i*² is moved outwardly, 25 which permits the zero key to be depressed without imparting any movement to the space bar.

The zero lever W is raised or bent upwardly above the cross bar *w*² so that the 30 zero lever will not come in contact with this cross bar and unlock the carriage frame when this lever is depressed.

w represents a rock shaft arranged transversely above the rear end of the carriage frame G and journaled at its ends in openings in the side frames A A'. *w*' represents forwardly projecting arms secured to opposite ends of the rock shaft *w* and connected with the rear ends of the side frames 40 G' of the carriage frame G, by vertical links *w*². By connecting opposite ends of the carriage frame in this manner, the carriage frame is held against tipping or twisting as both sides are caused to rise and descend 45 simultaneously, and enables a very light frame to be used. Any suitable means may be employed for resetting the numeral wheels to zero. The bar V is shown in the drawings in its lowermost position.

50 Each of the key levers F marked 1, 2, 3, 4, 5, 6, 7, 8, and 9, has arranged near the lower margin of its key a complementary number of smaller size, the two numbers on each key being the complement of ten.

55 W' represents an indicating finger secured to the front portion of the carriage shifting lever H' and which registers with a graduated segment *W*² secured to the lower front portion of the frame of the machine and which indicates the location or position of the carriage with reference to the spring levers J.

60 The operation of my improved calculating machine is as follows:—For instance, it is desired to add the two numbers 140 and

180. Having turned the dials to indicate zero and shifted the bar H' so that the carriage rests immediately below the spring lever J connected with the units wheel; the slide P No. 1 is moved to a locked position 70 and the stop bar *i*² locked in an inward position.

The zero key lever is first depressed. This does not move or change the units dial, but permits the carriage to move to the next 75 spring lever J which is connected with the tens wheel B. The key lever 4 is then depressed causing the tens wheel B to move four teeth and the tens dial to indicate 4. Upon releasing the key lever 4, the carriage 80 will move and come to rest below the spring lever connected with the one hundreds wheel. The key lever No. 1 is then depressed whereby the hundreds wheel will be moved a distance of one tooth, and indicate 85 one on its dial. The dials now indicate 140.

The carriage H is again returned to the units lever J and the key levers 0, 8, and 1 depressed successively, as in the case of the first number.

Having depressed the key lever 8, the tens wheel moves a distance of one hundredths wheel.

46 The key lever 1 is then depressed whereby the hundreds wheel will be moved a distance of one tooth, and indicate 90 141.

The carriage H is again returned to the units lever J and the key levers 0, 8, and 1 depressed successively, as in the case of the first number.

Having depressed the key lever 8, the tens wheel moves a distance of one hundredths wheel.

46 The key lever 1 is then depressed whereby the hundreds wheel will be moved a distance of one tooth, and indicate 95 142.

The carriage H is again returned to the units lever J and the key levers 0, 8, and 1 depressed successively, as in the case of the first number.

Having depressed the key lever 8, the tens wheel moves a distance of one hundredths wheel.

46 The key lever 1 is then depressed whereby the hundreds wheel will be moved a distance of one tooth, and indicate 100 143.

The carriage H is again returned to the units lever J and the key levers 0, 8, and 1 depressed successively, as in the case of the first number.

Having depressed the key lever 8, the tens wheel moves a distance of one hundredths wheel.

46 The key lever 1 is then depressed whereby the hundreds wheel will be moved a distance of one tooth, and indicate 105 144.

The carriage H is again returned to the units lever J and the key levers 0, 8, and 1 depressed successively, as in the case of the first number.

Having depressed the key lever 8, the tens wheel moves a distance of one hundredths wheel.

46 The key lever 1 is then depressed whereby the hundreds wheel will be moved a distance of one tooth, and indicate 110 145.

The carriage H is again returned to the units lever J and the key levers 0, 8, and 1 depressed successively, as in the case of the first number.

Having depressed the key lever 8, the tens wheel moves a distance of one hundredths wheel.

the carriage is returned so as to rest below the spring lever J of the units wheel, and the stop bar i^2 is locked, so as to allow the carriage to automatically feed from one lever 5 J to the next. The operator now moves the slide P No. 5 inwardly, 5 being the first figure of the multiplicand, to a locked position and thereby automatically releases the slide P No. 1 which was in a locked position.

10 This inward movement of the slide P No. 5 arranges its pins R respectively below the front bar s^7 of each wing S. The key lever No. 2 is then depressed which causes the wing S attached to No. 2 key lever to de-

15 press pin R, No. 10, below the same and move the stop bar m No. 10 and cause the lever J of the units wheel to turn the latter a distance of 10 teeth, thereby registering zero on the units wheel and 1 on the tens 20 wheel. The key lever 6 is next depressed causing its wing S to depress pin No. 30 and move stop bar m No. 30 across the path of the pawl arm of the tens wheel, and the lever J of the tens wheel to move the latter a distance of thirty teeth in addition to the one already registered. This movement of 25 the tens wheel causes the hundreds wheel to move a distance of three teeth so that the dials will now indicate 310 which is the product of 62 multiplied by 5. The operator now returns the carriage H to the units spring bar J and moves the slide P No. 3, corresponding to the second figure of the multiplicand, into a locked position thereby 30 releasing slide P No. 5. This arranges all the pins R of the slide P No. 3 below the various actuating bars s^7 of the wings S. The operator now depresses the space key I^2 so that the next figure will stand in the 35 tens column, or rather be registered on the tens wheel. The key lever No. 2 is then depressed which causes the pin R No. 6 to be depressed, so as to move the stop bar m No. 6 and the spring arm J to turn the tens wheel a distance of six teeth, so that the dial of 40 this wheel will indicate 7. The operator now depresses key lever No. 6 which causes pin R No. 18 to be depressed and move the stop bar m No. 18 into the path of the pawl 45 arm of the hundreds wheel, and the spring lever J to move this wheel a distance of eighteen teeth in addition to the three registered. This movement of the hundreds wheel causes its dial to indicate 1 and the 50 dial of the thousands wheel to indicate 2, the latter having been moved two teeth by the cam arm of the hundreds wheel. The four dials will now indicate the product 2170.

55 60 I claim as my invention:

1. The combination of a series of registering wheels, pivotal supporting means for said registering wheels, a series of keys, supporting means for said keys independent of

the said supporting means of the registering 65 wheels, means whereby any one of said keys may actuate any one of said registering wheels, and a series of universal stop members adapted to arrest the movement of any one of said registering wheels. 70

2. The combination of a series of number keys, supporting means for said number keys, a series of registering wheels, supporting means for said registering wheels independent of the supporting means of said 75 number keys, said registering wheels being capable of operative movements but incapable of movements in the direction of their axes, with relation to said number keys, actuators for said registering wheels, a coupling 80 device adapted to be successively interposed between said actuators and said number keys for bringing the registering wheels successively under the control of said number keys, and means independent of said number keys for driving said coupling device. 85

3. In a calculating machine the combination of a series of number keys, supporting means for said number keys, a series of registering wheels, supporting means for said 90 registering wheels independent of the supporting means of said number keys, said registering wheel's being capable of operative movements, but incapable of movement in the direction of their axes with relation to 95 said number keys, a stop device for said registering wheels controlled by said number keys, and a coupling device adapted to move transversely with relation to said registers and to be operated by any one of said number keys. 100

4. In a calculating machine the combination of a series of number keys, supporting means for said number keys, a series of registering wheels, supporting means for 105 said registering wheels independent of the supporting means of said number keys, a coupling member which is capable of being interposed successively between the series of number keys and the different registering 110 wheels, a spring for moving said coupling member forwardly, means independent of said number keys for straining said spring, and means for permitting said coupling member to advance one step at a time under 115 the action of said spring upon depressing the key levers successively.

5. The combination of a series of keys, a series of registering wheels, a rocking frame operated by said keys and whereby 120 said keys can be successively connected with for controlling said registering wheels, and a series of transversely movable stops simultaneously operated by said keys whereby the movement of any one of said registering 125 wheels may be arrested.

6. In a calculating machine the combination of a series of number keys, supporting

means for said number keys, a series of registering wheels, supporting means for said registering wheels independent of the supporting means of said number keys, said 5 registering wheels being capable of operative movements, but incapable of movement in the direction of their axes with relation to said number keys, a stop device for said registering wheels controlled by said number keys, a carriage interposed between said registers and number keys, and an escapement mechanism operated by said keys and adapted to control the movement of said carriage for bringing the number keys in 10 operative relation to successive registers upon the depression of any one of said number keys.

7. In a calculating machine the combination of a series of number keys, supporting 20 means for said number keys, a series of registering wheels, supporting means for said registering wheels independent of the supporting means of said number keys, said registering wheels being capable of operative movements but incapable of movement in the direction of their axes with relation to said number keys, a stop device for said registering wheels controlled by said number keys, a carriage, an escapement mechanism, and a rocking frame operated by said 25 number keys to actuate said escapement mechanism for controlling the movement of the carriage for bringing the number keys in operative relation to successive registering wheels upon the depression of any one of said number keys.

8. In a calculating machine the combination of a series of number keys, a support 40 for said number keys, a series of registering wheels, a support for said registering wheels independent of the support of said number keys, said registering wheels being capable of operative movements but incapable of movement in the direction of their axis with 45 relation to said number keys, a stop device for said registering wheels controlled by said number keys, a vibrating frame adapted to be operated by any one of said number keys, a movable carriage, and a rack and 50 pawl escapement mechanism adapted to be operated by said frame upon the depression of a key and operating to bring the registering devices successively under the control of the number keys.

55 9. The combination of a series of registering wheels, a series of number keys for actuating said registering wheels, a coupling device for connecting said series of number keys with any one of said registering wheels, an actuating key which may be actuated to 60 shift said coupling device step by step without actuating said registering wheels, a vibrating frame, connections between said vibrating frame and said number keys

whereby said frame may be vibrated to shift 65 said coupling device by the operation of any one of said number keys, and separate actuating means which may be operated to shift said coupling device independent of said vibrating frame.

10. The combination of a series of registering wheels, a series of number keys for actuating said registering wheels, a coupling device for connecting said series of number keys with any one of said registering wheels, 70 an actuating key which may be actuated to shift said coupling device step by step without actuating said registering wheels, a vibrating frame, connections between said vibrating frame and said number keys 75 whereby said frame may be vibrated to shift said coupling device by the operation of any one of said number keys, and a separate actuating key and connections independent of said vibrating frame which may 80 be operated to shift said coupling device step by step.

11. The combination of a series of registering wheels, a series of number keys, a carriage interposed between said wheels and 90 keys, an escapement mechanism operated by said keys and adapted to control the movement of the carriage for bringing the number keys in operative relation to successive registering wheels upon the depression of 95 any one of said number keys, and means settable at will for arresting the escapement movement of the carriage and permitting repeated accumulations on the same registering wheel.

12. The combination with a registering wheel provided with ratchet-teeth, and a pawl support carrying a pawl engaging with said teeth, of a single stop which is movable into the path of said pawl support 100 for arresting the movement thereof and also constructed to engage said pawl for locking the same in engagement with said ratchet teeth, substantially as set forth.

13. The combination with a registering 110 wheel provided with ratchet teeth and a pawl arm carrying a pawl engaging with said teeth, of a key lever whereby the pawl arm is actuated to rotate the registering wheel, a fixed stop bar adapted to arrest the movement of the pawl arm in one direction, and a stop bar made movable transversely of the registering wheel and actuated by said key lever to arrest the movement of the pawl arm and registering wheel in the opposite direction, substantially as set forth.

14. In a calculating machine, the combination with a registering wheel provided with ratchet teeth, and a pawl arm carrying a pawl engaging with said ratchet teeth, of 115 a series of key levers either of which is adapted to actuate said pawl arm and rotate the registering wheel, and a separate 120

- movable stop for each key lever, whereby the movement of the pawl arm and registering wheel is arrested upon depressing either one of said key levers, substantially as set forth.
15. In a calculating machine, the combination with a registering wheel provided with ratchet teeth and a pawl arm carrying a pawl engaging with said ratchet teeth, of a rock lever connected with said pawl arm, a vertically movable member adapted to contact with said rock lever, and key levers whereby the vertically movable member and rock lever are actuated to rotate the pawl arm and registering wheel, substantially as set forth.
16. In a calculating machine, the combination with a series of registering wheels having ratchet teeth and a series of pawl arms engaging with said teeth, of rock levers connected with said pawl arms, a vertically movable frame, a carriage supported upon said frame and adapted to contact with said rock levers, and a key lever whereby the carriage is raised to contact with said rock levers and rotate the registering wheels, substantially as set forth.
17. In a calculating machine, the combination with a series of registering wheels having ratchet teeth and pawl arms engaging with said teeth for rotating said wheels, of rock levers connected with said pawl arms, a vertically movable frame, a carriage supported on said frame and adapted to contact with said levers, mechanism whereby said carriage is moved upon said frame, and a key lever whereby said frame is actuated, substantially as set forth.
18. In a calculating machine, the combination with a series of registering wheels having ratchet teeth and pawl arms engaging with said teeth for rotating said wheels, of rock levers connected with said pawl arms, a vertically movable frame, a carriage supported on said frame and adapted to contact with said levers, mechanism whereby said carriage is moved upon said frame, a key lever connecting with said frame, and a stop whereby the movement of the carriage upon said frame is arrested upon releasing the key lever, substantially as set forth.
19. In a calculating machine, the combination with a series of registering wheels provided with ratchet teeth and pawl mechanism engaging with said teeth for actuating said wheels, of rock levers connected with said pawl mechanism, a vertically movable frame, a carriage movable transversely upon said frame and adapted to contact with said rock levers, mechanism whereby said carriage is moved upon said frame, a stop mechanism connected with said carriage and adapted to limit the movement of the carriage upon the frame, and a series of key levers whereby the carriage frame is actuated upon depressing any one of said key levers, substantially as set forth.
20. In a calculating machine, the combination with a vertically movable frame and a carriage supported upon said frame, of a shifting lever attached to said carriage and adapted to move the carriage transversely upon the supporting frame, a stop device connected with said carriage, and a series of key levers connected with said movable frame and adapted to release the carriage from said stop device, substantially as set forth.
21. In a calculating machine, the combination with a vertically movable carriage frame and the carriage supported thereon, of a shifting lever adapted to move said carriage transversely upon said frame, a pawl connected with the carriage and connected with fixed stops secured to the carriage frame, a movable stop bar also engaging with said pawl, and a key lever engaging with the carriage frame and adapted to release said carriage from either the teeth of said carriage frame or from said movable stop bar, substantially as set forth.
22. In a calculating machine, the combination with the vertically movable frame provided with a transverse bar having teeth i^4 , and a carriage supported upon said frame and provided with a pawl I engaging against said teeth, of a shifting lever H' attached to the carriage and provided with an actuating spring whereby the pawl I is held against the teeth i^4 , a key lever whereby the movable frame and carriage are raised, and a stop bar i^2 adapted to release the pawl I when the carriage is lowered and permit the carriage to be moved by the shifting bar H' , substantially as set forth.
23. In a calculating machine, the combination with the vertically movable frame provided with a transverse bar g having teeth i^4 , and a carriage supported upon said frame and provided with a pawl I engaging with said teeth, of a shifting lever H' attached to said carriage and provided with an actuating spring whereby the carriage is moved, a space bar adapted to engage with the pawl I, and a key lever whereby the space bar is actuated and the carriage released from said teeth, substantially as set forth.
24. The combination with a series of registering wheels and a series of key levers adapted to rotate said wheels, of stop bars adapted to arrest the movement of said wheels, transverse slides provided with movable pins connected with said stop bars, and mechanism connecting said pins with the key levers, whereby the movement of a key lever will actuate one of said pins and the

stop bar connected therewith and arrest the movement of a registering wheel, substantially as set forth.

25. In a calculating machine, the combination with a series of registering wheels and a series of key levers for rotating said wheels independently of each other, of a series of movable stop bars arranged radially around said wheels and adapted to arrest the movement of either of said wheels, transverse slides provided with pins connected with said movable stop bars, and mechanism connecting said pins with the key levers, whereby the movement of a key lever will 10 actuate one of said pins and the stop bar connected therewith and arrest the movement of the registering wheel, substantially as set forth.

26. In a calculating machine, the combination with the registering wheels B provided with ratchet teeth and detent pawls engaging with said teeth, of pawl arms mounted on the shaft of the registering wheels and each provided with a pawl engaging with the ratchet teeth of one of said wheels, a fixed stop whereby the pawl arms of all of said wheels are held in a normal position, movable stop bars arranged radially around the peripheries of said registering wheels, flexible levers connected with the pawl arms, and key levers connected with said flexible levers and the movable stop bars, whereby a movable stop bar is actuated to arrest the movement of one of the 30 registering wheels, upon depressing a key lever, substantially as set forth.

27. In a calculating machine the combination with the registering wheels B provided with ratchet teeth and detent pawls engaging with said teeth, of pawl arms mounted on the shaft of the registering wheels and each provided with a pawl engaging with the ratchet teeth of one of said wheels, a fixed stop bar whereby the pawl arms of all of said wheels are held in a normal position, movable stop bars arranged radially around the peripheries of said registering wheels, flexible levers connected with the pawl arms, key levers connected with said 45 flexible levers and movable stop bars whereby a movable stop bar is actuated to arrest the movement of one of the registering wheels upon depressing a key lever, and mechanism connected with said pawl arms and key levers whereby the pawl arms and key levers are returned to their normal position upon releasing the key levers, substantially as set forth.

28. In a calculating machine, the combination with the registering wheels B, provided with ratchet teeth, the pawl arms J^1 carrying pawls engaging with said teeth, and the key levers for actuating said pawl arms, of movable stop bars m actuated by

said key levers and provided with notches 65 m^4 which permit the free movement of the pawl arms past said stop bars and with projections whereby the movement of the pawl arms is arrested when the stop bars are actuated by the key levers, substantially as set 70 forth.

29. In a calculating machine, the combination with the registering wheels B provided with ratchet teeth, the pawl arms J^1 carrying pawls engaging with said teeth, 75 and key levers for actuating said pawl arms, of movable stop bars m actuated by said key levers and provided with notches m^4 which permit the free movement of the pawl arms past said stop bars and with projections m^5 80 whereby the movement of the pawl arms is arrested when the stop bars are actuated by the key levers, and mechanism connected with said stop bars whereby the stop bars are returned to their normal position when 85 the key levers are released, substantially as set forth.

30. In a calculating machine the combination with the registering wheels and the key levers for actuating said wheels, of movable 90 stop bars adapted to limit the movement of said registering wheels, elbow levers connected with said stop bars, wings connected with said key levers, pins interposed between said elbow levers and said wings, and mechanism 95 whereby said pins are thrown into and out of engagement with said wings and elbow levers, substantially as set forth.

31. In a calculating machine, the combination with the registering wheels and the 100 key levers for actuating said wheels, of pivoted wings connected with said key levers, stop bars for limiting the movement of said wheels, elbow levers connected with said stop bars and mechanism connecting said 105 elbow levers with said wings, substantially as set forth.

32. In a calculating machine, the combination with the registering wheels B, the key levers for rotating said wheels, and the 110 stop bars m , of the slides P each provided with a series of pins R, elbow levers T arranged below said pins, pivoted levers connecting said elbow levers with the stop bars, and pivoted wings S arranged above said 115 pins and connected with the key levers, whereby the stop bars are actuated by depressing the key levers, substantially as set forth.

33. In a calculating machine, the combination with a series of transverse slides P each provided with a series of pins R, of pivoted wings S arranged above said pins, and a series of key levers connected with said wings, substantially as set forth. 120

34. In a calculating machine, the combination with a series of transverse slides P each provided with a catch p^6 and a spring 125

17. *z³, of a rock shaft arranged above said slides and provided with pawls p⁵ adapted to engage with the catches p⁶, substantially as set forth.*
18. *35. In a calculating machine, the combination with a registering wheel and a key whereby said registering wheel is controlled, of a series of stops adapted to arrest the movement of said registering wheel and representing the value of said key or any product thereof, and mechanism whereby any one of said stops is controlled by said key.*
19. *36. In a calculating machine, the combination with the registering wheels B provided with ratchet teeth, and a cam disk connected with one of said wheels, of a finger e, spring e⁴ whereby the finger e is held against the cam disk, a pawl arm e¹ connected with the finger e and carrying a pawl engaging 20 with the adjacent registering wheel, a stop pin e⁵ secured to said pawl arm and adapted to engage with the teeth of said registering wheel at the termination of the feeding stroke of the pawl arm e¹, an arm E¹ and a 25 recoil spring e⁷ engaging against said arm and adapted to release the stop pin e⁵ from the registering wheel, substantially as set forth.*
20. *37. In a calculating machine the combination with the carriage frame and the carriage supported thereon and provided with a pawl engaging against stops carried by the carriage frame, of a space bar engaging 30 with said pawl, and adapted to release said pawl from engagement with the stops on the carriage frame, a zero key lever W, a rock shaft connected with the zero key lever, and a lifting bar w⁷ connecting the rock-shaft with the space bar, whereby the latter is actuated to release the carriage pawl upon depressing the zero lever, substantially as set forth.*
21. *38. In a calculating machine, the combination with the carriage frame provided 35 with teeth i⁴, and a carriage supported upon said frame and provided with a pawl I engaging against said teeth, of a movable stop bar i² provided with stops i¹ arranged in advance of the teeth i⁴ when the stop bar i² is moved inwardly, a locking catch engaging 40 against said stop bar whereby the latter is held in a locked position, and a spring whereby the stop bar is moved outwardly with its stops in rear of the teeth i⁴ when 45 said stop bar is released, substantially as set forth.*
22. *39. In a calculating machine the combination with the carriage frame and the carriage supported thereon, and provided with 50 a pawl I, of a movable stop bar i² provided with stops i¹ against which the pawl I engages, a space bar whereby the pawl I is released from the stops i¹, a zero key lever W, a rock shaft connected with said zero key 55 lever, a lifting bar connected with said rock*
- lever and with the movable stop bar i², a nose or projection formed on said shifting bar and engaging with the space bar when the stop bar is in a locked position whereby the space bar is actuated when said zero lever is depressed, substantially as set forth. 70
23. *40. In a calculating machine, the combination with the carriage frame and the carriage supported thereon, and provided with a pawl I, of a movable stop bar i² provided 75 with stops i¹ against which the pawl I engages, a space bar I¹ adapted to release the pawl I from said stops, a zero key lever W, a rock shaft w⁵ connected with said key lever, a lifting bar connected with said rock 80 lever and with the stop bar i², a lug w⁹ formed on said lifting bar and engaging under a projection on the space bar whereby the latter is actuated from the zero key lever, and mechanism connected with the stop bar 85 i² whereby the space bar is automatically disconnected from the key lever by the movement of the stop bar i², substantially as set forth.*
24. *41. The combination of a plurality of registers, means for carrying from each lower to its next higher register, a plurality of number keys, connections whereby any one of said number keys may drive one of said registers, and a separate stop shoulder 90 for each of said number keys and controlled thereby for limiting the movement of the driven register.*
25. *42. The combination of a plurality of registers, means for carrying from each lower 100 to its next higher register, a set of number keys, connections whereby any one of said number keys may drive any one of said registers, and a separate stop shoulder for each of said number keys and controlled thereby 105 for limiting the movement of the driven register.*
26. *43. The combination of a plurality of registers, means for carrying from each lower 110 to its next higher register, a set of number keys, connections whereby any one of said number keys may drive any one of said registers, a series of stops for each of said registers, and means whereby any one of said number keys may cause one of said stops 115 to control any one of said registers.*
27. *44. The combination of a plurality of registers, means for carrying from each lower to its next higher register, a set of number keys, connections whereby any one of said number keys may drive any one of said registers, and whereby the driving influence of said number keys may be automatically shifted to successive registers, and a separate stop shoulder for each of said number keys 120 and controlled thereby for limiting the movement of the driven register.*
28. *45. The combination of a plurality of registers, means for carrying from each lower 125 to its next higher register, a set of number keys, connections whereby any one of said number keys may drive any one of said registers, and whereby the driving influence of said number keys may be automatically shifted to successive registers, and a separate stop shoulder for each of said number keys 130 and controlled thereby for limiting the movement of the driven register.*

- keys, connections whereby any one of said number keys may drive any one of said registers, and whereby the driving influence of said number keys may be automatically shifted to successive registers, and a series of stop shoulders for each of said registers for controlling movement thereof. 5
46. The combination of a series of registers, a number key, connections whereby any one of said registers may be propelled to rotate by said number key, and a separate stop shoulder for each of said registers, which may be controlled by said number key so that the movement of any one of said registers may be arrested. 10
47. The combination of a series of registers, a series of number keys, connections whereby any one of said registers may be controlled by any one of said number keys, 20 and a separate stop device for each of said registers, which may be actuated by any one of said number keys so that the movement of any one of said registers may be arrested. 25
48. The combination of a series of registers, a separate actuator for each one of said registers, a series of stops for each actuator, a number key, and means whereby said number key may control any one of said actuators to transmit motion to its register. 30
49. The combination of a series of registers, a separate actuator for each one of said registers, a series of stops for each actuator, a series of number keys, and means whereby any one of said number keys may be connected with any one of said actuators to transmit motion to its register. 35
50. The combination of a plurality of registers, a plurality of number keys, a plurality of actuators, a plurality of stops, and 40 mechanism co-operative with said keys and said actuators and said stops whereby the power applied to operate one of said number keys simultaneously drives and actuates one of said registers and actuates one of said 45 stops. 51. The combination of a registering wheel provided with teeth, an actuator carrying a pawl engaging with said teeth, number keys constructed to have equal movement, and intermediate mechanism operated by said number keys whereby said actuator is made to actuate said registering wheel. 50
52. The combination of a series of registers provided with teeth and each provided 55 with an actuator carrying a pawl engaging with said teeth, number keys, and intermediate mechanism operated by said number keys whereby any one of said number keys may control any one of said actuators to actuate 60 its register. 53. The combination of a registering mechanism provided with teeth and an actuator carrying a pawl engaging with said teeth, number keys and intermediate mechanism operated by said number keys whereby 65
- said actuator is made to actuate said register, and a stop mechanism controlled by said number keys for arresting the movement of said register. 54. The combination of a series of registers provided with teeth and each provided with an actuator carrying a pawl engaging with said teeth, number keys and intermediate mechanism operated by said number keys whereby any one of said number keys may cause any one of said actuators to actuate its register, and a stop mechanism controlled by said number keys for arresting the movement of said register. 70
55. The combination with a set of registers, supporting means for said registers, a set of number keys for controlling said registers, supporting means for said number keys independent of the support of said registers, said registers being capable of operative movements but incapable of bodily movements in the direction of their axes with relation to said set of number keys, of means whereby the control of said registers by said number keys may be automatically 75 shifted from one register to another, and a stop device controlled by said number keys 80 for controlling said registers. 85
56. The combination with a set of registers, supporting means for said registers, a set of number keys for controlling said registers, supporting means for said number keys independent of the supporting means of said registers said registers being capable of operative movements but incapable of bodily movements in the direction 90 of their axes with relation to said set of number keys, of a movable connecting member, automatic means for imparting a step by step motion to said connecting member 95 upon each operation of any one of said number keys whereby the control of said registers by said number keys is shifted from one register to another, and a set of stop shoulders for each of said number keys for 100 controlling the movements of said registers. 105
57. The combination with a set of registers, a set of number keys for controlling said registers, of a movable connecting member between said registers and said number keys, automatic means for imparting a step by step motion to said connecting member upon each operation of any one of said number keys whereby the control of said registers by said number keys is shifted from one register to another, and means for rendering inoperative said automatic means 110 for imparting a step by step motion to said connecting means. 115
58. The combination of a registering wheel 120 provided with teeth and a pawl support carrying a pawl engaging with the teeth of the registering wheel, a key whereby the pawl support is actuated to rotate the registering wheel, and a stop actuated by said 125 130

- key and adapted to simultaneously arrest the movement of said pawl support and lock said pawl in engagement with said registering wheel.
5. 59. The combination of a plurality of registering wheels each provided with teeth and with a pawl support carrying a pawl engaging with the teeth of its registering wheel, a plurality of number keys whereby a pawl support may be actuated to rotate its registering wheel, and a plurality of stops any one of which may be controlled by one of said number keys to simultaneously arrest the movement of said pawl support and lock said pawl in engagement with its registering wheel.
10. 60. The combination of a plurality of registering wheels, a support for said registering wheels, a plurality of number keys, a support for said number keys independent of the support for said registering wheels, a stop device, and automatic means whereby the same stop device may be made to control different registers.
15. 61. The combination with a series of registers, supporting means therefor, a series of number keys, supporting means for said number keys independent of the supporting means for said registers, of a series of movable stop bars surrounding said registers and adapted to arrest the movement of any one of said registers, and means whereby said registers are controlled by said number keys.
20. 62. The combination with a series of registers, supporting means therefor, a series of number keys, supporting means for said number keys independent of the supporting means for said registers, of a series of movable stop bars surrounding said registers and adapted to arrest the movement of any one of said registers, and means whereby said number keys may actuate said stop bars to control said registers and whereby said number keys may drive and actuate said registers.
25. 63. The combination with a series of registers, supporting means therefor, a series of number keys, supporting means for said number keys independent of the supporting means for said registers, of a series of movable stop bars surrounding said registers and adapted to arrest the movement of any one of said registers, and means whereby any one of said number keys may control through the medium of said stops any one of said registers.
30. 64. The combination with a series of registers, supporting means therefor, of a series of number keys, supporting means for said number keys independent of the supporting means for said registers, and a series of movable stop bars extending across said registers and controlled by said number keys so that any one of said stop bars
35. may control the movements of any one of said registers.
65. The combination of a register having equally spaced engaging elements, an actuator carrying an engaging member engaging with said engaging elements for actuating said register, and a stop mounted on a stationary part of the machine and adapted to be moved into the path of the actuator and engage said engaging member to lock it in engagement with the engaging elements of said register.
70. 66. The combination of a register having equally spaced engaging elements, an actuator carrying an engaging member engaging with said equally spaced engaging elements for actuating said register, and a series of stops mounted on a stationary part of the machine any one of which is adapted to be moved into the path of the actuator and engage said engaging member to lock it in engagement with the equally spaced engaging elements.
75. 67. The combination of a series of registers having equally spaced engaging elements, each register provided with an actuator carrying an engaging member to engage with the engaging elements of its register, and a series of stops adapted to be moved into the path of the actuators to arrest their movement and lock their engaging members in engagement with the equally spaced engaging elements of their respective registers.
80. 68. The combination of a register having equally spaced engaging elements, an actuator carrying an engaging member engaging with said equally spaced engaging elements for actuating said register, a stop, and a number key connected with said actuator and said stop, whereby the actuator is moved to actuate said register and said stop is moved into the path of said actuator to limit its movement and engage said engaging member to lock it in engagement with the equally spaced engaging elements of the register.
85. 69. The combination of a register having equally spaced engaging elements, an actuator carrying an engaging member engaging with the equally spaced engaging elements of said register, a series of number keys, a separate stop for each number key, and connections whereby the operation of any one of said number keys operates to cause said actuator to move said register and cause its respective stop to limit the movement and to lock said engaging member in engagement with the equally spaced engaging elements of said register.
90. 70. The combination of a series of registers having equally spaced engaging elements, each register provided with an actuator carrying an engaging member to engage with the engaging elements of its register, a plurality of number keys for
95. 100. 105. 110. 115. 120. 125. 130.

actuating said registers, and a plurality of stops actuated by said number keys for controlling said registers and operating to lock said engaging members in engagement with 5 the equally spaced engaging elements of said registers.

71. The combination of a series of registers having equally spaced engaging elements, each register provided with an actuator carrying an engaging member to engage with the engaging elements of its register, a set of number keys, connections whereby any one of said number keys may actuate any one of said registers, and a plurality of sets of stops controlled by said number keys for controlling said registers and operating to lock said engaging members in engagement with the equally spaced engaging elements of said registers.

72. The combination of a registering mechanism supporting means therefor, an actuator provided with a projection, a series of stop bars provided with notches for the passage of said projection on said actuator, 25 a series of number keys each operatively connected to one of said stop bars, to shift it into the path of the projection on said actuator and arrest the latter, and supporting means for said number keys independent 30 of the supporting means for said registering mechanism.

73. The combination of a registering mechanism, an actuator provided with a projection, a series of stop bars provided 35 with notches for the passage of said projection on said actuator, a series of number keys, and means whereby any one of said keys may be connected to one or another of said stop bars to shift it into the path 40 of the projection on said actuator and arrest the latter at a position representing the number of the key or a multiple of said number.

74. The combination of a registering mechanism provided with teeth, an actuator provided with a pawl to engage said teeth, a fixed stop to arrest the movement of said actuator in one direction, and a plurality of stops positioned at different distances from said fixed stop for arresting the movements of said actuator in another direction.

75. The combination of a registering mechanism provided with teeth, an actuator provided with a pawl to engage said teeth, a plurality of number keys, a fixed stop for arresting the movement of said actuator in its normal position, and a series of stops arranged at different distances from 55 said fixed stop and actuated by said number keys for controlling the accumulating movements of said registering mechanism.

76. The combination with a plurality of registers each provided with teeth, a plurality of actuators each provided with a

pawl to engage the teeth of its respective register, of a fixed stop shoulder for each of said actuators for arresting their movement in one direction, and a plurality of stops positioned at different distances from 70 said fixed stop for arresting the movements of said actuators in the opposite direction.

77. The combination with a plurality of registers each provided with teeth, a plurality of actuators each provided with a pawl to engage the teeth of its respective register, of a fixed stop shoulder for each of said actuators for arresting its movement in one direction, a plurality of stops positioned at different distances from said fixed 80 stop for arresting the movements of said actuators in the opposite direction, and number keys for controlling said stops.

78. The combination of a plurality of registers, supporting means for said registers, 85 a different series of stops for each register, a set of number keys, supporting means for said number keys independent of the supporting means of the registers, and means whereby any one of said number keys may 90 simultaneously actuate a stop and any one of said registers.

79. The combination of a series of number keys, a series of registering wheels, supporting means for said number keys, supporting means for said registering wheels independent of the supporting means for said number keys, a plurality of sets of stops controllable by said number keys for controlling said registering wheels, and automatic means whereby the control of said 95 series of number keys can be successively shifted from one set of stops to another set of stops.

80. The combination of a series of number keys, a series of registering wheels, supporting means for said number keys, supporting means for said registering wheels independent of the supporting means for said number keys, a plurality of sets of stops controllable by said number keys for controlling said registering wheels, and a carriage movable transversely with relation to said number keys whereby the control of 100 said series of number keys can be automatically successively shifted from one set of stops to another set of stops.

81. The combination of a series of number keys, a series of registering wheels, supporting means for said number keys, supporting means for said registering wheels independent of the supporting means for said number keys, a plurality of sets of stops controllable by said number keys for controlling said registering wheels, and automatic means whereby the control of 110 said series of number keys is successively shifted from one set of stops to another set of stops upon the operation of any of said 115 keys.

82. The combination of a series of number keys, a series of registering wheels, supporting means for said number keys, supporting means for said registering wheels independent of the supporting means for said number keys, a plurality of sets of stops controllable by said number keys for controlling said registering wheels, and a carriage movable transversely with relation to said number keys whereby the control of said series of number keys can be automatically successively shifted from one set of stops to another set of stops upon the operation of any of said keys.
83. The combination of a series of number keys, a series of registering wheels, a plurality of sets of stops controllable by said number keys for controlling said registering wheels, automatic means whereby the control of said series of number keys can be successively shifted from one set of stops to another set of stops, and means for rendering said shifting means operative and inoperative.
84. The combination of a series of number keys, a series of registering wheels, supporting means for said number keys, supporting means for said registering wheels independent of the supporting means for said number keys, a plurality of sets of stops controlled by said number keys for controlling said registers, and mechanism whereby one after another of said registers may be brought under the control of said stops.
85. The combination of a series of number keys, a series of registering wheels, supporting means for said number keys, supporting means for said registering wheels independent of the supporting means for said number keys, a plurality of sets of stop devices controlled by said number keys for controlling said registers, and mechanism controlled by said number keys whereby the control of said stop devices can be shifted from one registering wheel to another.
86. The combination of a series of number keys, a series of registering wheels, supporting means for said number keys, supporting means for said registering wheels independent of the supporting means for said number keys, a plurality of sets of stops, and a carriage having a transverse movement with relation to said registering wheels whereby the controlling effect of said sets of stops on said registering wheels is shifted from one registering wheel to another.
87. The combination of a series of number keys, a series of registering wheels, supporting means for said number keys, supporting means for said registering wheels independent of the supporting means for said number keys, stop devices, and mechanism whereby one after another of said registers may be automatically brought under the control of said stop devices.
88. The combination of a series of number keys, a series of registering wheels, supporting means for said number keys, supporting means for said registering wheels independent of the supporting means for said number keys, stop devices, mechanism whereby one after another of said registers may be automatically brought under the control of said stop devices, and means for rendering said mechanism operative or inoperative.
89. The combination of a plurality of registers, supporting means for said registers, a plurality of actuators, a plurality of number keys, supporting means for said number keys independent of the supporting means of the registers, and means whereby any one of said number keys may cause any one of said registers to be actuated by one of said actuators.
90. The combination of a plurality of registers, supporting means for said registers, an actuator for each register, a plurality of number keys, supporting means for said number keys independent of the supporting means of the registers, and means whereby any one of said number keys may cause any one of said registers to be actuated by its actuator.
91. The combination of a plurality of registers, supporting means for said registers, a plurality of actuators, a plurality of number keys, supporting means for said number keys independent of the supporting means of the registers, and a plurality of sets of stops any one of which may be controlled by one or another of said number keys for controlling the actuating movements of any one of said actuators.
92. The combination of a plurality of registers, supporting means for said registers, a plurality of actuators, a plurality of number keys, supporting means for said number keys independent of the supporting means of the registers, and a separate series of stops for each register and correlated with said number keys so that any of said number keys may control any of said registers through the medium of said stops.
93. The combination of a plurality of registers, supporting means for said registers, a plurality of actuators, a plurality of number keys, supporting means for said number keys independent of the supporting means of the registers, a separate series of stops for each register, and means whereby any one of said number keys may control any one of said registers.
94. The combination of a plurality of registers, supporting means therefor, a plurality of number keys, supporting means for said number keys independent of the supporting means of the registers, a plurality of sets of stops, a plurality of actuators, and connections between said number keys and said stops and said actuators whereby the

registrations on any one of said registers may be controlled by any one of said number keys.

95. The combination with a plurality of registering wheels, an actuator for each registering wheel pivoted in axial alinement therewith, supporting means for said registering wheels and their actuators, of a plurality of number keys, and supporting means upon which said number keys are mounted and which is independent of the supporting means of the registering wheels.

96. The combination of a plurality of registering wheels, supporting means for said registering wheels, a set of number keys, supporting means for said number keys independent of the supporting means of said registering wheels, means whereby any one of said number keys may control any one of said registering wheels, and a plurality of reciprocating actuators controlled by said number keys, and constructed to actuate said registers when said actuators are moved in one direction and to move without actuating said registers when said actuators are moved in the opposite direction.

97. The combination of a plurality of registering wheels, supporting means for said registering wheels, a set of number keys, supporting means for said number keys independent of the supporting means of said registering wheels, means whereby any one of said number keys may control any one of said registering wheels, a plurality of reciprocating actuators controlled by said number keys, means operating to and constructed to actuate said registers when said actuators are moved in one direction and to move without actuating said registers when said actuators are moved in the opposite direction, and a stop device controlled by said number keys for controlling said registering wheels.

98. The combination of a plurality of registering wheels, supporting means for said registering wheels, a set of number keys, supporting means for said number keys independent of the supporting means of said registering wheels, means whereby any one of said number keys may control any one of said registering wheels, a plurality of reciprocating actuators controlled by said number keys means operating to and constructed to actuate said registers when said actuators are moved in one direction and to move without actuating said registers when said actuators are moved in the opposite direction, a plurality of sets of stops for controlling said registering wheels, and means whereby different sets of stops can be successively brought under the control of said number keys with relation to said registering wheels.

99. The combination of a series of registering wheels, a series of number keys any

one of which may control any one of said registering wheels, and actuating means which normally exerts no driving pressure and which comprises a driving member, said means being operable for rotating said registering wheels.

100. The combination of a series of number keys, a series of registering wheels capable of operative movements but incapable of bodily transverse movement with relation to said number keys, an element whereby any one of said number keys may control any one of said registering wheels, a plurality of actuators which normally exert no driving pressure, and means coöperative with said element for causing any of said actuators to drive for the purpose of actuating any of said registering wheels.

101. In a calculating machine, the combination of a registering mechanism, stops for controlling said registering mechanism, keys for controlling said stops, a carriage controllable by said keys for shifting the control of said stops with relation to said registering mechanism, and means for preventing movement of said carriage until a stop is set for controlling said registering mechanism.

102. In a calculating machine, the combination of a registering mechanism, operating mechanism comprising a plurality of actuators for operating said registering mechanism, stop mechanism movable for controlling said registering mechanism, and means for preventing operation of said registering mechanism until said stop mechanism has been moved a predetermined distance.

103. The combination of a plurality of registers, a controlling element for said registers, actuators for said registers, and means for preventing said actuators from actuating said registers before said controlling element has been properly operated.

104. The combination of a plurality of registers, a controlling element for said registers, actuators for said registers, locking means for normally locking said actuators against operation, and a releasing element for releasing said actuators from said locking means to permit the operation of said actuators.

105. The combination with a registering mechanism and a plurality of number keys for actuating said registering mechanism, of means associated with said number keys for rendering said number keys ineffective with relation to said registering mechanism when any number key has been only partly moved the required distance.

106. In a calculating machine, the combination of a register, an actuator therefor, a key for actuating said actuator, a second key for actuating said actuator, a stop device adapted to coöperate with said actuator.

ator and controllable by the first said key for controlling movement of said register, and a stop device independent of the first said stop device and adapted to coöperate with said actuator and controllable by said second key for controlling movement of said register.

107. In a calculating machine, the combination with a series of keys, an actuator actuated thereby, and means for arresting said actuator when it is moved a distance proportioned to the value of the key struck, such means consisting of a shoulder or tooth on the actuator and a plurality of movable stops each adapted to engage the shoulder or tooth and controlled by different keys.

108. In a calculating machine, the combination of a registering device, an actuating element therefor, means for moving the actuating element for causing it to move said registering device into position for registering a predetermined number, and means cooperative with said actuating device for locking said registering device against forward and return movement.

109. In a calculating machine, the combination of a register, an actuator therefor, a plurality of movable stops for limiting the actuating movement of said actuator, a plurality of keys for positioning said movable stops, a fixed stop for limiting the return movement of said actuator to normal position, and means independent of said number keys for locking said actuator in its normal position.

110. In a calculating machine, the combination of a plurality of registers, a carriage operatively related to said registers, a spring for driving said carriage to move, a plurality of number keys for controlling the movement of said carriage and causing said registers to register, means other than said keys for storing power in said spring, and hand controlled means for preventing said keys from affecting said registers.

111. In a calculating machine, the combination of a plurality of registers, a set of settable controlling keys therefor, means whereby the control of any of said keys when set may be shifted with relation to said registers, means for retaining said keys in set position, and means for operating said registers.

112. The combination of a series of number keys, supporting means for said number keys, a series of registering wheels, supporting means for said registering wheels independent of the supporting means of said number keys, means whereby any one of said registering wheels may be controlled by any one of said number keys, and a separate controlling element for each of said number keys for controlling the movements of any one of said registering wheels.

113. The combination with a main actua-

tor and a series of column actuators, of key operated means non-dependent on the movement of said column actuators for connecting any one of said column actuators with said main actuator.

114. The combination with a main actuator and a series of column actuators, of variable connecting means between said main actuator and any one of said column actuators, said variable connecting means being non-dependent on the movement of the column actuators for effecting their connection with said main actuator.

115. The combination with a main actuator and a series of column actuators, of separate variable connections one for each column actuator, and key-controlled means for connecting said column actuators with said main actuator, said means being non-dependent on the movement of said column actuators for effecting their connection with said main actuator.

116. The combination of a plurality of registers; a plurality of controlling keys therefor; a plurality of actuators, one for each register; a universal actuator; and separate variable connections, one for each of the first said actuators, communicating more or less movement from said universal actuator to the first said actuators according to the control of said controlling keys.

117. The combination with a main actuator member and a series of column actuator members, of separate variable connections one for each column, and means whereby said connections may be made operative or inoperative with relation to said main actuator member.

118. The combination of a register wheel, controlling keys therefor, a main actuator member, a column actuator member, and a variable elastic connection between the two actuator members whereby more or less of the movement of the main actuator member may be communicated to the column actuator member for moving said column actuator member according to the control of said controlling keys and thus controlling said register wheel according to the control of said controlling keys.

119. The combination of a numeral wheel provided with equispaced stopping points, an engaging member engaging said points, an actuating member for causing said engaging member to rotate said numeral wheel, and a second actuating member elastically connected to for causing wheel-actuating movement of the first said actuating member.

120. The combination of a series of numeral wheels each provided with equispaced stopping points, a plurality of pawls one for each wheel and adapted for engaging said stopping points, a column actuator member for each column, a main actuator common to all the columns, elastic connections be-

5 between the column actuator members and said main actuator, setting keys for controlling movement of said column actuator members, and a hand-actuated operation-controlling member for controlling operation of said main actuator.

10 121. In a calculating machine, the combination of a plurality of registers, number keys for controlling without actuating said registers, a carriage having a step-by-step movement with relation to said registers, a manually - actuated operation - controlling member for actuating said registers according to the control of said number keys and 15 for causing movement of said carriage, and means for rendering said movement of said carriage by said operation-controlling member effective and ineffective.

20 122. The combination of a plurality of registers, with a plurality of number keys for controlling the accumulation on said registers, and each of said number keys bearing two numbers one of which is the complement of the other.

25 123. The combination of a register, supporting means for said register, a number key, supporting means for said number key independent of the supporting means of said register, and a movable stop bar having 30 a plurality of stop shoulders and controllable by said key for controlling said register.

35 124. The combination of a plurality of registers, a plurality of number keys, and a movable stop bar having a plurality of stop shoulders and which may be actuated by any one of said number keys for controlling the movements of said registers.

40 125. The combination of a plurality of registers, supporting means for said registers, a plurality of number keys, supporting means for said number keys independent of the supporting means of said registers, actuators for actuating said registers, and 45 movable stop bars controlled by said number keys for arresting the movements of said actuators, each stop bar being provided with a plurality of stop shoulders.

50 126. The combination of a plurality of registers, supporting means for said registers, a plurality of number keys, supporting means for said number keys independent of the supporting means of said registers, actuators for actuating said registers, movable 55 stop bars controlled by said number keys for arresting the movements of said actuators and each stop bar being provided with a plurality of stop shoulders, and means cooperative with said keys and actuators for 60 actuating said registers under the controlling effect of said stop bars.

65 127. The combination with a plurality of registers, a supporting means for said registers, a set of number keys, supporting means for said number keys independent of the

supporting means of said registers, and means whereby any one of said number keys may actuate any one of said registers, of a separate stop device for each number key which may be made to control any one of 70 said registers.

128. The combination of a register, supporting means for said register, a number key, supporting means for said number key independent of the supporting means of said 75 register, of means whereby said number key may control said register, said means comprising a stop bar adapted to arrest the movement of said register and mechanism whereby said stop bar is controlled by said 80 number key.

129. The combination with a set of numeral keys, of a series of registers, a movable element by means of which the registers are brought under the control of the 85 numeral keys, a driving element for moving said movable element, said driving element deriving its power from a source other than said keys, and means controlled by said keys for controlling step-by-step movement of 90 said movable element by said driving element to shift the control of said numeral keys from one of said registers to another of said registers.

130. The combination with a set of numeral keys, of a series of registers, a movable element by means of which the registers are brought successively under the control of the numeral keys, a driving element for moving said movable element, means 100 controlled by said keys for controlling step-by-step movement of said movable element by said driving element to shift the control of said numeral keys from one of said registers to another of said registers, and a 105 hand controlled element for moving said movable element in the opposite direction against the power of said driving element and for delivering power to said driving element.

131. The combination of a plurality of setting keys, a lock shoulder for each of said setting keys said lock shoulders being arranged in a row, a locking device having lock shoulders for coöoperating with the lock shoulders of said setting keys and arranged in a row parallel to the row of lock shoulders of said setting keys and normally in their path, and means operable upon the depression of any one of said setting keys to move the lock shoulders of said locking device away from all of said lock shoulders of said setting keys in a direction at an angle to said row of lock shoulders of said setting keys so that any previously locked setting 115 key is released and which means operates to return the lock shoulders of said locking device back to a position to engage the stop shoulder of the depressed setting key for locking it in its operative position.

132. A key-controlled device comprising a
depressible controlling key which is always
rendered effectual when depressed, a second
controlling key which is always rendered
effectual when depressed, and means con-
structed and arranged for so correlating
said keys that when either of said keys is in
its effectual position and the other of said
keys is thereafter moved to its effectual posi-
tion, the key previously effectual is rendered
ineffectual and the key last moved to ef-
fectual position is always rendered effectual.

133. The combination of a row of setting
keys, a stop shoulder for each of said keys
and connected therewith, said stop shoulders
being arranged in a row, a hinged stop de-
vice having a plurality of stop portions en-
gaging said stop shoulders and movable at
an angle to the said row of stop shoulders,
and means whereby when any key of the row
is depressed the stop device is moved to
lock said key in its depressed position and
to release any previously depressed key in
said row.

134. A key-controlled device comprising a
plurality of depressible controlling keys
each of which when depressed is detained
and always rendered effectual exclusively of
the keys not depressed, and means con-
structed and arranged for the purpose of
so correlating said keys that when any one
of said keys is detained in its effectual posi-
tion, the next key thereafter depressed is
always rendered effectual and operates to
release the detained key and thereby render
said detained key ineffectual.

135. The combination of a register, num-
ber keys, means controlled by said number
keys for determining the extent of move-
ment of the register, and means for auto-
matically locking in its operating position
any key depressed and to simultaneously re-
lease any previously locked key, thereby
changing the determination of the extent of
actuation of said register in accordance with
the value of the key last depressed.

136. The combination of a plurality of
registers, a plurality of number keys for
controlling said registers, a carriage having
a transverse movement with relation to said
number keys for shifting the control of said
number keys with relation to said registers,
and means other than said number keys for
driving to move said carriage.

137. The combination of a plurality of
registers, a plurality of number keys for
controlling said registers, a carriage having
a transverse movement with relation to said
number keys and said registers for shifting
the control of said number keys with rela-
tion to said registers, and means other than
said number keys for driving to move said
carriage.

138. The combination of a plurality of

registers, a plurality of number keys for
controlling said registers, a carriage having
a transverse movement with relation to said
number keys and said registers and provided
with an engaging shoulder, a plurality of
actuators for said registers, and means
whereby the same engaging shoulder of said
carriage operates to engage any one of said
actuators for actuating its register upon the
depression of any one of said number keys.

139. The combination of a plurality of
registers, a plurality of number keys, a stop
device, a controlling carriage having a trans-
verse movement with relation to said regis-
ters and number keys, and an escapement
mechanism operated by said keys and adapt-
ed to control movement of said controlling
carriage for rendering the number keys ef-
fective with relation to successive registers
upon the depression of any one or another
of said number keys.

140. In a calculating machine, the combi-
nation of a plurality of accumulators; a
plurality of actuating members, one for
each of said accumulators; a plurality of
pivotally mounted driver members, one for
each of said actuating members; a plurality
of elastic members, one for each of said
driver members and each having one end
connected to its respective one of said driver
members and its other end connected to a
respective one of said actuating members;
and a universal operating frame for oper-
ating said driver members to actuate their
respective actuating members for actuating
said accumulators.

141. The combination of a plurality of
registers, a plurality of number keys, a car-
riage whereby any one of said registers may
be controlled by any one of said number
keys, a spring constructed to exert continu-
ous tension on said carriage in one direc-
tion, means independent of said number
keys for storing power in said spring, and a
detent escapement device for holding said
carriage against movement by said spring
and constructed to be operated by any one
of said number keys for permitting a step
by step movement of said carriage by said
spring.

142. The combination of a series of regis-
tering devices, a series of number keys, a
carriage interposed between said devices and
keys, an escapement mechanism operable by
said keys and adapted to control the move-
ment of the carriage for bringing the num-
ber keys in operative relation to the regis-
tering devices in succession upon the de-
pression of any one of said number keys,
and key-operated means independent of said
number keys for shifting the operative re-
lation of said number keys with respect to
said registering devices.

143. The combination of a plurality of

registers, a plurality of number keys, a carriage having a transverse movement with relation to said number keys, and which operates to enable any one of said number 5 keys to control any one of said registers, a spring for driving said carriage in one direction, means independent of said number keys for storing driving power in said spring, a detent escapement device comprising 10 two members one of which being a pawl and the other a plurality of stops, one of said members being connected with said carriage and being under the tension of said spring and the other connected to a stationary 15 part of the machine for holding said carriage against movement by said spring, and connections between said detent escapement device and said number keys whereby the successive operation of any of said number 20 keys causes said escapement device to permit a step by step movement of said carriage under the power of said spring and cause said number keys to control successive registers.

144. The combination of a plurality of 25 registers, a plurality of number keys, a carriage whereby any one of said registers may be brought into operative relation to said number keys, a track upon which said carriage 30 is mounted to travel back and forth, a spring for driving said carriage in one direction by power derived from a source other than said number keys, a detent escapement device for said carriage, means operating 35 to actuate said escapement device to permit said carriage to move a step under the propelling power of said spring at each depression of any one of said number keys, and a hand controlled carriage returning 40 device mounted on a stationary part of the machine and connected with said carriage for moving said carriage against the tension of said spring.

145. The combination of a series of 45 registers, a series of number keys, means whereby any one of said registers may be controlled by any one of said number keys and comprising actuating means mounted to be capable of operative movements with relation 50 to said registers but incapable of lateral movement with relation to said number keys and an indicating device for indicating the register under control of said number keys.

146. The combination of a series of 55 registers, a series of number keys, means whereby the control of said registers by said number keys may be shifted from one register to another and comprising an actuator 60 mounted on a pivot and capable of operative movements but incapable of movements in the direction of its axis and an indicating device for indicating the register under control of said number keys.

147. The combination of a series of registers, a series of number keys, means whereby the control of said registers by said number keys may be shifted from one register to another and comprising a carriage movable transversely with relation to said number 65 keys and comprising means independent of said number keys for driving to move said carriage and comprising an actuator mounted on a pivot and capable of operative movements but incapable of movements in the direction of its axis and an indicating device, an element of which is movable concomitant with said carriage for indicating the register under control of said number keys.

148. The combination of a series of registers, a separate actuator for each of said registers, a series of number keys, means whereby any one of said number keys may actuate any one of said actuators and comprising a connecting device between said actuators and said number keys, and an indicating device to indicate the register which is operatively connected with the number keys.

149. In a calculating machine, the combination of a series of accumulators of successive arithmetical denominations, a series of number keys, a carriage movable step by step and whereby the control of said number keys may be shifted from one to another of 90 said registers successively, an indicator for indicating the register under the control of said series of keys, means for moving said carriage and indicator and which means derives its power from a source other than 95 through the medium of said keys, and an escapement mechanism controllable by any one of said keys for controlling step by step movement of said carriage and said indicator.

150. The combination of a series of registers, a series of number keys; a shifting element between said registers and said number keys whereby said number keys may control any one of said registers; a driving element 110 which derives its power from a source other than the manipulation of said keys, for driving said shifting element; and means independent of said number keys for controlling the movement of said shifting element from 115 one register to another.

151. The combination of a plurality of registers, a plurality of number keys, a carriage whereby any one of said registers may be brought into operative relation to said number keys, a support upon which said carriage is mounted to move, a spring for driving said carriage in one direction, a detent device for holding said carriage against movement by said spring, a universal element operable by any one of said number keys and correlated with said spring and said detent device for causing a step by step 120 125.

movement of said carriage, for successively operatively connecting said set of number keys to successive registers, and means independent of said universal element to shift 5 said carriage whereby the number keys may be brought into operative relation with different registers.

152. The combination of a series of registers, a series of number keys, a connecting 10 element between said registers and said number keys whereby any one of said number keys may control any one of said registers, a shifting element whereby said connecting element can be shifted to shift the 15 control of said series of number keys from one register to another, a shifting key independent of said number keys to shift said shifting element, a second shifting key, and means whereby said second shifting key may 20 be operatively connected with or disconnected from said shifting element.

153. The combination of a series of registers, a series of number keys, a connecting element between said keys and registers 25 whereby any one of said number keys may control any one of said registers, means whereby the operation of any one of said keys may cause the said connecting element to shift the operative relation of said keys 30 from one of said registers to another, and means whereby the first said means may be made operative or inoperative.

154. The combination of a plurality of registers, a key for controlling any one of 35 said registers, and means for rendering said key ineffective with relation to said registers.

155. The combination with a series of 40 number keys, supporting means for said number keys, of a series of registering wheels, supporting means for said registering wheels independent of the supporting means of said number keys, a plurality of sets of stops, a rocking frame operated by 45 said keys, and mechanism operable by said rocking frame whereby said keys can be brought into operative relation with successive sets of stops for controlling the different registering wheels.

156. In a calculating machine, the combination of a registering mechanism, stops, 50 keys for controlling said registering mechanism through the medium of said stops, a carriage controlled by said keys for shifting the control of said stops with relation to said registering mechanism, and means for preventing movement of said carriage by said keys until said stops are set for controlling said registering mechanism.

157. In a calculating machine, the combination of a registering mechanism, operating mechanism for operating said registering mechanism, stop mechanism movable 55 for controlling said registering mechanism,

and means for preventing operation of said 65 registering mechanism by said operating mechanism until said stop mechanism has been moved from normal position.

158. The combination with a series of registers, a series of number keys, a carriage 70 adapted to be shifted to connect said series of number keys with one or another of said registers, a movable support upon which said carriage is mounted, means whereby said carriage support is normally locked, 75 and means whereby any one of said number keys when actuated may unlock said support.

159. In a calculating machine the combination of a plurality of registers, a plurality 80 of number keys, a movable frame intermediate between said registers and said number keys and locking means for said frame controlled by said number keys.

160. The combination of a plurality of 85 registers, a plurality of number setting devices, means for holding said setting devices in the set position when depressed, means whereby any one of said number keys may be made to control without actuating 90 any one of said registers, and separate hand controlled operating means for actuating said registers.

161. The combination of a plurality of 95 registers; a plurality of number setting keys; a plurality of setting-up elements controllable by said keys; a device for retaining said setting-up elements in set position when set; mechanism coöperating with said setting-up elements, whereby said number keys may control without actuating any 100 of said registers; and a manually-actuated operation-controlling member for actuating said registers.

162. The combination of a plurality of 105 registers of different denominations, a plurality of number keys, a plurality of setting-up devices settable by said number keys for controlling without actuating said registers, a device for retaining said setting-up devices in set position when set, mechanism for causing said setting-up devices and any of 110 said registers to coöperate, and a manually-actuated operation-controlling member for operating said registers.

163. The combination of a plurality of 115 registers of different denominations, a plurality of setting-up devices for controlling without actuating said registers, means for holding said setting-up devices in set position, an element for causing said series of setting-up devices and any of said registers to coöperate, and a manually operable device for actuating said registers.

164. In a key-controlled machine, the combination of a plurality of correlated mechanisms for performing calculations and each constructed to perform a function different 125

from the other of said mechanisms, means for detaining one of said mechanisms in an inoperative position, and a key constructed and arranged to be depressed and to first 5 actuate certain of said mechanisms and thereafter release the detained mechanism from the detaining means and then actuate the released mechanism.

165. The combination of a number setting 10 device, a plurality of registers controlled thereby, automatic means whereby the control of said setting device may be shifted to control without actuating any one of said registers, and a separate hand controlled 15 operating element for actuating said registers.

166. The combination of a plurality of number setting devices, a plurality of registers, means whereby the control of said 10 setting devices may be automatically shifted with relation to said registers and without actuating said registers, and a separate hand controlled operating element for actuating said registers.

167. The combination of a plurality of registers, stops for said registers, setting keys, automatic means whereby through the medium of said stops any one of said setting keys may control without actuating any 15 of said registers, and means which may be operated independent of said setting keys for actuating said registers.

168. The combination of a plurality of registering wheels, a plurality of number 20 keys, a stop device controllable by said number keys for controlling said registering wheels, a carriage for shifting the control of said stop device with relation to said registering wheels, connections from said 25 keys to said carriage, driving means controllable by said number keys for driving said carriage, and means other than said keys and their said connections for delivering power to said driving means.

169. The combination of a plurality of registers, stops for said registers, setting keys, means whereby through the medium of said stops any one of said setting keys may be made to successively control without 30 actuating any one of said registers through the medium of said stops, and means which may be operated independent of said setting keys for actuating said registers.

170. The combination of a plurality of 35 registers, a plurality of sets of stops, setting keys, means whereby one or another of said sets of stops may be controlled by any one of said setting keys for controlling without actuating said registers, and means 40 independent of said setting keys which means may be operated for actuating said registers.

171. The combination of a plurality of registers, a plurality of sets of stops, setting

keys for controlling one or another of said 65 sets of stops so as to control without actuating said registers, and means independent of said setting keys, whereby said registers are actuated and whereby successive settings of said setting keys may be made to cause successive sets of stops to control successive registers. 70

172. The combination of a plurality of registers, a plurality of sets of controlling elements, setting keys, means whereby one 75 or another of said sets of stops may be set by any one of said setting keys for controlling without actuating said registers, and means independent of said setting keys which may be operated for actuating said 80 registers.

173. The combination of a plurality of registers, a plurality of number setting keys, a plurality of stops for each of said 85 number setting keys and controlled thereby for controlling without actuating said registers, and independent means which may be operated after said setting mechanism has been set to actuate said registers for effecting registrations thereon according to the setting 90 of said setting mechanism.

174. The combination of a plurality of registers, a plurality of number setting keys, a plurality of stops for each of said number setting keys and controlled thereby for controlling without actuating said registers, and independent means which may be operated after said setting mechanism has been set to actuate said registers for effecting registrations thereon according to the setting 100 of said setting mechanism, and whereby the successive setting of the number setting keys may be made to control successive registers. 95

175. The combination of a plurality of registers, a plurality of number setting keys, a plurality of sets of stops comprising a plurality of stops for each one of said number setting keys and controlled thereby for controlling without actuating said registers, and means whereby said registers are actuated 110 and whereby the successive setting of said number setting keys may be made to control a stop of the successive sets of stops for controlling successive registers.

176. The combination of a plurality of registers, a plurality of number setting keys, a stop mechanism for each of said number setting keys, means whereby the stop mechanism of any one of said number setting keys may be made to control any one of said registers whereby said registers may be actuated. 115 120

177. The combination of a plurality of registers, a set of number setting keys, a plurality of sets of stops, elements whereby any one of said number setting keys may control its relative stop of any one of said sets of stops for the purpose of controlling without 125

actuating said registers, an operating element which may be operated independent of said number setting keys for actuating said registers according to the setting of said 5 number setting keys.

178. The combination with a plurality of registers, of a plurality of number keys, any one of which may control without actuating any one of said registers, a plurality of actuators, and separate hand controlled operating means which can be operated to cause 10 said actuators to actuate said registers.

179. The combination with a plurality of registers, of a plurality of number keys, any 15 one of which may control without actuating any one of said registers, a plurality of actuators, and separate hand controlled operating means which can be operated to cause 20 said actuators to actuate said registers, whereby said number keys may be successively operated to control successive registers.

180. In a calculating machine, calculating means comprising a plurality of registers, a 25 plurality of number keys, a plurality of stops settable by said keys, actuators, and mechanism correlated with said registers and stops and actuators and number keys, whereby any one of the number keys may 30 control without actuating any one of said registers and whereby said actuators may actuate said registers according to the setting of said stops by said number keys.

181. In a calculating machine, calculating 35 means comprising a plurality of registers, a plurality of number keys, a stop element for each of said number keys, actuators, and mechanism correlated with said registers and number keys and stop elements and actuators, whereby the stop element of any one 40 of said number keys may control without actuating any one of said registers and whereby said actuators may actuate said registers according to the setting of said number keys.

182. The combination with a plurality of registers, of a plurality of number setting keys, a plurality of sets of stops arranged so that any one of said number keys may 45 control its relative stop of any one of said sets of stops for the purpose of controlling said registers, actuators, and operating means which may be operated independent of said number setting keys to cause said actuators to actuate said registers according 50 to the setting of said setting keys.

183. The combination of a plurality of registers, a plurality of number keys, a plurality of sets of stops controlled by any of 60 said number keys for controlling without actuating any of said registers, a plurality of actuators, and independent operating means which may be operated to cause said actuators to actuate said registers.

184. The combination with a series of 65 registers and a series of number setting de-

vices mounted on a stationary part of the machine and any one of which may control without actuating any one of said registers, of retaining means whereby said setting devices are held in their operative position.

185. The combination with a series of registers and a series of number setting devices mounted on a stationary part of the machine and any one of which may control without actuating any one of said registers, 70 of retaining means whereby said setting devices are held in their operative position, and operating means which may be operated independent of said number setting devices, whereby said registers may be actuated according to the control of said setting devices.

186. The combination of a register, a set of number keys, setting-up devices operable by said keys, means for automatically locking in its operative position any setting-up device and simultaneously releasing any previously locked setting-up device in the series, and means for operating the register to the extent determined by the setting-up 85 device last locked.

187. In a calculating machine, the combination of a register, an actuator, operating means, and a plurality of controlling keys any one of which keys when depressed releases any previously depressed key and is rendered effectual for controlling said actuator, said keys, actuator, and operating means being so constructed and arranged that said actuator may be actuated by said 100 operating means to actuate said register according to the value of any of said keys which is last depressed.

188. The combination of a plurality of registers, a series of setting keys which may 105 be set to control without actuating said registers, means which operates to automatically lock in its operative position any key depressed and to simultaneously release any previously locked key in the series, and a 110 hand actuated reciprocating operation-controlling members which when operated causes actuation of said registers according to the setting of said setting keys.

189. The combination of a plurality of 115 registering wheels, a series of setting keys which may be set to control without actuating said registering wheels, means which operates to automatically lock in its operative position any key depressed and to simultaneously release any previously locked key in the series, stops controlled by said setting keys, a hand actuated reciprocating operation controlling member which when operated actuates said registers according 120 to the setting of said setting keys, and means for restoring said stops to their normal position.

190. The combination of a plurality of 125 registering wheels, a series of setting keys

which may be set to control without actuating said registering wheels, means which operates to automatically lock in its operative position any key depressed and to simultaneously release any previously locked key in the series, stops controlled by said setting keys, a plurality of actuators controlled by said stops, an operating lever which when operated causes said actuators to actuate said registering wheels according to the setting of said setting keys and means for restoring said stops and actuators to their normal position.

191. The combination of a registering wheel, an actuator for said registering wheel, a series of stops for controlling said actuator, a series of setting keys for controlling said stops without actuating said registering wheel, means which operates to automatically lock when depressed, any one of said setting keys and to release any previously locked setting key and a hand operated reciprocating operation controlling member for controlling actuation of said registering wheel through the medium of said actuator.

192. The combination of a register, a series of setting keys which may be set without actuating said register, a plurality of locking faces one for each of said setting keys and arranged in a row, a locking device having lock shoulders for engaging with the locking faces of said setting keys and arranged in a row parallel to the locking faces of said setting keys and normally in their path, cam faces whereby the depression of any one of said setting keys operates to move the lock shoulders of said locking device away from all of the locking faces of said setting keys in a direction at an angle to the row of locking faces of said setting keys whereby any previously locked setting key is released and which operates to return the lock shoulders of said locking device back to a position to engage the locking face of the depressed setting key for locking it in its operative position, stops controlled by said setting keys for controlling said registers, an actuator for said register, and a manually-actuated operation-controlling member whereby said actuator is caused to actuate said register according to the setting of said setting keys.

193. The combination of a series of registers, a series of number setting keys any one of which may be set to control without actuating any one of said registers, means for automatically locking any one of said keys in its operative position when actuated and automatically simultaneously releasing any previously locked key of the series, and operating means which may be operated independent of said number setting keys for actuating said registers according to the setting of said setting keys.

194. The combination of a plurality of keys, and means constructed and arranged to be controlled by one of said keys, for restoring any depressed key to its normal position.

195. The combination of a register, a plurality of keys, means constructed and arranged to be controlled by one of said keys for restoring any depressed key to its normal position, and a manually-actuated operation-controlling device comprising means whereby said register may be actuated according to the value of a depressed key of said row.

196. The combination of a register, a row of number key-members mounted on a stationary part of the machine for controlling without actuating said register, automatic means for locking when depressed any one of said number key-members, a key operated device for releasing any depressed key-member, stops controlled by said key members for controlling said register, and a reciprocating hand operated operation-controlling member for actuating said register.

197. In a calculating machine, the combination of a plurality of registers, setting keys for controlling said registers, a plurality of actuators one for each of said registers, means which operates to detain said actuators in their normal position when said keys are in their normal position and when any one of said keys is depressed, and a manually-actuated operation-controlling member for causing said actuators to actuate said registers according to the control of said setting keys.

198. In a calculating machine, the combination of a register, a plurality of number setting keys for controlling said register, operating means for actuating said register, and detaining means for said setting keys whereby one setting of a number key may operate to control said register during successive actuations by said operating means.

199. The combination of a plurality of registers, a plurality of keys any one of which may be actuated for controlling without actuating any one of said registers, actuating elements for said registers, a manually-actuated operation-controlling member which may be operated independent of said elements, keys to cause said actuating means to actuate said registers, and an elastic connection between said actuating elements and said member and which is sufficiently yielding to permit said operating member to move through its full stroke while moving said actuator through any portion of its full stroke.

200. The combination of a plurality of registers, a stop device, a plurality of keys any one of which may be actuated for controlling through the medium of said stop device without actuating any one of said

- registers, actuating elements for said registers, a manually-actuated operation-controlling member which may be operated independent of said setting keys to cause said actuating elements to actuate said registers, and an elastic connection between said actuating elements and said member and sufficiently yielding to permit said operating member to move through its full stroke while moving any of said actuators through any portion of their full stroke.
201. The combination of a plurality of registers; a stop device, constructed and arranged to control different registers; a plurality of number keys which may be actuated to control, through the medium of said stop device, without actuating said registers; and a manually-actuated operation-controlling member for actuating said registers.
202. The combination of a series of registers, a set of number keys, a plurality of sets of stops, controlled by said number keys for controlling without actuating said registers, an automatic device whereby the control of said set of number keys can be successively shifted from one set of stops to another set of stops, and a manually-actuated operation-controlling member for actuating said registers according to the setting of said stops.
203. The combination of a series of registers, a series of number keys, for controlling without actuating said registers, stops controlled by said number keys for controlling said registers, a device whereby the control of any one of said stops can be shifted with relation to said registers, and a manually-actuated operation-controlling member for actuating said registers.
204. The combination of a series of registers; a series of number keys, for controlling without actuating said registers; stops controlled by said number keys for controlling said registers; a carriage having a transverse movement with relation to said registers whereby the control of said stops is shifted from one register to another; and a manually-actuated operation-controlling member for actuating said registers.
205. The combination of a plurality of registers, a plurality of number keys constructed to control without actuating said registers, a manually-actuated operation-controlling member for actuating said registers according to the control of said number keys, and a carriage movable with relation to said number keys for shifting the control of said number keys with relation to said registers.
206. The combination of a series of registers, a series of number keys, which may control without actuating said registers, a manually-actuated operation-controlling member which may be operated independent of said number keys to actuate said registers, and shiftable means whereby the con-

trol of said registers by said number keys may be automatically shifted by the operation of said operation-controlling member.

207. The combination of a series of registers, a series of number keys, which may control without actuating said registers, a manually-actuated operation-controlling member which may be operated independent of said number keys to actuate said registers, shiftable means whereby the control of said registers by said number keys may be automatically shifted by the operation of said operation-controlling member, and means for preventing the shifting of said shiftable means.

208. The combination of a plurality of registers, a plurality of number keys, for controlling without actuating said registers, means comprising a carriage whereby the control of said number keys may be successively and automatically shifted with relation to said registers, and a manually-actuated operation-controlling member for said registers.

209. The combination of a plurality of registers, a plurality of sets of stops for controlling said registers, a plurality of number keys for controlling said stops without actuating said registers, means comprising a carriage whereby the control of said number keys may be successively shifted from one set of stops to another for controlling the different registers, and a manually-actuated operation-controlling member for said registers.

210. The combination of a plurality of registers, a plurality of number keys for controlling without actuating said registers, a manually-actuated operation-controlling member for actuating said registers, a carriage which may be moved for shifting the control of said number keys with relation to said registers, and means for automatically moving said carriage.

211. The combination of a plurality of registers, a plurality of number keys for controlling without actuating said registers, a manually-actuated operation-controlling member for actuating said registers, a carriage which may be moved for shifting the control of said number keys with relation to said registers, a device for automatically causing step-by-step movement of said carriage, and means for rendering the automatic carriage moving device ineffective.

212. The combination of a plurality of registers, a plurality of number keys for controlling without actuating said registers, a carriage whereby the controlling influence of said number keys may be successively shifted with relation to said registers, a manually-actuated operation-controlling member for actuating said registers, and means for returning said carriage to its normal position.

213. The combination of a plurality of registers, a plurality of number keys for controlling without actuating said registers, a carriage whereby the controlling influence of said number keys may be successively shifted with relation to said registers, a manually-actuated operation-controlling member for actuating said registers, and a hand controlled carriage returning device 5 mounted on a stationary part of the machine and connected with said carriage for returning said carriage to its normal position.
214. The combination of a series of registers, a series of number keys, so constructed 10 and arranged that any one of said number keys may control the accumulating movements of any of said registers without actuating the latter, a manually-actuated operation-controlling member which may be operated independent of said setting keys for actuating said registers according to the control of said keys, and an indicating device, for indicating the register which is being controlled by said number keys.
215. In a calculating machine, the combination of a series of registers, a series of number keys for controlling registering movements of said registers, a manually-actuated operation-controlling member for 20 causing actuation of said registers according to the control of said number keys, a carriage automatically movable at each operation of said operation-controlling member, and a hand-controlled element for preventing movement of said carriage upon operating said operation-controlling member to permit the control of said number keys to be repeatedly exerted on the same register upon repeatedly operating said operation-controlling member.
216. In a calculating machine, the combination of a series of registers, a series of number keys for controlling registering movements of said register, a manually-actuated operation-controlling member for causing actuation of said registers according to the control of said number keys, a carriage automatically movable at each operation of said controlling member, and a hand-controlled element for preventing movement of said carriage upon operating said operation-controlling member to permit the control resulting from a single manipulation of said number keys to be repeatedly exerted on the same register upon repeatedly operating said operation-controlling member.
217. In a calculating machine, the combination of a series of registers, a series of number keys for controlling registering movements of said registers, a manually-actuated operation-controlling member for causing actuation of said registers according to the control of said number keys, a carriage automatically movable at each operation of said controlling member, and a hand-controlled element for preventing movement of said carriage upon operating said operation-controlling member to permit the control resulting from a single manipulation of said number keys to be repeatedly exerted on the same register upon repeatedly operating said operation-controlling member.
218. The combination of a registering wheel, a series of independently operable number keys for controlling said registering mechanism, operating means for actuating said registering wheel, and means whereby one setting of one of said number keys may operate to control said registering wheel during successive operations of said operating means.
219. The combination of a plurality of registers, number keys for controlling said registers, means for actuating said registers, a controlling key for controlling repeated operations of said registers by said actuating means under control of said number keys, and a lock whereby said controlling key may be locked in its operative position.
220. The combination of a register; a series of number keys for controlling said register; an operating device for actuating said register; and means for locking any number key, when actuated, in its operative position whereby repeated additions may be made on the same register by the one setting of said number key and the repeated operation of said operating device.
221. The combination of a series of registers, a series of number keys, a carriage whereby any one of said number keys may control any one of said registers, a manually-actuated operation-controlling member whereby said registers are caused to be actuated and said carriage may be shifted, and an independent shifting device which operates independent of said operation controlling member for shifting said carriage, said shifting device comprising a hand controlled actuating element mounted on a stationary part of the machine.
222. The combination of a series of registers, a series of number keys, a carriage whereby any one of said number keys may control any one of said registers, a manually actuated operation-controlling member whereby said registers are caused to be actuated and said carriage may be shifted, an independent shifting device which operates independent of said operating device for shifting said carriage, a shifting key, and means whereby said shifting key may be operatively connected with or disconnected from said independent shifting device.
223. The combination of a registering wheel, stops for controlling its movement, a number key for controlling said stops, and means whereby the control of said number key may be shifted from one to another of said stops.

224. The combination of a registering wheel, stops for controlling its movement, and a number key for controlling different ones of said stops for the purpose of registering on said wheel an amount representing the value of said key or a product thereof at the will of the operator and at a single operation of said machine.

225. The combination of a registering wheel, stops for controlling its movement, a number key for controlling said stops, and a plurality of multiplying keys whereby the control of said number key may be shifted from one to another of said stops for the purpose of registering on said registering wheel the product of the value of said key and any one of said multiplying keys that have been actuated.

226. The combination with a register of two sets of number controlling devices, one of which represents the multiplicand and the other of which represents the multiplier, and means whereby the multiplication of two numbers may be controlled by the shifting into an operative position of devices of both of said sets.

227. In a multiplying machine the combination of a plurality of registers, devices for controlling the introduction therein of the multiplicand, devices for controlling the introduction therein of the multiplier, and a movable carriage, operable to shift the control of said multiplicand and multiplier controlling devices with relation to said registers.

228. The combination of a register; primary controlling means which may be actuated by a single operation to control said register; and secondary controlling means for varying the control of said register at said primary controlling means, by a single operation of said secondary controlling means.

229. In a calculating machine, the combination of a register, and means comprising primary and secondary controlling devices by which means the register is operated at a single actuation of said primary and secondary controlling devices according to the control of said primary controlling devices as varied by said secondary controlling devices.

230. In a calculating machine, the combination of a register, and means comprising primary and secondary controlling devices by which means the register is operated at a single actuation of said primary and secondary controlling devices according to the control of said primary controlling devices as varied by said secondary controlling devices, said means being operable to shift the control of said primary and secondary controlling devices with relation to said register.

231. In a calculating machine, the combination of a register, and means comprising

settable primary controlling devices and also comprising secondary controlling devices, by which means the register is operated at a single actuation of said primary and secondary controlling devices according to the setting of said primary controlling devices as varied by said secondary controlling devices, said means being operable to shift the control of said primary and secondary controlling devices with relation to said register.

232. The combination of a registering mechanism, with primary and secondary controlling mechanisms for controlling said registering mechanism and so constructed and arranged that the controlling effect on said registering mechanism of one of said controlling mechanisms is variable by the other at a single operation of said primary and secondary controlling mechanisms.

233. The combination of a registering mechanism, a set of individual number keys each of which represents a single number, for actuating and otherwise controlling said registering mechanism, and means for varying the control of said registering mechanism by said number keys.

234. The combination of a plurality of registers; stop devices therefor; and means comprising a plurality of hand controlled devices, for effecting a primary control of said registers and a secondary control of said registers through the medium of said stop devices, said primary control being variable by said secondary control, and for operating said registers in accordance with the combined controlling effect of said stop devices.

235. The combination of a plurality of registers, a stop device for controlling said registers, a primary controlling device for controlling said stop device, and means for varying the control of said stop device by said primary controlling device and for operating said registers in accordance with the varied control and whereby the control of said stop devices may be shifted with relation to said registers.

236. The combination of a register, actuators for said register, stops for controlling said register, and means comprising a primary controlling device and a secondary controlling device, said means being so constructed and arranged that at a single operation of said means, said primary and secondary controlling devices will effect a combined control of said stops, and said actuators will be caused to operate said registering device according to said combined control.

237. The combination of a registering mechanism, actuators for said registering mechanism, stops for controlling the movements of said registering mechanism, and controlling means for exercising a primary

control of the movements of said registering mechanism through the medium of said stops and for exercising a secondary control to vary said primary control and thereby the 5 control of said registering mechanism and for causing said actuators to actuate said registering mechanism under the combined influence of said primary control and said secondary control and the combined control 10 of said primary and secondary controlling means may be shifted with relation to said registering mechanism.

238. The combination of a register primary controlling means comprising a plurality of separately movable number keys 15 each of which represents a different numeral, connections correlating said primary controlling means with said register for controlling said register, according to the number key actuated, and secondary controlling means for varying the control of said register by said primary controlling means.

239. The combination of a registering mechanism, and means comprising a primary controlling device which includes a plurality of individual number keys each of which represents a different number and said means also comprising a secondary controlling device for varying the amount 30 to be registered on said registering mechanism under the control of said number keys at a single operation of said primary and secondary controlling devices, said means being constructed and arranged to operate 35 said registering mechanism in accordance with the combined control of said primary and secondary controlling devices.

240. In a calculating machine, the combination of a register, and means comprising 40 a primary controlling element and a secondary controlling element, said elements being operable independently of each other, said means being operable for multiplying two numbers and for causing said register to 45 register the product of said two numbers with a single operation of said primary controlling element and a single operation of said secondary controlling element.

241. The combination of a register and 50 means comprising a primary controlling device which includes a plurality of individual number keys each of which represents a different number and said means also comprising a secondary controlling device for varying the amount to be registered on said 55 register under the control of said number keys at a single operation of said primary and secondary controlling devices, said means being constructed and arranged so 60 that the combined control of said primary and said secondary controlling devices may be shifted with relation to said registers.

242. The combination of a plurality of 65 registers, primary controlling means comprising a plurality of separately movable

number keys each of which represents a different numeral and so constructed and arranged that any one of said number keys may control any one of said registers, and secondary controlling means for varying 70 the control of said registers by said primary controlling means.

243. The combination of a plurality of registers; stop devices therefor; and means comprising a plurality of separately movable number keys for effecting a primary control of said registers, and a secondary controlling device for effecting a secondary control of said registers through the medium of said stop devices, and said means 75 being operable for operating said registers in accordance with the combined controlling effect of said stop devices.

244. The combination of a plurality of registers; stop devices therefor; and means comprising a plurality of separately movable number keys for effecting a primary control of said registers, and a secondary controlling device for effecting a secondary control of said registers through the medium 80 of said stop devices, said primary control being variable by said secondary control, and said means being operable for operating said registers in accordance with the combined controlling effect of said stop devices 85 and being also operable to shift the control of said number keys and said secondary controlling device and said stop devices with relation to said registers.

245. The combination of a plurality of registers; actuators for said registers; stops for controlling the movements of said actuators; and means comprising a primary controlling device including a plurality of separately movable number keys each of which represents a different number, for controlling said registers through the medium of said actuators and stops, said means also comprising a secondary controlling device for modifying the control of said primary controlling device, and said means being operable for causing said actuators to actuate 95 said registers.

246. The combination of a plurality of registers; actuators for said registers; stops for controlling the movements of said actuators; and means comprising a primary controlling device including a plurality of separately movable number keys each of which represents a different number, for controlling said registers through the medium of said actuators and stops, said means also comprising a secondary controlling device for modifying the control of said primary controlling device, said means being operable for causing said actuators to actuate 105 said registers, and said means being also operable to shift the control of all of said controlling parts with relation to said registers. 110

247. The combination of a registering mechanism, a set of individual primary controlling number keys each of which represents a different number for controlling said registering mechanism, and a set of individual secondary controlling number keys each of which represents a different number for varying the control of said registering mechanism by said primary controlling keys. 5
248. The combination of a registering mechanism, and means comprising a primary controlling device including a plurality of separately movable number keys each of which represents a different numeral, for controlling said registering mechanism, said means also comprising a secondary controlling device including a plurality of separately movable number keys each of which represents a different numeral, for varying 10 the control of said registering mechanism by said primary controlling device, and said means being operable for actuating said registering mechanism in accordance with the combined control of said primary and secondary controlling devices. 15
249. The combination of a registering mechanism, and means comprising a primary controlling device including a plurality of separately movable number keys each of which represents a different numeral, for controlling said registering mechanism, said means also comprising a secondary controlling device including a plurality of separately movable number keys each of which 20 represents a different numeral, for varying the control of said registering mechanism by said primary controlling device, said means being operable for actuating said registering mechanism in accordance with the combined control of said primary and secondary controlling devices. 25
250. The combination of a registering mechanism, a plurality of separately movable primary controlling keys each of which represents a different numeral, stops which may be controlled by said controlling keys for controlling said registering mechanism, and a plurality of separately movable secondary controlling keys each of which represents a different numeral, for varying the control of said registering mechanism by said primary controlling keys and stops. 30
251. The combination of a registering mechanism, and means comprising a plurality of separately movable primary controlling keys each of which represents a different numeral, stops which may be controlled by said controlling keys for controlling said registering mechanism, and a plurality of separately movable secondary controlling keys each of which represents a different numeral, for varying the control of said registering mechanism by said primary controlling keys and stops. 35
252. The combination of a registering mechanism, and means comprising a plurality of separately movable primary controlling keys each of which represents a different numeral, stops which may be controlled by said controlling keys for controlling said registering mechanism, and a plurality of separately movable secondary controlling keys each of which represents a different numeral, for varying the control of said registering mechanism by said primary controlling keys and stops, said means being operable for actuating said registering mechanism according to the combined control through the medium of said stops of said primary and secondary controlling keys. 40
253. The combination of a registering mechanism comprising a plurality of registers; and means comprising a plurality of separately movable primary controlling keys each of which represents a different numeral; an element whereby any one of said controlling keys may control any one of said registers; stops which may be controlled by said controlling keys, for controlling said registering mechanism; and a plurality of separately movable secondary controlling keys each of which represents a different numeral, for varying the control of said 45 registering mechanism by said primary controlling keys and stops; said means being operable for actuating said registering mechanism according to the combined control, through the medium of said stops, of said primary and secondary controlling keys; said means being also operable for shifting the control of said primary and secondary controlling keys and said stops with relation to said registering mechanism. 50
254. The combination of a plurality of registers; and means comprising a plurality of separately movable primary controlling keys each of which represents a different numeral; stops which may be controlled by said controlling keys, for controlling said registers; actuators for rotating said registers; and a plurality of separately movable secondary controlling keys each of which represents a different numeral, for varying the control of said registers by said primary controlling keys and stops; said means being operable for causing said actuators to actuate said registers according to the combined control, through the medium of said 55

stops, of said primary and secondary controlling keys.

255. The combination of a registering mechanism, multiplier controlling devices each capable of representing a number, and multiplicand controlling devices each capable of representing a number, said controlling devices being coöperative for controlling said registering mechanism to register products of numbers represented by said controlling devices.

256. The combination of a registering mechanism; and means comprising multiplier controlling devices each capable of representing a number, and multiplicand controlling devices each capable of representing a number, said means being operable to cause said registering mechanism to register the product of any two numbers

20 which may be represented by said multiplier and multiplicand controlling devices.

257. The combination of a plurality of registers; and means comprising a plurality of separately movable multiplicand-controlling keys each of which represents a different number, and a multiplier-controlling device movable for representing different numbers, said means being operable to cause said registers to register the product of the

30 amounts represented by the moved multiplicand keys and multiplier device.

258. The combination of a plurality of registers; and means comprising a plurality of separately movable multiplicand-controlling keys each of which represents a different number, and a multiplier-controlling device movable for representing different numbers, said means being operable to cause said registers to register the product of the

40 amounts represented by the moved multiplicand keys and multiplier device, and said means being also operable for shifting the control of said keys and device with relation to said registers.

45 259. The combination of a plurality of registers; and means comprising a plurality of separately movable multiplicand-controlling keys each of which represents a different number, and a plurality of separately

50 movable multiplier-controlling keys each of which represents a different number, said means being operable to cause said registers to register the product of the amounts represented by the moved multiplicand and

55 multiplier keys.

260. The combination of a registering mechanism, a number key, and a multiplying key whereby said number key may be made to control the movement of said register

60 tering mechanism an amount representing the product of the numbers represented by said number key and said multiplying key.

261. The combination of a registering mechanism, a number key, and a series of

65 multiplying keys whereby said number key

may be made to control the accumulation on said registering mechanism an amount equal to the product of the value of said number key multiplied by the value of any one of said multiplying keys which has been operated in conjunction with said number key.

262. In a calculating machine, the combination of a registering mechanism, a plurality of separately movable multiplier-controlling keys each of which represents a different number, a plurality of separately movable multiplicand-controlling keys each of which represents a different number, and means whereby the depression of any one of said multiplier keys and any one of said 80 multiplicand keys may control the registration on said registering mechanism of the product of the numbers representing the values of the two keys depressed.

263. The combination of a plurality of registers; operating means for said registers; a plurality of separately movable number setting keys each key representing a different number, for controlling operation of said registers by said operating means, and 90 means whereby said number keys may be made to remain in their operative position during successive operations of said operating means.

264. The combination of a plurality of number keys any one of which may control any one of said registers, means for retaining said number keys in an operative position when actuated, a plurality of registers controlled by said keys, and operating 100 means for actuating said registers, said number key retaining means operating to retain any operative number key in its operative position during successive operations of said operating means, for successively controlling said registers.

265. In a calculating machine, the combination of a register, a shiftable actuator therefor, a plurality of keys for controlling said register, and a stop device operable for 110 arresting and locking said actuator in any one of a plurality of shifted positions according to the key operated.

266. In a calculating machine, the combination of registers, number setting keys 115 which may be set for controlling without actuating said registers, a hand controlled operating device for operating said registers according to the setting of said number setting keys, and a shift key for selecting the 120 register to be operated by said operating device.

267. The combination of a plurality of registers a plurality of number keys for controlling said registers, a movable carriage whereby the control of said number keys may be shifted relatively to said registers, a spring for moving said carriage, a main stop device controlled by said number keys for arresting the movement of the car- 125

riage, an auxiliary stop device for arresting the movement of said carriage, and means independent of said number keys for controlling said auxiliary stop device.

268. The combination of a plurality of registers, a plurality of number keys for controlling said registers, a movable carriage whereby the control of said number keys may be shifted relatively to said registers, a spring for moving said carriage, a main stop member comprising a plurality of stops controlled by said number keys for arresting the movement of the carriage, an auxiliary stop member comprising a plurality of stops for temporarily arresting the movement of said carriage independent of said main stop member, and means independent of said number keys for controlling said auxiliary stop member, said number keys being operable to release said carriage from one stop of said main stop member and to permit said spring to move said carriage until arrested by a succeeding stop of said main stop member and said auxiliary controlling means being operable to cause said auxiliary stop member to release said carriage from said main stop member and allow said carriage to be moved by its spring until arrested by said auxiliary stop member.

269. The combination of a plurality of registers, a plurality of number keys for controlling said registers, a movable carriage whereby the control of said number keys may be shifted relatively to said registers, a spring for moving said carriage, a main stop member comprising a plurality of stops controlled by said number keys for arresting the movement of the carriage, an auxiliary stop member comprising a plurality of stops for temporarily arresting the movement of said carriage independent of said main stop member, and means independent of said number keys for controlling said auxiliary stop member, said number keys being operable to release said carriage from one stop of said main stop member and to permit said spring to move said carriage until arrested by a succeeding stop of said main stop member, and said auxiliary controlling means being operable to cause said auxiliary stop member to release said carriage from said main stop member and allow said carriage to be moved by its spring until arrested by said auxiliary stop member, said carriage being automatically releasable from said auxiliary stop member and adapted to be again arrested by one of the stops of the main stop member.

270. The combination of a plurality of registers, a movable carriage for controlling registration on said registers, a spring for moving said carriage, a detent escapement mechanism comprising a pawl member and a stop device for controlling the movement

of said carriage by said spring, universal actuating means for said registers and said escapement mechanism whereby the latter is actuated to permit step-by-step movement of said carriage under the propelling power of said spring, and an auxiliary stop device whereby said carriage is arrested during its travel independent of said stop device of said escapement mechanism, said carriage being releasable from said auxiliary stop device and adapted to be again arrested by said stop device of said escapement mechanism.

271. The combination of a plurality of registers, a plurality of number keys for controlling said registers, a movable carriage for shifting the control of said number keys relatively to said registers, a spring for moving said carriage, a detent escapement mechanism comprising a pawl member and a stop device for controlling the movement of said carriage by said spring, universal connecting means between said number keys and said escapement mechanism whereby the latter is actuated to permit step-by-step movement of said carriage under the propelling power of its spring at each operation of any of said number keys, an auxiliary stop device independent of any part of said escapement mechanism, and key controlled means for temporarily disengaging said pawl member from its stop device while said carriage is allowed to move under the power of said spring until arrested by said auxiliary stop device and whereby said pawl member is permitted to again engage its stop device to arrest said carriage and said carriage is disengaged from said auxiliary stop device.

272. The combination of a plurality of registers, a plurality of number keys for controlling said registers, a movable carriage for shifting the control of said number keys with relation to said registers, a spring for driving said carriage in one direction, a detent escapement device, universal means whereby said escapement device is actuated to allow said spring to move said carriage a step whenever any one of said number keys is operated, and key operated means for shifting said carriage independent of said number keys and their universal connections to said escapement device.

273. The combination of a plurality of registers, a movable carriage operatively related thereto means for driving said carriage to move, a main stop device for arresting the movement of said carriage, and an auxiliary stop device which may be operated independent of said main stop device for arresting the movement of said carriage and which is movable from an inoperative to an operative relationship with said carriage.

274. The combination of a plurality of

registers; a plurality of number keys for controlling said registers; a movable carriage; a spring for driving said carriage to move in one direction; a main stop device controlled by said number keys, for arresting said carriage in different positions against movement by said spring; an auxiliary stop device independent of said main stop device, for arresting said carriage against movement by said spring; and a key independent of said number keys, for operating said auxiliary stop device.

275. The combination of a plurality of registers; a plurality of number keys for controlling said registers, a movable carriage for shifting the control of said number keys with relation to said registers; a spring for driving said carriage to move in one direction, a main stop device controlled by said number keys, for arresting said carriage in different positions against movement by said spring; an auxiliary stop device independent of said main stop device, for arresting said carriage against movement by said spring and which is normally inoperative with relation to said carriage; and a key independent of said number keys, for positioning said auxiliary stop device in operative relation to said carriage.

276. The combination of a plurality of registers, a plurality of number keys for controlling said registers, a movable carriage for shifting the control of said number keys with relation to said registers, a spring for driving said carriage to move in one direction, a main detent escapement mechanism comprising stops for controlling the movement of said carriage under the driving power of said spring and normally operative in relation to said carriage, and being so constructed and arranged as to be operable by any of said number keys to permit step-by-step movement of said carriage under the propelling power of said spring, an auxiliary stop device independent of said number keys and said stops and being normally positioned inoperatively with relation to said carriage and a key independent of said number keys, for positioning said auxiliary stop device operatively with relation to said carriage.

277. The combination of a plurality of registers, a plurality of number keys for controlling said registers, a movable carriage for shifting the control of said number keys with relation to said registers, a spring for driving said carriage to move in one direction, a main detent escapement mechanism comprising stops for controlling the movement of said carriage under the driving power of said spring and normally operative in relation to said carriage, and being so constructed and arranged as to be operable by any of said number keys to permit step-by-step movement of said carriage

under the propelling power of said spring, an auxiliary stop member independent of said number keys and said stops and being normally positioned inoperatively with relation to said carriage, a key independent of said number keys, for positioning said auxiliary stop member operatively with relation to said carriage, and key operated means for moving the carriage in the opposite direction against the power of said spring.

278. The combination of a plurality of registers, a plurality of number keys for controlling said registers, a movable carriage operatively related to said registers and said number keys, a spring for driving to move said carriage, means other than said number keys for tensioning said spring, and a detent escapement mechanism comprising a plurality of stops and a co-operating pawl device and being so constructed and arranged as to be operable by any of said number keys to permit said carriage to be moved step-by-step by its spring.

279. The combination of a plurality of registers; a plurality of number keys for controlling said registers; a movable carriage operatively related to said registers and number keys, a spring for driving said carriage; a detent escapement device comprising two separate sets of stop teeth, the teeth of one set being arranged in advance of the teeth of the other set; and a pawl operable for alternately engaging with successive teeth of the said two sets, whereby the carriage is permitted to move step-by-step under the action of its spring upon the operation of any of said number keys.

280. The combination of a plurality of registers, a plurality of number keys for controlling said registers, a movable carriage operatively related to said registers and said number keys, means for driving said carriage, an escapement mechanism for controlling the movements of said carriage, and being so constructed and arranged as to permit the carriage to be moved by said carriage moving means upon the operation of any of said number keys, and means for rendering said escapement mechanism inoperative.

281. In an adding machine, the combination of a series of registers, a series of number keys, a movable carriage whereby any one of said registers may be brought into operative relation to said number keys, an indicating device controlled by said carriage for indicating the register under the control of said number keys, means for driving said carriage to move in one direction, means exclusive of said number keys for delivering driving power to said driving means, a detent escapement device for controlling the movement of said carriage by said driving means and being so constructed and arranged as to permit said carriage to move

step by step at each operation of said number keys under the propelling power of said driving means.

282. In an adding machine, the combination of a series of registers, a series of number keys, a movable carriage whereby any one of said registers may be brought into operative relation to said number keys, an indicating device controlled by said carriage for indicating the register under the control of said number keys, means for driving said carriage to move in one direction, means exclusive of said number keys for delivering driving power to said driving means, a detent escapement device for controlling the movement of said carriage by said driving means, and being so constructed and arranged as to permit said carriage to move step-by-step at each operation of said number keys under the propelling power of said driving means, and key operated means independent of said number keys, for permitting said carriage to move a predetermined distance under the propelling power of said spring.

283. In an adding machine; the combination of a series of registers; a series of number keys; a movable carriage whereby any one of said registers may be brought into operative relation to said number keys; driving means for driving said carriage to move in one direction; a detent escapement device for controlling the movement of said carriage by said driving means and being so constructed and arranged as to permit said carriage to move step-by-step at each operation of any of said number keys under the propelling power of said driving means; key operated means independent of said number keys for permitting said carriage to move a predetermined distance under the propelling power of said driving means; key operated means for moving said carriage in the opposite direction against the propelling power of said driving means; and an indicating device for indicating the register brought under the control of said number of keys by said escapement mechanism and by each said key operated means.

284. A calculating machine comprising the combination of a plurality of independently movable setting devices which may be independently positioned so as to represent a number consisting of a plurality of digits, a series of number keys, a plurality of number-wheels and means operated by any one of said number-keys for actuating the number-wheels to indicate the product of the number represented by said setting devices and the number represented by the key operated.

285. In an adding machine the combination of a series of registers; a series of number keys; a movable carriage whereby any

one of said registers may be brought into operative relation to said number keys; driving means for driving said carriage to move in one direction; a detent escapement device for controlling the movement of said carriage by said driving means and being so constructed and arranged as to permit said carriage to move step-by-step under the propelling power of said driving means upon operating any of said number keys; and key operated means for moving said carriage in the opposite direction against the propelling power of said driving means; and an indicating device for indicating the register brought under the control of said number keys by said escapement mechanism and by said key controlled means.

286. The combination of a plurality of registering devices, a plurality of number keys, a carriage, means independent of said keys for driving to move said carriage, a controlling device for controlling the movement of said carriage, and means whereby the operation of any one of said number keys actuates said controlling device to permit step by step movement of said carriage by said driving means, whereby any one of said registering devices may be brought into operative relation to said number keys.

287. The combination of a plurality of registering devices, a plurality of number keys, a carriage, a spring for moving said carriage in one direction, means independent of said number keys for tensioning said spring, and a detent escapement device for holding said carriage against movement by said spring, and being so constructed and arranged as to permit step by step movement of said carriage by said spring under power derived from the tensioning means, whereby any of said registering devices may be brought into operative relation to said number keys.

288. In a calculating machine, the combination of a plurality of registers, a plurality of number keys for controlling said registers, a carriage whereby the control of said number keys may be automatically shifted with relation to said registers, means independent of said number keys for driving to move said carriage in one direction under the control of said number keys, and a key movable relatively to said carriage for moving said carriage in the opposite direction for shifting the control of said number keys with relation to said registers.

289. In a calculating machine, the combination of a plurality of number wheels, a plurality of number keys for controlling said number wheels, mechanism comprising a carriage for shifting the control of said number keys successively from one number wheel to another setting-up devices arranged to be set up by the depression of said keys,

- and means operable to prevent actuation of said number wheels by said keys until said devices have been set up.
290. In a calculating machine, the combination of an accumulator, keys for controlling without actuating said accumulator, a carriage movable transversely with relation to said accumulator, and universal operating means for actuating said accumulator according to the control of said keys and for effecting transverse rectilinear movement of said carriage step-by-step with relation to said accumulator.
291. In a calculating machine, the combination of a plurality of registers, a plurality of keys for controlling without actuating said registers, a movable carriage, a spring for driving to move said carriage in one direction, a detent escapement device for said carriage, and universal operating means for actuating said registers and for actuating said escapement device to permit said carriage to move step-by-step under the propelling power of said spring.
292. The combination of a plurality of registering devices, a plurality of number keys any one of which may be operated to drive by power exerted thereupon any one of said registering devices, a carriage where by any one of said registering devices may be brought under the control of said number keys, means independent of said keys for driving said carriage, and an escapement mechanism controlled by said keys for controlling the movement of said carriage.
293. In a calculating machine, the combination of a register; keys for controlling said register; a carriage operatively related with, and movable with relation to said register, and a spring for moving said carriage, under the control of said keys.
294. The combination of a plurality of numeral wheels, a plurality of stops any one of which is adapted to coöperate with any one of the numeral wheels to stop the same, numeral keys adapted to move the stops, and actuating means for the numeral wheels.
295. In a calculating machine, the combination of a plurality of registers, setting keys for controlling without actuating said registers, and a plurality of manually-actuated operation-controlling members for actuating said registers according to the setting of said keys modified by the actuated operation-controlling member.
296. The combination of a plurality of registers; a plurality of number keys for controlling said registers, a shift key for modifying the control of said registers by said number keys, and a device for locking said shift key.
297. In a calculating machine, the combination of a plurality of registers, controlling keys therefor, shifting keys correlated with said registers and said controlling keys, a device for locking said shifting keys in their operative position, and a manually operable device for releasing said shifting keys.
298. In a calculating machine, the combination of a plurality of registers, a plurality of number keys, a carriage operable for step-by-step movement whereby the control of said registers by said number keys is shifted from one register to another, an indicating device movable concomitantly with said carriage, and means for moving said carriage and said member of the indicating device step by step.
299. The combination of registering mechanism, a carriage coöoperative therewith, means for moving said carriage with relation to said registering mechanism, and a detent escapement device for controlling movement of said carriage.
300. In a calculating machine, the combination of a plurality of registers, a movable carriage correlated with said registers, a stop device for positioning said carriage with relation to said registers, and an auxiliary stop device for positioning said carriage with relation to said registers.
301. In a calculating machine, a counter comprising a plurality of denominations, and means for periodically advancing different denominations of said counter, said counter having transfer devices adapted to carry one unit to a dial when the dial of next lower denomination has passed once from 9—0 during a periodic actuation, and to also be adapted to carry two units to a dial when the dial of next lower denomination is twice passed through 9—0 during a periodic actuation.
302. A calculating machine comprising the combination of a plurality of independently movable setting devices which may be independently positioned to represent a number consisting of a plurality of digits and constituting a multiplicand, a series of depressible number keys, a series of number wheels, and means operated by the depression of any one of the number keys for operating the number wheels to position them in accordance with the product of said multiplicand and the value of the depressed key.
303. A calculating machine comprising the combination of movable setting devices which may be positioned to register a number consisting of a plurality of depressible keys, a plurality of number wheels, carrying mechanism for carrying from one number wheel to the number wheel of the next higher denomination, and means operated by the depression of any one of said keys for operating the number wheels to position them in accordance to the product of said multiplicand and value of the key depressed.

304. A calculating machine comprising the combination of setting means for setting up a number consisting of a plurality of digits, a plurality of number wheels, a plurality of keys, and means actuated by the depression of a key for actuating said wheels to cause them to indicate the product of said number and the number of the key depressed, substantially as set forth. 65
- 10 305. A calculating machine comprising the combination of a plurality of shafts, means for operating them, setting devices movable to control the operation of said shafts by said means, and a number wheel 70 connected to each of said shafts, substantially as set forth.
306. A calculating machine comprising the combination of setting means for setting up a number, a plurality of number wheels, 20 carrying mechanism, between said wheels, a plurality of keys, and means actuated by the depression of a key for actuating said wheels to cause them to indicate the product of said number and the number of the key 75 depressed with the digits of the product in line upon said wheels, substantially as set forth.
307. In a calculating machine, a group of multiplicand keys, a group of multiplier 25 keys, devices selected and positioned by the keys, and mechanism operable to add together the numbers represented by the key 80 positioned devices.
308. In a calculating machine, the combination of a plurality of registers, a plurality of number keys, and devices selected and controlled by said keys for controlling registration on said registers of multiples of the numbers represented by the keys actuated. 85
309. The combination of a register involving a series of numeral wheels, a series of setting pins, bars, keys, means controlled by said keys for actuating said bars to set 90 40 said pins, and decimal order selecting means comprising devices which may be operated to successively actuate said registers according to the setting of said pins by said keys. 95
- 50 310. The combination with a register involving a series of numeral wheels, a series of number keys, a series of bars one for each of said number keys a plurality of slides, each comprising a set of preliminary setting pins, means for shifting said slides to bring their respective pins in operative relation to said bars, and means whereby the depression of any one of said number keys controls its bar to set a pin in a shifted slide 100
- 60 to control the accumulation in said register. 105
311. The combination with a register involving a series of numeral wheels, a series of number keys, a series of bars one for each of said number keys a plurality of slides 110
- each comprising a set of preliminary setting pins, means for shifting said slides to bring their respective pins in operative relation to said bars, means whereby the depression of any one of said number keys controls its bar to set a pin in a shifted slide to control 70 the accumulation in said register, and means whereby said controlling effect of said pin may be shifted with relation to said register to effect different numeral wheels. 115
312. The combination with a series of adding wheels, a series of setting keys for controlling said adding wheels, an order selecting device which has a step by step movement, means correlated with said order selecting device and operable for determining 80 the extent of actuation of said adding wheels, and a manually operated member for effecting the actuation of said adding wheels. 120
313. The combination with a key controlled order selecting device, comprising a movable member, a series of adding wheels, a series of actuators for said adding wheels, said actuators being controlled by said order selecting device, controlling pins for differentially controlling movements of the actuators, keys for controlling said pins, and a manually actuated member for controlling said actuators. 125
314. In a calculating machine, the combination of a plurality of bars each provided with a series of setting devices, a series of number keys, a series of actuating bars one for each number key and connected therewith, said first mentioned bars being normally in a position to render their setting 100 devices inoperative with relation to said actuating bars, and being shiftable into a position to render their setting devices operative with relation to said actuating bars, and means for holding the first said bars in 105 said shifted position. 130
315. In a calculating machine, the combination of a plurality of bars each provided with a series of setting elements, a series of number keys, a series of actuating bars one 110 for each number key and connected therewith, said first mentioned bars being normally in a position to render their setting elements inoperative with relation to said actuating bars, and being shiftable into a position to render their setting elements operative with relation to said actuating bars, a device for holding the first said bars in said shifted position, and an element whereby said first mentioned bar is automatically released when another bar is shifted to bring its setting elements in an operative position. 135
316. In a calculating machine, a series of number keys, a series of adding wheels controllable by said number keys, a carriage, mechanism whereby said carriage may be caused to move step by step at each depre- 140

sion of a number key and thereby shift the control of said number keys from one adding wheel to another, and means whereby said step by step movement of said carriage 5 by said number keys may be prevented.

317. In a calculating machine, the combination of a series of numeral keys, a series of parallel reciprocatory bars one for each of said keys and each being connected to 10 its respective key actuated thereby, and a registering mechanism and a plurality of devices controllable by said reciprocatory bars for controlling said registering mechanism.

318. In a calculating machine, the combination of a series of numeral keys, a series of parallel reciprocatory bars one for each of said keys and each being connected to its 15 respective key and actuated thereby, a plurality of transversely movable slides provided with setting devices and with means whereby said slides may be shifted to bring 20 its setting devices into operative relation to said reciprocatory bars, and a registering mechanism controlled by said setting devices.

319. The combination of a registering mechanism comprising a plurality of numeral wheels, a denominational order selecting mechanism comprising a plurality of devices arranged to be brought into action in 25 succession to select the denominations, keys, spring power mechanism controlled by said keys for operating said denominational order selecting mechanism, and bars provided with setting elements adapted to be controlled by said keys, said registering mechanism being operable under the combined control of said setting elements and 30 said order selecting mechanism.

320. In a computing machine, the combination with a registering mechanism, a device for actuating said mechanism, controlling devices for limiting the movements of 35 said registering mechanism, keys for setting said controlling devices, means for operating said actuating device, and a device for causing said setting devices to be positioned before the actuating devices are operated.

321. The combination with a register, a movable denominational order selector comprising a plurality of devices arranged to be brought into action in succession, actuators operable for causing a differential action 40 on the register, said register being automatically subjected to the action of the actuators during movements of the latter in one direction and automatically released from the action of said actuators during re-

verse movements, setting devices, and number keys, operable to control said register through the medium of said setting devices and said order selector.

322. In a calculating machine, the combi-

nation of a series of registers, actuators 35 therefor, number keys, determining devices controllable by said number keys for limiting the movement of said registers by said actuators, and means between said keys and said determining devices whereby any one 70 of said keys may control a plurality of said determining devices.

323. The combination in a calculating machine of a numeral wheel, a series of keys for controlling said wheel, a member for 75 actuating said wheel, a vibratory frame normally detached from said wheel-actuating member and operable to give motion to the latter, means independent of said keys for actuating said frame, and means non-dependent on said member whereby the operator can operatively connect said wheel-actuating member to said frame.

324. The combination in a calculating machine of the numeral wheels each representing one denomination, devices for actuating the wheels, a vibratory frame normally detached from said wheel actuating devices but common to all of them and operable to give motion to them when connected thereto, 80 and means non-dependent on said actuating devices whereby the operator may connect the actuating devices of any wheel to said frame.

325. In a calculating machine, the combination of a plurality of registers, actuators for actuating said registers, a movable member for actuating said actuators and being normally out of operative connection with the latter, a member non-dependent on said 100 actuators whereby any one of said actuators may be brought into operative connection with said movable member, and means for actuating said movable member.

326. In a calculating machine, the combination of a plurality of registers, controlling keys therefor, a plurality of individual actuators one for each of said registers, operating mechanism, and a plurality of movable members one for each of said actuators 110 and each operable by said operating mechanism for operating its respective individual actuator according to the control of said controlling keys, said movable members being connected with said actuators during 115 substantially the same portion of the operation of said operating mechanism irrespective of the value of the key controlling.

327. The combination of a plurality of registers, a plurality of actuators therefor, 120 a movable frame correlated with for moving said actuators and being normally out of operative connection with the latter, means for connecting said frame with said actuators, a detaining device for said connecting 125 means, and a releasing element for said detaining means.

328. In a calculating machine, the combi-

nation of numeral wheels and their actuators, keys for controlling movements of said actuators, a vibratory frame for actuating said actuators, and means for connecting the keys to the frame.

329. In a calculating machine, the combination with the keys, the numeral wheels, and their actuators, of a vibratory frame, means independent of the keys for vibrating the frame, and means non-dependent on said actuators for connecting the actuators to the frame.

330. In a calculating machine, the combination of a register, an actuator therefor, a plurality of controlling keys for controlling without actuating said register, a manually-actuated operation-controlling member for causing said actuator to actuate said register in accordance with the control of said keys, and a stop operable by said operation-controlling member to arrest movement of said register.

331. In a calculating machine, a carrying lever consisting of a U-shaped member, the sides thereof forming bearings and one of said sides having a stop thereon.

332. In a calculating machine, a carrying lever consisting of a U-shaped member, having a stop projection on one of the sides thereof.

333. In a calculating machine, a carrying lever consisting of a U-shaped member comprising two connected arms, bearings at one end of the arms, and a stop on one of said arms.

334. In a calculating machine, the combination of a plurality of registering wheels each comprising ratchet teeth, a plurality of actuators one for each wheel and each comprising an element for engaging the ratchet teeth thereof, a plurality of keys for controlling without actuating said registering wheels, and a manually-actuated operation-controlling member for causing actuation of said registers according to the control of said controlling keys.

335. In a calculating machine, the combination of a registering wheel comprising ratchet teeth, an actuator therefor comprising an engaging element for engaging said ratchet teeth, a member operable for controlling without actuating said wheel, and a member for operating said wheel through the medium of said actuator in accordance with the control of the first said member.

336. In a calculating machine, the combination of a number wheel, a series of number keys, an actuator, a stop mechanism and means whereby any one of said number keys may actuate said actuator and actuate said stop mechanism to engage and arrest the movement of said actuator whereby the number wheels are turned an amount represented by the number key actuated.

337. In a calculating machine, the combi-

nation of a number wheel, a number key, a plurality of stops for controlling the movements of said number wheel, and means whereby said number key may actuate any one of said stops.

338. In a calculating machine, the combination of a series of registers having equally spaced stopping points, a series of pivotally mounted arms, a plurality of engaging members one for each of said arms and movably mounted thereon and co-operative therewith for actuating said register, and a universal actuator for causing said arms and engaging members to actuate said registers.

339. In a calculating machine, the combination of registers of higher and lower denominational order, and transferring mechanism controllable by the register of lower order for transferring to the register of higher order, said transferring mechanism comprising means for rotating a register and for preventing over-rotation of the said register.

340. In a calculating machine, the combination of an accumulator wheel, and means for actuating said wheel and for stopping said wheel at the completion of its registering movement and for locking said wheel when so stopped, said means comprising a movable power transmitting member and a stop whereby said member is stopped non-dependently of and prior to the stopping of said wheel, whereby the wheel is relieved of the duty of arresting said member.

341. The combination with a registering wheel, of mechanism comprising devices for rotating and preventing over-rotation of the registering wheel and comprising devices for stopping the wheel-rotating device without assistance of the registering wheel and prior to the stopping thereof by the over-rotation-preventing device, such over-rotation-preventing device being positioned and held in action by the wheel-rotating device, and a spring for releasing the over-rotation-preventing device from its effective position.

342. The combination with the numeral wheel and its column actuator, of the locking detent constructed and arranged to be moved by said actuator into position for locking said numeral wheel.

343. In a calculating machine, the combination of a numeral wheel, keys, a wheel-driving device controllable by said keys for driving said numeral wheel various distances, and a stop device for stopping the wheel-driving device independently of said numeral wheel, said wheel driving device being instrumental in preventing over-rotation of the numeral wheel.

344. In a calculating machine, the combination with a numeral wheel and a driving member for driving said numeral wheel, of a stop device adapted to arrest the movement of said driving member non-depend-

ently of said numeral wheel, and a member controllable by said driving member for locking said numeral wheel.

345. The combination with the keys, and 5 the column actuators actuated by the keys and each provided with a shoulder, of a plurality of stop devices adapted to be actuated by said keys and comprising stops for engaging the shoulders on said actuators, whereby the movement of said actuators by said keys may be arrested in different positions by said stops.

346. The combination with a series of denominational numeral wheels, a series of 15 digital keys for imparting movements to column actuators proportional to the value of the keys, vibrating column actuators serving to operate the wheels, and means independent of the wheels for arresting the 20 actuators, said actuators being instrumental in preventing over-rotation of the numeral wheels.

347. In a calculating machine, the combination of a series of calculating wheels, a 25 series of stops for each of said calculating wheels, carrying elements for carrying from lower to higher of said calculating wheels, setting keys which may be set without causing rotary movement of said calculating 30 wheels, a series of pivotally mounted actuator members, a second series of actuator members each movably mounted on one of the first said actuator members, a series of springs each connected to one of the first 35 said actuator members and to one of the second said actuator members, and a universal operating frame for actuating said calculating wheels through the medium of said actuator members of the first and second said series, according to the setting of 40 said setting keys.

348. The combination with the registering wheel, of a carrying number with a carrying pawl pivotally mounted thereon, 45 and a stop on one of said members and arranged to move throughout each movement of said member, for preventing over-rotation of said wheel.

349. In a calculating machine; a plurality 50 of number wheels; and a transferring device for transferring from a lower to a higher order of said number wheels, said transferring device comprising a pivoted main member, an actuating pawl pivoted on 55 said main member and adapted to move, a number wheel of a higher order for transferring thereto, and a stop associated with said main member to always move therewith and to engage with to arrest the movement of said number wheel after said number wheel has been moved a space.

350. In a calculating machine; including 60 a plurality of accumulator wheels; a transferring device for transferring from a lower to a higher order of said accumulator wheels,

said device comprising a pivoted member, an actuating pawl member pivoted on said pivoted member and adapted to engage with and move an accumulator wheel of a higher order for transferring thereto, a stop on 70 one of said pivoted members arranged to always move therewith to engage with and arrest the movement of said higher order accumulator wheel when the transferring device has moved said wheel a predetermined amount, a spring for actuating said pivoted member and stop, and means for withdrawing said pivoted member to disengage its stop from said accumulator wheel. 75

351. In a calculating machine, the combination of a dial-member having a series 80 of numerals thereon, and a rotatable supporting member to which said dial-member is secured against movement relative to said rotatable supporting member.

352. In a calculating machine, the combination of a rotary dial member having numerals thereon, and a pair of clamping members between which said dial member is clamped.

353. In a numeral wheel, the combination of a dial member having a plurality of numerals on its face, and a hub comprising two members for clamping said dial member between them.

354. In a calculating machine, the combination of a plurality of accumulators, an actuator for each accumulator, a universal actuator for actuating any of said actuators, and a plurality of number keys for 100 driving and controlling said accumulators.

355. In a calculating machine, the combination of a plurality of registers, an actuator for each register, a universal actuator for actuating any of said actuators, stops, 105 and a plurality of number keys for driving said registers and controlling them through the medium of said stops.

356. In a calculating machine, the combination of a plurality of accumulators, a plurality of actuators one for each of said accumulators, a stop device for controlling the extent of actuating movement of said actuators independently of said accumulators, a plurality of keys for controlling said stop device and actuators, carrying devices for carrying from lower to higher accumulators, a plurality of dials one for each accumulator, and gearing operatively connecting said accumulators and dials for driving the latter.

357. In a calculating machine, the combination with a series of accumulators, a series 115 of actuators for said accumulators, stops adapted to engage said actuators for limiting their movement, keys for actuating said stops and driving said actuators, carrying devices for carrying from lower to higher accumulators, a stop fixed on each carrying device for arresting the respective accumu- 125 130

lator when the latter has moved a distance sufficient to cause a unit to be added thereon, a spring for driving said carrying device, a spring for withdrawing said carrying device and its stop after it has moved its accumulator one space, a plurality of members one for each actuator and operable by its respective actuator for driving said accumulator in one direction, a detent for preventing movement of said accumulator in the opposite direction, a gear wheel secured to said accumulator, a dial, and gear secured to said dial and operable by said gear on said accumulator to turn said dial.

358. In a calculating machine, the combination of a plurality of registers, keys for controlling said registers, and means for preventing said registers from registering under the control of said keys until said keys have been depressed a predetermined distance.

359. In a calculating machine, the combination of the registering wheels, number keys, stop devices settable under the control of said number keys for controlling the registering movements of said registering wheels, an actuator for each of said registering wheels, and locking means which operates to prevent the registering wheels from being actuated by said actuators until said stop devices have been set.

360. In a calculating machine, the combination with the accumulator wheels, the keys for actuating said wheels, and the train of mechanism for carrying motion from the keys to the wheels, of means for locking said train of mechanism until any one of the keys has been moved a predetermined distance.

361. In a calculating machine, the combination of the numeral wheels, the keys for actuating said wheels, and a normally locked train of mechanism for carrying motion from the keys to the wheels, which train of mechanism may be unlocked by the movement of any one of the keys a predetermined distance.

362. In a calculating machine, the combination with a numeral wheel, the series of keys actuating the wheel, and the mechanism for carrying motion from the keys to the wheel, of means for preventing actuation by said keys of said wheel during down strokes of the keys, such means being releasable by down strokes of the keys, and remaining released during the ensuing up strokes.

363. In a calculating machine, the combination of the numeral wheels, keys for actuating said wheels, and locking means for preventing the actuation of said numeral wheels by the keys, such means retaining their normally locking action in case of partial strokes of the keys and until predetermined strokes are given to the keys.

364. The combination in a calculating

machine, with the numeral mechanisms, the keys, and the column actuators, of means for preventing actuation by said keys of said column actuators when the keys are only partially depressed.

365. The combination in a calculating machine, of keys the operation of which determines the amounts added, column actuators driven by said keys, and normally effective means for preventing the driving by said keys of said actuators.

366. In a calculating machine, the combination with the numeral wheels, number keys for actuating said numeral wheels, and locking means whereby said number keys are prevented from actuating said numeral wheels until said number keys have been depressed a predetermined distance.

367. In a calculating machine, the combination with the numeral wheels, number keys for actuating said numeral wheels to make registering movements, stop devices under the control of said number keys for determining the movements of said numeral wheels, and locking means whereby said number keys are prevented from actuating said numeral wheels until said number keys have been depressed a predetermined distance and their relative stop devices have been set.

368. In a calculating machine, the combination of a plurality of registering wheels, an operating member, and a train of connections constructed and arranged to be operated by said operating member and to be capable of moving any of said registering wheels a plurality of digit spaces after the operating movement of said operating member has terminated.

369. In a calculating machine, the combination of registering wheels, actuating members therefor, a universal operating member, and a train of connections between said universal operating member and said actuating members and comprising an elastic connection so constructed and arranged as to be operable by said operating member and to be capable of causing said actuator to move said registering wheels a plurality of digit spaces after said operating member has completed its operating movement.

370. In a calculating machine, the combination of a plurality of registers, operating means therefor, and a carrying mechanism constructed and arranged to be capable of carrying successively from one of said registers to its next higher register during a single operation of said machine by said operating means and to carry successively to successively higher registers.

371. The combination of a movable carriage, parts adjustable therein to represent numbers, devices representing mechanically the products of the digits multiplied by themselves and by each other, members for

controlling said devices, and movable against the parts adjusted to represent numbers in the carriage, wheels, and mechanism operable to cause said wheels to register the products represented by certain of the devices controlled by said members when said members are moved.

372. In a calculating machine, the combination of a plurality of registers, actuators therefor, keys, and a movable carriage carrying parts controlled by said keys for controlling actuation by said actuators of said registers.

373. In a calculating machine, the combination of a plurality of registers, keys, and a movable carriage carrying parts controlled by said keys for controlling said registers, the control of said parts being shiftable with relation to said registers.

374. In a calculating machine, the combination of a plurality of registers, keys, stops, and a movable carriage carrying parts controlled by said keys to control said stops for controlling said registers, the control of said parts being shiftable with relation to said registers.

375. In a calculating machine, the combination of a plurality of registers, keys, stops representing the digits multiplied by themselves and by each other, and a carriage carrying parts controlled by said keys to control said stops for controlling said registers, the control of said stops being shiftable with relation to said registers.

376. The combination with the multiplicand keys, of a series of digit keys, a series of independently movable multiplying parts for each digit key, and a device for moving one of the independently movable multiplying parts for each digit of the multiplicand after operation of one of the digit keys, to produce the product of the corresponding digit of the multiplicand multiplied by the digit of the digit key operated.

377. In a multiplying machine, the combination with a register-carriage and keys for registering numbers therein, of members constructed and arranged to register by projecting shoulder the product of the digit represented by said key devices multiplied by another digit, devices for operating said members to perform said functions, and product-register wheels, operable for receiving the products.

378. In a machine of the character described, the combination of a series of devices, each representing the product of a digit multiplied by itself and by the other digits, and means co-operative with said devices for adding together any desired products so represented.

379. In a machine of the character described, a series of groups of multiplying devices, the combination of a common shifting member for all the devices in each group,

means for causing said devices to move separately, and wheels to receive products when the multiplying devices are operated.

380. In a calculating machine, the combination of a plurality of registers, a series of multiplying parts representing mechanically the digits multiplied by themselves and by each other for controlling registrations of products on said registers, and mechanism operable to carry the required number of units from lower to higher orders of said registers.

381. In a calculating machine, the combination of a plurality of accumulators, a plurality of controlling keys therefor, an operating lever for operating said accumulators in accordance with the setting of said controlling keys, and a key controlled device which enables a single setting of said controlling keys to control said accumulators during repeated operations of said operating lever.

382. In a calculating machine, the combination of a register, a series of setting keys for controlling said register, an operating lever for operating said register according to the setting of said keys, means for rendering said keys ineffective with relation to said register after a single operation of said operating lever, and key-controlled means for rendering the first said means ineffective.

383. In a calculating machine, the combination of a plurality of registers; a plurality of controlling members therefor, said controlling members representing different values; and a plurality of keys each of which may control a plurality of said controlling members.

384. In a calculating machine, the combination of a plurality of registers; a plurality of number keys; a plurality of controlling devices controllable by said keys; and a plurality of controlling members for controlling said registers, said controlling members representing different values and each of said controlling members being controllable by a plurality of said controlling devices.

385. In a calculating machine, the combination of a plurality of registers, a plurality of separately operable controlling keys, and a plurality of controlling members for controlling said registers, said controlling members being controllable by a plurality of said controlling keys.

386. In a machine of the character described, a plurality of plates arranged to represent the products of the digits multiplied by themselves and by each other, wheels, actuating devices controlled by the plates to operate the wheels, and means to operate the plates as required to multiply numbers in combination with mechanism operable to register the products of the numbers which were multiplied together.

387. In a machine of the character described, the combination of a device for each digit, each device representing the product of a digit multiplied by itself and by the other digits, and means for adding together any desired combination of the products so represented.

388. In a machine of the character described, the combination of a series of devices representing the products of the digits multiplied by themselves and by the other digits, and means for adding together and registering the final product of any desired combination of the products so represented.

389. In a machine of the character described, a series of multiplying parts containing a mechanical representation of the products of the digits multiplied by themselves and by each other, wheels, mechanism operable in connection with the multiplying parts and the wheels to introduce the products into the latter, and means to register the products, substantially as described.

390. In a calculating machine, the combination of a series of accumulator wheels, an actuator for each wheel, a row of stops for each actuator, a series of keys, and members for positioning corresponding stops in different rows of stops by operation of each key, for limiting movement of the actuators.

391. In a calculating machine, the combination of elements for obtaining the partial products, and means for adding said partial products together.

392. In a calculating machine, the combination of elements for separately obtaining partial products, and means for adding said partial products together.

393. In a calculating machine, the combination of elements for separately registering partial products of different denominations, and means for adding said partial products together.

394. In a calculating machine, the combination with a registering device comprising a plurality of registering wheels, of digit keys, setting devices for controlling said registering wheels, and a device whereby the control of said setting devices may be successively shifted with relation to said registering wheels at each operation of any of said digit keys.

395. In a key-controlled machine, the combination of a traveling carriage, a hinged track frame in which said carriage is mounted, and means for raising and lowering said track frame.

396. In a key-controlled machine, the combination of a traveling carriage, a hinged track frame supporting said carriage, mechanism for advancing said carriage step by step along said track frame, and a device for raising and lowering said track frame and its supported carriage.

397. In a key-controlled machine, the com-

bination of a traveling carriage, a hinged track frame supporting said carriage, finger keys and mechanism for advancing said carriage step by step along said track frame at each operation of any of said finger keys.

398. In a key-controlled machine, the combination of a traveling carriage, a hinged track frame supporting said carriage, finger keys, and mechanism whereby said track frame is raised and lowered and said carriage is advanced step by step along said track frame at each operation of any of said finger keys.

399. In a calculating machine, the combination of totalizer wheels, a traveling carriage, mechanism for advancing said carriage step by step actuators for said totalizer wheels, and mechanism for bodily lifting said traveling carriage to control said actuators.

400. In a calculating machine, the combination of a traveling carriage, a hinged track frame supporting said carriage, finger keys, an escapement mechanism whereby said carriage can be made to move step by step along said track frame upon the operation of any of said finger keys, elements for raising and lowering said track frame and its supported carriage, a rod connected with said carriage, and a finger piece on one end of said rod for operating said rod to move said carriage to different positions on said track frame or to the home position.

401. In a calculating machine, the combination of a group of keys by which the multiplicand may be introduced into the machine, a group of multiplier keys, and multiplying parts positioned by said last mentioned keys.

402. In a calculating machine, the combination of a group of multiplicand keys, a group of multiplier keys, multiplying devices positioned by said last mentioned keys, and a device for restoring a wrongly depressed multiplier key and its multiplying devices to normal position.

403. In a key-controlled machine, the combination with keys, of a traveling carriage, an escapement mechanism for controlling the travel of said carriage, said escapement mechanism being operable by said keys, and means for preventing said keys from operating said escapement mechanism.

404. In a key-controlled machine, the combination of a denominational-order calculating mechanism comprising a traveling carriage, digit keys, and escapement mechanism controlled by said digit keys, for effecting a step by step travel of said carriage from one order for another order, and a key controlled device for preventing the travel of said carriage.

405. In a calculating machine, the combination with keys, of a traveling carriage, an escapement mechanism controlled by said

- keys, for controlling the travel of said carriage, and means for rendering said escape-
ment mechanism inoperative with respect to
said keys.
- 5 406. In a calculating machine, the com-
bination of two groups or banks of keys,
multiplying devices, whereby upon the op-
eration of a key in one group the number
to be multiplied will be set up, and means
10 connected with the keys of the other group
whereby the number set up in the said mul-
tiplying devices may be multiplied.
407. The combination of a plurality of
15 accumulators, controlling keys, operating
means for operating said accumulators ac-
cording to the control of said keys, and
automatic means for shifting the effect of
said operating means with relation to said
20 accumulators.
408. In a calculating machine, the com-
bination of a register, a group of multipli-
cand keys, a group of multiplier keys, and
means whereby upon the successive oper-
ation of keys in each of said groups the
25 product of the numbers represented by the
keys so manipulated will be introduced into
said register.
409. In a calculating machine, the com-
bination of a register, multiplying devices,
30 and two groups of digital keys for control-
ling said register through the medium of
said multiplying devices, whereby one num-
ber may be multiplied by another and the
product thereof registered on said register
35 by the actuation of the keys of one of said
groups according to one of said numbers and
the successive actuation of the keys of the
other group according to the other of said
numbers.
410. In a calculating machine, the com-
bination with multiplying devices operable
for obtaining partial products, of a register
45 operable in conjunction therewith to add
together the partial products obtained upon
the operation of said multiplying devices.
411. In a calculating machine, the com-
bination of a totalizer, actuating devices for
50 said totalizer, multiplying devices, and
means for connecting said multiplying de-
vices to said actuating devices.
412. In a calculating machine, the com-
bination with actuating devices, of totalizers
55 in operative relation thereto, multiplying
devices, and members coöperative with said
actuating devices for causing said totalizers
to register the products obtained from the
operation of said multiplying devices.
413. In a calculating machine, the com-
bination with totalizers, actuating elements
60 therefor, multiplying elements including
mechanism for obtaining partial products,
and means for connecting said actuating ele-
ments with said multiplying elements where-
by said partial products are added on said
65 totalizers.
414. In a calculating machine, the com-
bination of multiplying devices, a group of
multiplier keys and their connections for
selectively rendering certain of said devices
operative, and key controlled devices for re-
70 storing said multiplying devices to normal
position.
415. In a calculating machine, the combi-
nation of two groups of digital keys, and mul-
tiplying devices, whereby the multiplicand
75 may be set up by the operation of keys
in one of said groups, and whereby the mul-
tiplier may be rendered effective in said
multiplying devices by the operation of the
keys in the other of said groups.
416. In a calculating machine, the combi-
nation of a series of devices, each device rep-
resenting the products of a digit multiplied
by itself and by other digits, wheels adapt-
ed to add said products, movable actuators
80 controlled by each of said devices to limit the
movement of the actuators to cause the cor-
rect partial products to be introduced into
the wheels when said devices are operated.
417. In a calculating machine, the combi-
nation of wheels adapted to add partial
products, actuators for operating the wheels
to introduce the partial products therein,
a movable member to limit movement of
95 each actuator to cause the correct partial
products to be introduced into the wheels,
a series of multiplying parts, means for
operating said multiplying parts to adjust
the necessary movable members, and reg-
100 istering devices to register the products.
418. In a calculating machine, the combi-
nation of a series of multiplying devices
representing the products of the digits mul-
tiplied by themselves and by each other, a
105 series of movable members whose positions
from an initial or starting point represent
numbers which are coincident with the
members represented by said multiplying
devices, means for operating the multiply-
110 ing devices, and wheels operable to receive
the product when the multiplying devices
are operated.
419. In a calculating machine, the combi-
nation of totalizers, actuators to operate
115 them, stops to limit movement of the actu-
ators, a carriage, parts carried thereby to
adjust the stops, means for moving the actu-
ators into engagement with the stops, and
means for restoring the stops and actuators
120 to idle position.
420. In a calculating machine, the combi-
nation of registering wheels, a series of mul-
tiplying devices representing products of
the digits multiplied by themselves and by
125 other digits, keys for controlling said mul-
tiplying devices for determining the move-
ments of said registering wheels, and key
operated means for shifting the control of
said registering wheels by said multiplying
130

devices to different orders of said registering wheels.

421. In a calculating machine, the combination of a series of multiplying devices representing the products of digits multiplied by themselves and by each other, wheels adapted to add partial products, actuators for operating the wheels, and means for bringing any actuator under the control of said multiplying devices to introduce and totalize the partial products in said wheels.

422. The combination of a controller device shiftable from an inoperative to an operative position comprising a plurality of controlling elements movable independently of each other, and means coöperative with said controller device for selecting the desired controlling elements.

423. The combination of a plurality of controller devices shiftable from an inoperative to an operative position and each comprising a plurality of controlling elements movable independently of each other, and means coöperative with said controlled devices for selecting the desired controlling element.

424. In a calculating machine, the combination with registering wheels of actuators for said wheels, a movable carriage, a plurality of movable controlling devices in said carriage, and means whereby said controlling devices may be made to control said actuators for determining the movements of said registering wheels.

425. In a calculating machine, the combination of registers, actuators therefor, adjustable stops to limit the throw of said actuators, a carriage, and key controlled devices therein for prearranging the stops to limit the throw of the actuators.

426. In a calculating machine, the combination with multiplying devices, of multiplier keys coöperative therewith, parts which are positioned upon the operation of a key and means under control of the operator for restoring said keys and positioned parts.

427. The combination of multiplying mechanism, elements adjustable to control the same for multiplying, means for actuating said multiplying mechanism under control of said controlling elements, said controlling elements being constructed and arranged to be restored to idle position without affecting the multiplying mechanism.

428. In a calculating machine, the combination with keys and a plurality of denominational registers, of a movable field of setting-up devices for controlling said registers, means for positioning said field of setting-up devices operatively with relation to said keys, a device for setting up any of said setting-up devices when so positioned,

and a device operable to shift the control of said setting-up devices successively from one denomination to another denomination of said registers.

429. In a calculating machine, the combination with keys, of multiplying parts positioned by said keys, and key-controlled means for restoring said keys and positioned parts to normal position.

430. The combination of a register involving a series of numeral wheels, number keys for controlling said register, and an order selecting device comprising a series of members each member representing a different order, whereby the successive depression of said number keys renders said members successively operative and the control of said number keys is shifted with relation to said register.

431. In a registering machine, the combination with a registering device and its carrying device; of an actuator for said registering device; a setting device comprising a finger piece and mounted on a stationary part of said machine and which finger piece may be set and left in said set position for controlling the registering movement of said registering device without actuating said registering device and without causing movement of said actuator for actuating or controlling said registering device; and a manually-actuated operation-controlling member for controlling actuation of said registering device through the medium of said actuator under the control of said setting device and after said setting device has been set.

432. In a registering machine, the combination with a registering device and its carrying device; of an actuator for said registering device; a setting device comprising a finger piece and mounted on a stationary part of said machine and which finger piece may be set and left in said set position for controlling the registering movement of said registering device without actuating said registering device and without causing movement of said actuator for actuating or controlling said registering device; and a manually-actuated operation-controlling member for controlling actuation of said registering device through the medium of said actuator under the control of said setting device and on the first or forward movement of said member after said setting device has been set.

433. In a registering machine, the combination with a registering indicator and its carrying device; of an actuator for said registering device; a setting device comprising a finger piece and mounted on a stationary part of said machine and which finger piece may be set and left in said set position for controlling the registering movement of said registering indicator without actuating said registering device and without causing

movement of said actuator for actuating or controlling said registering indicator; and a single hand-actuated operating device for actuating said registering indicator through the medium of said actuator under control of said setting device and after said setting device has been set.

434. In a registering machine, the combination with a registering indicator and its carrying device; of an actuator for said registering indicator; a setting device comprising a finger piece and mounted on a stationary part of said machine and which finger piece may be set and left in said set position for controlling the registering movement of said registering indicator without actuating said registering device and without causing movement of said actuator for actuating or controlling said registering indicator; and a single hand-actuated operating device for actuating on its first or forward movement said registering indicator through the medium of said actuator under the control of said setting device and after said setting device has been set.

435. In a registering machine, the combination of a registering device, a setting device comprising a finger piece and mounted on a stationary part of the machine and which finger piece can be set and left set in one of only two positions one of which positions is operative and the other inoperative for controlling without actuating said registering device, and a manually actuated operation controlling member which may be operated to control actuation of said registering device under the control of said setting device after said setting device is set in its operative position.

436. In a registering machine, the combination of a registering dial, a setting device comprising a finger piece and mounted on a stationary part of the machine and which finger piece can be set and left set in one of only two positions one of which positions is operative and the other inoperative for controlling without actuating said registering dial, and a manually actuated operation controlling member which may be operated to control actuation of said registering dial under the control of said setting device after said setting device is set in its operative position.

437. In a registering machine, the combination of a registering device, a setting device comprising a finger piece and mounted on a stationary part of the machine and which finger piece can be set and left set in one of only two positions one of which positions is operative and the other inoperative for controlling without actuating said registering device, and a manually actuated operation controlling member which may be operated to control actuation of said registering device on the first or forward movement

of said member after said setting device is set in its operative position.

438. In a registering machine, the combination of a registering dial, a setting device comprising a finger piece and mounted on a stationary part of the machine and which finger piece can be set and left set in one of only two positions one of which positions is operative and the other inoperative for controlling without actuating said registering dial, and a manually actuated operation controlling member which may be operated to control actuation of said registering dial on the first or forward movement of said member after said setting device is set in its operative position.

439. In an adding machine, the combination of a registering device, a setting device comprising a plurality of finger pieces and mounted on a stationary part of said machine and each of which finger pieces can be set and left set in one of only two positions one of which positions is operative and the other inoperative for controlling without actuating said registering device, and a manually actuated operation-controlling member which when actuated operates to actuate said registering device according to the setting of said setting device.

440. In an adding machine, the combination of a registering device, a setting device comprising a plurality of finger pieces and mounted on a stationary part of said machine and each of which finger pieces can be set and left set in one of only two positions one of which positions is operative and the other inoperative for controlling without actuating said registering device, and a manually-actuated operation controlling member which when actuated operates to actuate said registering device on its first or forward movement and according to the setting of said setting device.

441. In a calculating machine, the combination of a set of registers; means for carrying from a lower to a higher of said registers; a plurality of actuators one for each of said registers; a plurality of setting devices mounted on a stationary part of the machine and each comprising a key, which keys may be set and left set in one of only two positions one of which positions is operative and the other inoperative for controlling the registering movements of said registers without actuating said registers; and a manually-actuated operation-controlling member for controlling actuation of said registers by said actuators under the control of said setting devices.

442. In a registering machine, the combination of a registering device, an actuator therefor, a plurality of setting key members mounted on a stationary part of said machine any one of which key members may be set and left in set position for controlling

the registering movement of said registering device without actuating said registering device and without causing movement of said actuator for actuating said registering device, and a manually actuated operation-controlling member for controlling actuation on said registering device according to the setting of said setting key members.

443. In a registering machine, the combination of a registering device, an actuator therefor, a plurality of setting key members mounted on a stationary part of said machine any one of which key members may be set and left in set position for controlling the registering movement of said registering device without actuating said registering device and without causing movement of said actuator for actuating said registering device and a manually-actuated operation-controlling member for actuating said registering device on the first or forward movement of said operation-controlling member after said setting key members have been set.

444. In a registering machine, the combination of a plurality of registers, a plurality of setting keys any one of which may be set to control without actuating any one of said registers, hand controlled selecting means for shifting the control of said setting keys from one register to another, and a manually-actuated operation-controlling member other than said setting keys, for actuating the selected register according to the setting of said setting keys.

445. In a registering machine, the combination of a plurality of accumulators, each accumulator comprising a plurality of carrying actuator elements and a set of accumulator teeth for each of said elements, a plurality of setting keys for controlling without actuating said accumulators, hand controlled selecting means for selecting the accumulator to be controlled by said setting keys, and operating means for actuating the selected accumulator according to the setting of said setting keys.

446. In a registering machine, the combination of a plurality of registering devices, each registering device comprising a plurality of carrying actuator elements and a set of accumulator teeth for each of said elements, a plurality of setting keys any one of which may be set to control without actuating any one of said registering devices, hand controlled selecting means for selecting the registering device to be controlled by said setting keys and operating means for actuating the selected registering device according to the setting of said setting keys.

447. In an adding machine, the combination of a registering wheel; an actuator therefor; a plurality of stops; a plurality of setting key-members mounted on a stationary part of said machine, any one of which members may be set, without setting in mo-

tion said actuator and remains so set without manual aid, for controlling, without actuating, said registering wheel through the medium of said stops; an elbow lever and connections for each key-member for connecting each key-member with its respective stop; and a manually-actuated operation-controlling member for controlling actuation of said registering wheel through the medium of said actuator according to the setting of said control key members.

448. In an adding machine, the combination of a plurality of registers, setting key members mounted on a stationary part of the machine and any of which members can be set to control without actuating one or another of said registers, and an operating device comprising the combined means for shifting the control of said setting keys from one of said registers to another and for actuating the selected register according to the setting of said setting keys.

449. In a registering machine, the combination of a plurality of registers, a plurality of setting keys which may be set to control without actuating one or another of said registers, a shifting device for shifting the control of said setting keys from one register to another, and a manually actuated operation-controlling-member for controlling said shifting device to shift the control of said setting keys from one register to another and for controlling actuation of the selected register according to the setting of said setting keys.

450. In a registering machine, the combination of a register wheel, a plurality of setting members therefor, each of said setting members comprising a finger piece mounted on a stationary part of said machine and which setting members may be set and left in set position for controlling without causing registration on said register, and a manually-actuated operation-controlling member which may be operated to cause registration on said register after any of said setting members have been set.

451. The combination of a registering device; actuators therefor, a setting member comprising a finger piece, said setting member being mounted on a stationary part of said machine and which setting member can be set and left in set position for controlling without actuating said registering device and without causing movement of said actuator for actuating said registering devices, and a manually-actuated operation-controlling member for controlling actuation of said registering device after said setting member has been set.

452. In a registering machine, the combination of a plurality of registers; setting members comprising finger pieces, which finger pieces may be set without actuating said registers, said setting members being

5 mounted on a stationary part of the machine; an actuator for each register; a hand controlled main actuator, and means for connecting any one of the first said actuators with said main actuator, whereby its respective register may be actuated to register.

10 453. In an adding machine, the combination of a plurality of accumulating devices each comprising an indicating device for indicating the amounts accumulated on said accumulating devices, key-members mounted on a stationary part of the machine and which may be set and left in set position for controlling the movements of said accumulating devices, and hand-controlled means other than said key members for actuating said accumulating devices and their coöperating indicating devices.

15 454. In an adding machine, the combination of accumulator wheels, indicating dials movable thereby for indicating the amounts accumulated on said accumulator wheels, actuating devices for actuating said accumulator wheels, setting key-members mounted 20 on a stationary part of the machine for controlling the movements of said accumulator wheels by said actuating devices, and operating means other than said setting key-members for actuating said accumulator 25 wheels and their coöperating indicating dials through the medium of said actuating devices.

30 455. In an adding machine, the combination of registering wheels, actuating devices 35 for actuating said registering wheels, stops for controlling the actuation of said registering wheels by said actuating devices; setting keys for controlling without setting said stops, and operating mechanism other 40 than said setting keys for setting said stops and for actuating said registering wheels through the medium of said actuating devices, according to the control of said setting keys.

45 456. In an adding machine, the combination of registering wheels, indicating dials operatively connected therewith for indicating the amounts registered on said registering wheels, actuating devices for actuating 50 said registering wheels, stops for controlling the movements of said registering wheels by said actuating devices, setting keys for controlling without setting said stops, and operating mechanism other than said setting 55 keys for setting said stops and for actuating said registering wheels through the medium of said actuating devices, according to the control of said setting keys.

60 457. In an adding machine, the combination of a plurality of registering devices each comprising an indicating device for indicating the amounts registered on said registering devices, hand operated setting members mounted on a stationary part of the 65 machine and which members may be set for

controlling without actuating any one of said registering devices, may control any one of said registering devices, and means other than said setting devices for actuating said registering devices and their coöperating indicating devices.

458. In an adding machine, the combination of accumulator wheels, indicating dials movable thereby for indicating the amounts accumulated on said accumulator wheels, 75 actuating devices for actuating said accumulator wheels, hand operated setting members mounted on a stationary part of the machine and which members may be set for controlling the movements of any one of said accumulator wheels by said actuating devices, and operating means other than said setting devices for actuating said accumulator wheels and their coöperating indicating dials through the medium of said actuating devices.

459. In an adding machine, the combination of registering wheels; actuating devices for actuating said registering wheels; stops for controlling the actuation of said registering wheels by said actuating devices; setting keys any one of which may control without actuating any one of said registering wheels through the medium of said stops without actuating said stops; and operating mechanism other than said setting keys, 90 for setting said stops and for actuating said registering wheels through the medium of said actuating devices, according to the control of said setting keys.

460. In an adding machine, the combination of registering wheels; indicating dials operatively connected therewith for indicating the amounts registered on said registering wheels; actuating devices for actuating 105 said registering wheels; stops for controlling the actuation of said registering wheels by said actuating devices; setting keys any one of which may control without actuating any one of said registering wheels, through the medium of said stops, and without actuating said stops, and operating mechanism other than said setting keys, for setting said stops and for actuating said registering wheels through the medium of said actuating devices, according to the control of said setting keys.

461. In a registering machine, the combination of a registering element having gear teeth and an indicator having thereon numbers which are separate from said gear teeth, an actuator therefor, a setting member comprising a finger piece and which member is mounted on a stationary part of said machine and which finger piece may be set and left in set position for controlling the registering movement of said registering element without actuating said registering element and without causing movement of said actuator for actuating or controlling said 120 125 130

registering wheel, and a manually-actuated operation-controlling member for actuating said registering element after said setting device has been set.

- 5 462. In a registering machine, the combination of a registering element having gear teeth and an indicator having thereon numbers which are separate from said gear teeth, an actuator therefor, a setting member comprising a finger piece and which member is mounted on a stationary part of said machine and which finger piece may be set and left in set position for controlling the registering movement of said registering element without actuating said registering element and without causing movement of said actuator for actuating or controlling said registering element, and a single manually-actuated operation-controlling member for 20 actuating said registering element on the first or forward movement of said operation-controlling member after said setting device has been set.

463. The combination of a registering wheel; controlling mechanism therefor comprising setting keys, an operating member, and normally ineffective stops; and means for preventing said operating member from operating said wheel until one of said stops 30 has been moved a predetermined distance.

464. In a calculating machine, the combination of a registering wheel, a controlling device for said registering wheel, a key for actuating said controlling device and rotating said registering wheel, and means for preventing said key from rotating said wheel until said controlling device has been put into operation.

465. In a calculating machine, the combination of a plurality of registers, a plurality of number keys for controlling said registers, a carriage for shifting the control of said number keys from one register to another, means other than said number keys 40 for driving to move said carriage, and detaining means for detaining said carriage against shifting the control of said number keys with relation to said registers during down strokes of said keys, said means releasing said carriage so that the latter may shift said control during up strokes of said keys.

466. In a registering machine, the combination of a registering wheel having gear teeth, a dial operatively connected to and movable with relation to said registering wheel, an actuator for said registering wheel and dial, a setting device comprising a finger-piece mounted on a stationary part of 55 the machine and which finger-piece is capable of being set and left in set position so as to control without effecting registering movement of said registering wheel and without causing register-actuating or con-

trolling movement of said actuator, and a 65 manually-actuated operation-controlling member for causing said actuator to actuate said registering wheel according to the control of said setting device after the latter has been set.

467. In an adding machine, the combination of a plurality of registering elements each comprising gear teeth and an indicator having thereon numbers which are separate from said gear teeth; an actuator for each 75 of said registering elements; a plurality of stops for each of said actuators; a series of setting members mounted on a stationary part of said machine, which members may be set and left to remain in set position without setting in motion said actuators, for controlling said registering elements through the medium of said stops without actuating said registering elements; an elbow lever and a connection for connecting each key 80 with its respective stop; and a manually-actuated operation-controlling member for actuating said registering elements through the medium of said actuators according to the setting of said setting key members. 90

468. In a registering machine, the combination of a registering wheel, and a controlling key lever therefor, said key lever being movable during each depression of the key, about a plurality of fulcrums. 95

469. In a calculating machine, the combination of a registering wheel, and a plurality of controlling key levers therefor each key lever being movable during each depression of the key, about a plurality of 100 fulcrum points.

470. In a calculating machine, the combination of a plurality of registering wheels, and a plurality of controlling key levers therefor each key lever being movable during each depression of the key, about a plurality of fulcrum points. 105

471. In a registering machine, the combination of a plurality of registers, a carriage operatively related to said registers, and a plurality of key levers for controlling said registers and said carriage, each of said key levers being constructed and arranged to move about different points of fulcrum. 110

472. In a calculating machine, the combination of a plurality of registers, a carriage operatively related to said registers, and a plurality of key levers for controlling said registers and said carriage each of said key levers being constructed and arranged to 120 turn about one fulcrum for controlling said registers and to turn about another fulcrum for controlling said carriage.

473. In an adding machine, the combination of a register, an actuator for said register, setting keys for controlling said register, operating mechanism for said actuator, locking means for preventing said operating 125

mechanism from operating said actuator, and a device for releasing said locking means when said operating mechanism has been moved a predetermined distance for permitting said actuator to actuate said register.

474. In a calculating machine, the combination of a plurality of registers and controlling key levers therefor, with a carriage operatively related thereto and being capable 10 of transverse step-by-step movement and vertical movement with relation to said key levers, and means independent of said key levers for driving said carriage step-by-step.

475. In a calculating machine, the combination of a plurality of registers and controlling key levers therefor, with a carriage operatively related thereto and being capable 15 of transverse movement and vertical movement with relation to said key levers, a key operated mechanism for effecting the transverse movement of said carriage, and a separate key operated mechanism for controlling the vertical movement of said carriage.

476. In a calculating machine, the combination of a plurality of registering devices; an elongated track a carriage mounted on said track and operatively related to said registering devices and transversely movable 30 along said track, with relation to said registering devices, a plurality of setting keys for controlling without actuating the registering movements of said registering devices and means independent of said setting keys, 35 for controlling the operative positioning of said carriage to move transversely with relation along said track.

477. In a calculating machine, the combination of a plurality of registering devices; 40 an elongated track a carriage mounted on said track and operatively related to said registering devices and transversely movable with relation to said registering devices; a plurality of setting keys for controlling 45 without actuating the registering movements of said registering devices and means independent of said setting keys, for controlling the operative positioning of said carriage along said track, and for actuating said 50 registering devices according to the setting of said setting keys.

478. In a calculating machine, the combination of a plurality of registering devices, a plurality of setting keys for controlling 55 without actuating said registering devices, a carriage capable of transverse movement with relation to said registering devices, and universal operating means for actuating said registering devices according to the setting 60 of said setting keys and for moving said carriage transversely with relation to said registering devices.

479. In a calculating machine, the combination of a plurality of registers, setting

keys which can be set and left in set position to control without actuating one or another of said registers, a carriage movable transversely step-by-step with relation to said registers, and a manually-actuated operation-controlling member operable for causing shifting of the control of said setting keys from one of said registers to another, and for causing actuation of the selected register according to the setting of said setting keys, and for causing transverse step-by-step movement of said carriage with relation to said registers.

480. The combination of a series of registers, a series of number keys, a connecting device between said registers and said number keys whereby any one of said number keys may be made to control any one of said registers, shifting means whereby said connecting device may be automatically shifted to shift the control of said number keys from 80 one register to another register, means independent of said number keys to shift said shifting means, and a key for shifting said connecting device to normal position.

481. In a calculating machine, the combination of a registering mechanism, and two sets of number keys each of which sets is operatively related to for controlling said registering mechanism, one of said sets being capable of modifying the controlling influence of the other of said sets with respect to said registering mechanism.

482. In a calculating machine, the combination of a plurality of registers; keys for controlling said registers, means for operating said registers under control of said keys, and means for preventing operation of said registers by said operating means.

483. In a calculating machine, the combination of a plurality of registers, a plurality of number keys for controlling said registers, and means for rendering ineffective the control of said registers by said number keys so that said machine is rendered ineffective for performing calculating 105 operations.

484. In a calculating machine, the combination of a plurality of registers, keys for controlling without actuating said registers, a carriage operatively related with and having a step-by-step movement relative to said registers, a manually-actuated operation-controlling member for operating said registers according to the control of said keys and causing said carriage to move step-by-step relatively to said registers, and means for rendering said operation-controlling member ineffective with relation to said registers without affecting said step-by-step movement of said carriage.

485. In a calculating machine, the combination of a plurality of registers, a carriage correlated with said registers, and a

plurality of number keys for actuating said carriage and said registers, said keys being capable of being rendered ineffective with relation to said registers without effecting 5 the control of said carriage by said keys.

486. In combination, a plurality of accumulators arranged in successive denominational order, a plurality of denominational actuators one for each of said accumulators, a plurality of number keys, and a normally ineffective denominational stop 10 for each of said actuators and each controllable by a plurality of said keys for controlling its respective actuator and accumulator.

487. In combination, a plurality of accumulators arranged in successive denominational order, a plurality of denomination actuators one for each of said accumulators, 20 a plurality of number keys, a normally ineffective denominational stop for each of said actuators and controllable by a plurality of said keys for controlling its respective actuator and accumulator, and a device other than 25 said keys for driving said accumulators.

488. In a calculating machine, the combination of a plurality of registers, keys which may be set to control without actuating said registers, a carriage mounted for 30 step-by-step rectilinear movement with relation to said registers, and a universal operating means for actuating said registers according to the setting of said setting keys and for controlling said step-by-step rectilinear movement of said carriage.

489. In a calculating machine, the combination of a plurality of register wheels provided with ratchet teeth and mounted in axial alinement; a plurality of actuators, 40 one for each of said register wheels and pivotally mounted in axial alinement therewith; a plurality of pawls, one carried by each of said actuators, and adapted to engage the teeth of the correlated register 45 wheel; a step device; and a plurality of keys co-operative with said actuators for actuating said register wheels until arrested by said stop device.

490. In a calculating machine, the combination of an accumulator dial, a gear for 50 said dial, an actuating gear constructed and arranged to engage the first said gear for actuating said dial, a ratchet wheel correlated with for driving said actuating gear, 55 an actuating device pivoted in axial alinement with said ratchet wheel and comprising a pawl correlated with for actuating said ratchet wheel, a stop mechanism, and a number key mechanism operable for driving 60 said accumulator dial a predetermined number of spaces through the medium of said actuating device and said ratchet wheel and said actuating gear and the first said gear until arrested by said stop mechanism.

491. In a calculating machine, the combination of a plurality of accumulator dials; a plurality of gears, one for each of said dials, and correlated therewith; a plurality of actuating gears, one for each of the first 65 said gears and adapted to engage therewith for actuating the correlative dial; a plurality of ratchet wheels, each correlated with for driving a respective one of said actuating 70 gears; a plurality of oscillatory actuators pivotally mounted in axial alinement 75 with said ratchet wheels, there being one actuator for each ratchet wheel and each actuator being provided with a pawl correlated with for actuating a respective one of said ratchet wheels; a universal stop 80 mechanism for said actuators; and a plurality of number keys whereby said dials may be driven to turn a predetermined number of spaces until their movement is arrested by said stop mechanism. 85

492. A calculating machine, comprising the combination of a plurality of number keys, a plurality of actuating keys, a plurality of registering devices, and devices operable by any of said actuating keys for 90 actuating said registering devices to indicate the product of the number represented by the number keys and the number represented by actuating keys which have been operated. 95

493. The combination of an indexing mechanism, a wheel-rotating mechanism, a series of keys for controlling said mechanisms, and a detaining device controllable by any of said keys and effective to prevent operation of said wheel-rotating mechanism until said indexing mechanism has been put into operation. 100

494. The combination of a plurality of accumulators, accumulator operating means, 105 and means whereby different amounts may be transferred from one to another of said accumulators at different single operations of said operating means.

495. The combination of a plurality of 110 accumulators each accumulator being constructed to be capable of accumulating at a single operation items of one or more denominations, accumulator operating means, and means whereby different amounts may 115 be transferred from one to another of said accumulators at different single operations of said operating means.

496. The combination of a plurality of 120 accumulators, and means whereby at a single operation of one of said accumulators, the operated accumulator may control accumulations greater than unity on another of said accumulators.

497. The combination of a plurality of 125 accumulators, each accumulator being constructed to be capable of accumulating at a single operation items of one or more de-

nominations; and means whereby at a single operation of one of said accumulators, the operated accumulator may control accumulations greater than unity on another of said 5 accumulators.

498. In a calculating machine, the combination of a plurality of number wheels, means for actuating a wheel of higher order to transfer numbers thereto from a wheel 10 of lower order, means for preventing over-rotation of said wheel by said actuating means, means for engaging the preventing means with said wheel, and means for disengaging said preventing means from said 15 wheel.

499. In a calculating machine, the combination of an accumulator, a number key for actuating said accumulator and controlling the extent of its accumulating movement, 20 and a second accumulator, both of said accumulators being so correlated with said number key as to be movable a plurality of digit spaces by a single stroke of said number key.

500. In a calculating machine, the combination of an accumulator, a second accumulator, a number key for actuating the first said accumulator, and means whereby the first said accumulator may actuate said second 30 accumulator a plurality of digit spaces at a single operation of said number key.

501. In a calculating machine, the combination of an accumulator, a second accumulator, a key for controlling accumulations 35 on both of said accumulators, and a manually-actuated operation-controlling member which at a single operation from and to its starting position can effect movement of said registers from zero position so as to add on 40 both of said registers, under the control of said key.

502. In a calculating machine, the combination of an accumulator, a second accumulator, a key for controlling accumulations 45 on both of said accumulators, and a manually-actuated operation-controlling member which at a single operation from and to its starting position causes both of said accumulators to move for accumulating on each a 50 plurality of digits, under the control of said key.

503. In a calculating machine, the combination of an accumulating mechanism of a lower order, an accumulating mechanism 55 of a higher order, a key-controlled mechanism for controlling said accumulating mechanisms, and means for transferring from the accumulator of the lower order to the accumulator of the higher order a number 60 greater than unity of the higher order by a single operation of said key-controlled mechanism.

504. In a calculating machine, the combination of a plurality of accumulators of dif-

ferent denominational orders, a plurality of 65 controlling keys therefor, a manually-actuated operation-controlling member for operating said accumulators according to the control of said controlling keys, and a carrying mechanism capable of carrying from a 70 lower to a higher order of said accumulators upon a single movement from and to normal position of said operation-controlling member a plurality of units of the order carried to. 75

505. In a calculating machine, the combination of a plurality of accumulators of relatively low and high denominations, and means including an actuating member common to said accumulators for controlling 80 their accumulating movements and for shifting the control of said actuating member from one to another of said accumulators and also during the same operation, transferring from a low to a high accumulator an 85 amount greater than unity of said high accumulator.

506. In a calculating machine, the combination of an accumulating mechanism comprising a plurality of tappets, a second accumulating mechanism, a set of keys for controlling the actuation of either of said accumulating mechanisms, and means whereby the first said accumulating mechanism may under the control of its tappets transfer to said second accumulating mechanism upon a single movement of any of said keys from and to its normal position. 95

507. In a calculating machine, the combination of an accumulator comprising a plurality of tappets; a second accumulator; a manually-actuated operation-controlling member for said accumulators; and means whereby an amount greater than unity of the denomination of said second accumulator may be transferred from the first said accumulator, under the control of its tappets, to said second accumulator at a single actuation of said manually-actuated operation-controlling member. 100 105 110

508. In a calculating machine, the combination of a plurality of accumulators, setting devices for controlling the accumulations on either of said accumulators, operating means for operating either of said accumulators in accordance with the setting of said setting devices and comprising a manually-actuated operation-controlling member, and means whereby accumulations greater than unity of the denomination of one of 115 the accumulators may be transferred thereto from another of said accumulators at a single movement of said manually-actuated operation-controlling member from and to its starting position. 120 125

509. In a calculating machine, the combination of an accumulator, a number key for controlling accumulating movements of said

5 accumulator, a second accumulator, and means whereby accumulations greater than unity on the second of said accumulators may be controlled by the accumulations on 5 said first accumulator.

10 510. In a calculating machine, the combination of a plurality of accumulators, key mechanism for controlling the accumulations on either of said accumulators, and means whereby at a single operation of said key mechanism a number exceeding unity of the denomination of one of said accumulators may be transferred thereto from another of said accumulators.

15 511. In a calculating machine, the combination of an accumulator, keys for controlling without actuating said accumulator, operating means for actuating said accumulator according to the control of said controlling keys and comprising a manually-actuated operation-controlling member, and a stop movable by said operating means into an unyielding accumulator-stopping position for locking said accumulator against 20 over-rotation when the latter has been rotated the distance determined by said keys.

30 512. In a calculating machine, the combination of a plurality of accumulators; a set of keys any of which may control any of 35 said accumulators; and an operating device other than said keys for operating any one of said accumulators according to the control of said keys, one of said accumulators being operative for controlling accumulations on another of said accumulators to an extent greater than unity of the denomination of the accumulator so controlled, at a single operation of said operating device.

40 513. In a calculating machine, the combination of a plurality of accumulators; a set of keys which may control any of said accumulators; and an operating device other than said keys for operating any one of said accumulators according to the control of 45 said keys, one of said accumulators being operative for controlling accumulations on another of said accumulators to an extent greater than unity of the denomination of the accumulator so controlled, at a single 50 operation of said operating device from and to its normal position.

514. In a calculating machine, the combination of a plurality of accumulators, and means including an actuating member common to both of said accumulators, for transferring from one to another of said accumulators an amount greater than unity of the denomination of the accumulator transferred to and for shifting the control of 55 said actuating member from one to another of said accumulators at the same operation, of said actuating member, in which the transfer is made.

60 515. In a calculating machine, the combination of a plurality of accumulators, a gen-

65 eral actuator for actuating any of said accumulators, and means coöperative with said accumulators and said actuator for causing an amount greater than unity of the 70 denomination of one of said accumulators to be transferred thereto from another of said accumulators, and for causing the general actuator to be disconnected from the accumulator transferred from, at a single operation of said general actuator from and to 75 its normal position.

80 516. In a calculating machine, the combination of a plurality of accumulators; a general actuator for actuating any of said accumulators; and means coöperative with 85 said accumulators and said actuator for causing an amount greater than unity of the denomination of one of said accumulators to be transferred thereto from another of said accumulators, and for causing the general actuator to be disconnected from the 90 accumulator transferred from and thereafter connected with the accumulator transferred to, by a single operation of said general actuator from and to its normal position.

95 517. In a calculating machine, the combination of a plurality of accumulators; an actuating member common to both of said accumulators; and means for shifting the control of said actuating member from one to another of said accumulators and transferring an amount greater than unity accumulated on one of said accumulators to another of said accumulators, by a single operation of said actuating member from and 100 to its normal position.

105 518. In a calculating machine, the combination of two accumulators, a set of controlling keys for controlling accumulations on either of said accumulators, an operating lever for operating one after the other of said accumulators, and automatic means for shifting the control of said operating lever and said set of keys from one to the other of 110 said accumulators.

115 519. In a calculating machine, the combination of two accumulators, one of which may control accumulations on the other; a set of controlling keys for controlling accumulations on either of said accumulators; an operating lever for operating one after the other of said accumulators; and automatic means for shifting the control of said operating lever and said set of keys from one to the other of said accumulators.

120 520. In a calculating machine, the combination of a plurality of accumulators; and means, comprising a manually-actuated operation-controlling member, for operating said accumulators and for transferring from one to another of said accumulators a number greater than unity of the denomination of the accumulator transferred to, at a single actuation of said member from and to its 125 normal position.

521. In a calculating machine, the combination of a plurality of accumulators; and means, comprising a manually-actuated operation-controlling member, for differentially operating said accumulators and for transferring from one to another of said accumulators a number greater than unity of the denomination of the accumulator transferred to, at a single actuation of said member from and to its normal position. 10
522. In a calculating machine, the combination of a plurality of accumulators; a set of number keys for controlling any of said accumulators; and means, comprising a manually-actuated operation-controlling member, for actuating any of said accumulators differentially according to the control of said keys and for transferring from one to another of said accumulators an amount greater than unity of the denomination of the accumulator transferred to, at a single actuation of said member from and to its normal position. 15
523. In a calculating machine, the combination of an accumulator, a hand-controlled member, an element controlled by said hand-controlled member for controlling said accumulator, and a prime mover which operates to affect said element for controlling said accumulator and actuating said accumulator according to its control. 20
524. In a calculating machine, the combination of an accumulator, a plurality of hand-controlled members, means controlled by said hand-controlled members for controlling said accumulator, and a prime mover which operates to affect said means for controlling said accumulator and for actuating said accumulator according to the control of said means. 25
525. In a calculating machine, the combination of an accumulator, a manually-actuated operation-controlling member, a controlling key, and an accumulator-controlling member arranged to be moved a distance by said key and an additional distance by said operation-controlling member so as to cooperate with said key and operation-controlling member in controlling operation of said accumulator. 30
526. In a calculating machine, the combination of an accumulator, a plurality of keys, a manually-actuated operation-controlling member, and a plurality of members arranged to be operated first by said keys and thereafter by said operation-controlling member for controlling accumulations on said accumulator. 35
527. In a calculating machine, the combination of an accumulating device, an actuating element therefor, a manually-actuated operation-controlling member, a plurality of connecting elements which are normally out of operable relation with said operation-controlling member, and a plurality of control- 40
- ling keys for establishing an operable relation of said connecting elements with said operation-controlling member, whereby any one of said connecting elements may control said actuator so that its actuation of said accumulating device is commensurate with the value of the key in control. 70
528. In a calculating machine comprising a registering wheel, a carrying device comprising in combination, a reciprocatory actuating member, a second actuating member arranged for rotating said registering wheel, a pivot immediately connecting said second actuating member to said reciprocatory actuating member, a stop element mounted to move throughout each movement of said reciprocatory actuating member, and means for moving said actuating member sufficiently to cause them to move the registering wheel one digit space at each actuation, and to engage said stop element with said registering wheel for preventing over-rotation of the latter. 75
529. In a calculating machine comprising an accumulator wheel, a transferring device comprising in combination a reciprocatory actuating member, a second actuating member arranged for rotating said accumulator wheel, a pivot immediately connecting said second actuating member to said reciprocatory actuating member, a stop element mounted to move throughout each movement of said reciprocatory actuating member, means for moving said actuating members sufficiently to cause them to move the accumulator wheel a predetermined distance at each actuation thereof by said transferring device and to engage said stop element with said registering wheel for preventing over-rotation of the latter, and means for withdrawing said reciprocatory actuating member so as to disengage said stop element from said accumulator wheel. 90
530. In a calculating machine, the combination of a plurality of accumulator wheels of different denominations, an operating member for causing accumulating movements of one of said wheels, and carrying mechanism controlled by said wheel to effect a plurality of carrying operations from said wheel to a wheel of next higher denomination during a single movement from and to normal position of said operating member. 100
531. The combination of an accumulator wheel, an actuator therefor, and an operating member operable to cause at a single movement thereof a plurality of actuations of said actuator for rotating the accumulator wheel. 110
532. In a calculating machine, the combination of a plurality of number wheels; and transferring means for transferring from one to another of said wheels, said transferring means comprising a jointed member adapted to move one of said number wheels 120
- 125
- 130

at a rate of motion that gradually decreases to nullity.

533. In a calculating machine, the combination of an accumulator, and actuating means therefor constructed and arranged for causing such accumulating movement of said accumulator that after the initial movement of said accumulator the latter moves at a continuously gradually retarded speed 10 until the accumulator comes substantially to rest.

534. In a calculating machine, the combination of an accumulator, and actuating means therefor comprising two members 15 connected by a pivot and so constructed and arranged that they move the accumulator for accumulating at a speed which is continuously gradually less in relation to the speed of the movement of said pivot until 20 said accumulator comes substantially to rest.

535. In a calculating machine, the combination of an accumulator wheel, an actuating member, and a second actuating member pivotally connected to the first said actuating member and operatively related to said accumulator wheel and so constructed and arranged that they rotate the accumulator wheel for accumulating at a speed that is continuously gradually less in relation to 25 the speed of the movement of the first said actuating member until said accumulator wheel comes substantially to rest.

536. In a calculating machine, the combination of an accumulator wheel, an oscillatory actuating member, an axle on which said actuating member is pivoted, a second actuating member, a pivotal connecting element which connects said oscillatory actuating member with said second actuating member, and a second pivotal connecting element establishing operative relation of 35 said actuating members with said accumulating wheel so as to rotate the latter, the oscillation of said oscillatory actuating member being sufficient to swing the first said pivotal connecting element substantially into alignment with the said second pivotal connecting element and the axle of said oscillatory actuating element, whereby said actuator is moved at a continuously gradually less speed with relation to the speed of said oscillatory actuating member until said 40 accumulator comes substantially to rest.

537. The combination of a register wheel, 55 a series of keys, means for enabling any of said keys to drive said wheel, a series of movable stops, one for each of said keys, and means for enabling any key to move its associated stop to position to arrest the wheel driven thereby.

538. The combination of a register wheel, a series of keys, a driver for said wheel, means for enabling any of said keys to drive said driver, a series of movable stops ar-

ranged in proximity to said driver, one stop 65 for each of said keys, and means for enabling any key to move its associated stop into the path of said driver.

539. The combination of a register wheel, a driving pawl for said wheel, a series of 70 keys, means for enabling any of said keys to actuate said driving pawl, a series of movable stops, one for each key, and means for enabling any key to move its associated stop to position to arrest said driving pawl. 75

540. The combination of a register wheel, a driving pawl for said wheel, a series of keys, means for enabling any of said keys to actuate said driving pawl, a series of 80 movable stops, one for each key, and means for enabling any key to move its associated stop to position to arrest said driving pawl, means being provided to enable each of the stops to co-act with the pawl to lock the wheel against overthrow. 85

541. The combination with a registering wheel and a series of keys, of a set of stops movable independently of each other and associated with said keys, means for transmitting the motion of the keys to the registering wheel, means to enable each key to set its stop, and means to enable each stop to arrest the driven wheel. 90

542. In a calculating machine, the combination of a registering wheel having ratchet 95 teeth, a pawl engaging with the teeth of said registering wheel, a key whereby said pawl is actuated for rotating said registering wheel, and a stop member actuated by said key and adapted to limit movement of said 100 registering wheel.

543. In a calculating machine, the combination of a registering wheel provided with engaging elements, an actuating device provided with an engaging member for engaging said engaging elements of said registering wheel, and a stop adapted to be moved to a position in which it is substantially unyielding with relation to said engaging member, whereby said engaging member is 105 arrested in its forward movement and held in engagement with said registering wheel for preventing overrotation thereof. 110

544. In a calculating machine, the combination of a registering wheel provided with 115 engaging elements, an actuating device provided with an engaging member for engaging said engaging elements of said registering wheel, a key lever whereby the engaging member is actuated to rotate the registering 120 wheel, and a stop adapted to be moved to a position in which it is substantially unyielding with relation to said engaging member, whereby said engaging member is arrested in its forward movement and held in engagement with said registering wheel for preventing overrotation thereof. 125

545. In a calculating machine, the combi-

nation with a registering wheel and a key lever whereby said registering wheel is controlled and driven, of a stop bar adapted to arrest the movement of said registering wheel, and mechanism whereby said stop bar is actuated by said key lever.

546. In a calculating machine, the combination of a plurality of accumulators, actuators for said accumulators, stops for said actuators, a plurality of key members each comprising a finger-piece and mounted on a stationary part of said machine and which can be set and left in set position for controlling said stops, and a manually-actuated operation-controlling member for causing operation of said accumulators according to the control of said key-members.

547. The combination with a register wheel and a series of numeral keys, of stops settable by said keys to limit the stroke of the register wheel, and a device which may be driven by any of said keys for rotating the register wheel as far as permitted by the set stop.

548. In a calculating machine, the combination with a series of registering wheels, of a key lever constructed and arranged to rotate any one of said registering wheels, and a stop bar arranged to be operated by said key lever, whereby the movement of either one of said registering wheels is arrested upon depressing said key lever.

549. In a calculating machine, the combination with a series of registering wheels, and a series of key-levers constructed and arranged to drive for rotating either one of said wheels independently of the others, of a plurality of stop bars one for each of said key levers and arranged to be actuated thereby and to arrest the movement of either one of said registering wheels upon depressing a key lever.

550. The combination of a series of figure keys, a series of adding wheels, a plurality of drivers one for each adding wheel and co-operative therewith, an actuator common to all the drivers, a member for enabling any of the keys to render any of the drivers operable by said common actuator to actuate the adding wheel driven by the actuated driver, a series of stop bars each common to all of the drivers, and means controllable by the keys for determining by which stop bar the moving driver shall be stopped.

551. The combination of a series of figure keys; a series of adding wheels; an actuating device cooperative with said keys, for actuating said adding wheels; a series of stops adapted to be individually positioned by said keys, for variably arresting said actuating device; and means, between the series of stops and said actuating device, for causing the latter to act only after the positioning of the respective stops, the construc-

tion and arrangement being such that the actuating device is put into action upon the same stroke of the key that causes the stop to be positioned.

552. The combination of a series of figure keys, a series of adding wheels controllable thereby, a series of drivers for said adding wheels, a series of key-controlled stop bars each constructed to be projected into the path of all of said drivers, an actuator with which any of said drivers may be connected, and means for imparting movement to said actuator and delaying said movement until any one of said stop bars is moved to working position.

553. In a calculating machine, the combination with a series of registering wheels, of a series of stops, one for each of said registering wheels, and a key operatively connected for effecting the operative positioning of said series of stops.

554. In a calculating machine, the combination with a series of registering wheels; of a key for rotating any one of said wheels; and a stop for each registering wheel, each said stop being operable by said key, for arresting the movement of its respective registering wheel.

555. In a calculating machine, the combination of a plurality of movable registering members, a plurality of keys each one of which is correlated with for controlling any one of said registering members, a plurality of sets of stops comprising a different set for each of said registering members, and connecting means whereby each of said keys controls its respective stops.

556. In a calculating machine, the combination of a plurality of registering members, a plurality of movable stop members each comprising a plurality of stops and being operative for stopping any one of said registering members, a key for each stop member, and means whereby each of said stop members is operatively connected with its key.

557. The combination of a series of registering devices; a series of number keys; a coupling device between said registering devices and said number keys whereby any one of said number keys may control any one of said registering devices; connections from said number keys to said coupling device; means, other than said keys and said connections to said coupling device, for driving said coupling device; and a series of universal stop bars controllable by said number keys and adapted to arrest the movement of any one of said registering wheels.

558. The combination with a registering wheel and a lever adapted to rotate said wheel, of stop bars adapted to arrest the movement of said wheel, transverse slides provided with movable pins connected with

said stop bars, and mechanism connecting said pins with the lever, whereby the movement of said lever will actuate one of said pins and the stop bar connected therewith and arrest the movement of the registering wheel.

559. The combination of a register, a series of number setting devices each comprising a finger piece which may be set and left in its set position and which devices are supported on a stationary part of the machine, means whereby any one of said number setting devices may be made to control without actuating said register, retaining means whereby said setting devices are held in their operative position, and operating means which may be operated independent of said number setting devices, whereby amounts may be accumulated on said registers according to the setting of said setting devices.

560. The combination with a number wheel, of a set of indexing devices; separately operable setting devices each comprising a finger-piece which may be set and left in set position and which devices are supported on a stationary part of the machine, for selectively controlling the setting of said indexing devices; and means controllable manually independently of said keys so as to rotate the said wheel until arrested by the set indexing device.

561. The combination with an accumulator, of a set of indexing devices, separately operable keys for selectively controlling the setting of said indexing devices, a yielding device for actuating said accumulator as far as permitted by any of said indexing devices, and a manually operable member to which said yielding device is connected to be directly driven thereby for rotating said number wheel.

562. In a calculating machine, the combination of an accumulator, keys for controlling said accumulator, a carriage correlated with said accumulator, upper and lower horizontal track elements supporting said carriage to travel horizontally therealong, and a manually actuated operation-controlling member for controlling operation of said accumulator according to the control of said keys and for controlling the operative positioning of said carriage along said track.

563. In a calculating machine, the combination of an accumulator, a carriage, a track for said carriage, comprising two horizontal guideways arranged in parallel relation to each other and so that both of said guideways are cut longitudinally by a common plane which is approximately vertical, an operating lever for operating said accumulator, and means controllable by said lever for moving said carriage along said track.

564. In a calculating machine, the combination of an accumulator, a carriage comprising two horizontal guideways arranged in parallel relation to each other and so that both of said guideways are cut longitudinally by a common plane which is approximately vertical, an operating lever for operating said accumulator, and means controllable by said lever for moving said carriage along said track.

nation of an accumulator, a movable carriage, a track for said carriage comprising two horizontal guideways arranged in parallel relation to each other and so that a substantially vertical plane cuts both of said guideways longitudinally, and an operating lever for controlling both the operation of said accumulator and the movement of said carriage.

565. In a calculating machine, the combination of an accumulator, keys for controlling without actuating said accumulator, a carriage movable transversely with relation to said accumulator, a track on which said carriage is mounted for rectilinear movement, a universal manually-actuated operation-controlling member for effecting actuation of said accumulator according to the control of said keys and for causing transverse movement of said carriage, and key-controlled means, independent of said controlling keys, for rendering said operation-controlling member ineffective for causing transverse movement of said carriage.

566. In a calculating machine, the combination with a series of registering wheels, of a series of stops for controlling said registering wheels, a key operatively connected for controlling the operative positions of said series of stops without causing movement of said registering wheels, and means other than said key for actuating said registering wheels according to the control of said stops by said key.

567. In a calculating machine, the combination of a series of registering wheels, a series of controlling devices each comprising a finger-piece which may be set and left in set position and which devices are mounted on a stationary part of the machine, for controlling without causing movement of said registering wheels; a plurality of stop bars one for each of said keys and controllable thereby for controlling the registering movements of said registering wheels; and means, other than said keys, for actuating said registering wheels according to the control of said stops by said keys.

568. In a calculating machine, the combination of a registering wheel, number keys, stop devices settable under control of said number keys for controlling the registering movements of said registering wheel, operating means for setting said stops according to the control of said number keys and for actuating said registering wheel according to the control of said stops, and means which operates to prevent the registering wheel from being actuated by said operating means until a stop device has been set.

569. The combination of a registering mechanism, devices for controlling said registering mechanism, a carriage whereby the

control of said devices is shifted denominational with relation to said registering mechanism, means for moving said carriage, and a détent escapement device for controlling movement of said carriage.

570. In a calculating machine, the combination of an accumulator, a carriage correlated with said accumulator, a spring for moving said carriage, an escapement mechanism, keys and connections for controlling accumulations on said accumulator and for effecting step-by-step movement of said carriage by said spring through the medium of said escapement mechanism, and means independent of said keys and connections for causing movement of said carriage by said spring without causing actuation of said accumulators.

571. A machine comprising a movable carriage, a track, feeding mechanism for moving said carriage step-by-step along said track, a normally inoperative stop for arresting movement of said carriage, and key controlled means for moving said stop from inoperative to operative position.

572. A machine comprising a movable carriage, a track, feeding mechanism for moving said carriage step-by-step along said track, a normally inoperative stop for arresting movement of said carriage, and key controlled means for moving said stop from inoperative to operative position, said means being separate from and independent of any other means for moving said stop.

573. A machine comprising a track; a carriage movable along said track, controlling means for effecting step-by-step movement of said carriage along said track; a stop separate from and independent of said controlling means and being shiftable to an operative position in which it controls movement of said carriage along said track; and means separate from and independent of said controlling means, for shifting said stop from its inoperative position to its operative position.

574. A machine comprising a track; a carriage movable along said track and adapted to be stopped; a movable main stop therefor; means for operating said main stop so as to control movement of said carriage along said track; a movable auxiliary stop for said carriage; and means separate from and independent of the first said means, for moving said auxiliary stop from its inoperative to its operative position.

575. The combination of a track; a carriage operable for step-by-step feeding movement along said track; a dog device for normally arresting said carriage in the step-by-step feeding movements thereof; means for operating said dog device; an auxiliary stop device, for arresting the movement of said carriage along said track, said auxiliary

stop device being ineffective during the normal step-by-step movements of said carriage; and means independent of the first said means, for moving said auxiliary stop device from normal position to carriage-arresting position.

576. A machine comprising a power driven carriage; a main stop device for arresting movement of said carriage; a plurality of keys; intermediate mechanism through the medium of which any one of said keys may actuate said main stop device, for controlling step-by-step movement of said carriage; an auxiliary stop; an auxiliary key; and means connecting said auxiliary key with said auxiliary stop, said auxiliary key and its connecting means being separate from and independent of the first said keys and their intermediate mechanism, for moving the auxiliary stop into its operative position.

577. The combination of a carriage, a plurality of keys, a stop member comprising a plurality of stops coöperative with said keys for effecting step-by-step movement of said carriage, an auxiliary stop member ineffective during the said step-by-step movement of said carriage, a counter-stop for co-operating with said auxiliary stop member, an auxiliary key, and means operable by said auxiliary key independently of said plurality of keys for rendering said auxiliary stop member and counter-stop effective thereby rendering the said plurality of keys and the first said stop member ineffective for causing step-by-step movement of said carriage.

578. The combination of a carriage operable for step-by-step movement; a stop member; a counter-stop; a plurality of keys coöperative with said stop member and counter-stop, for effecting step-by-step movement of said carriage; a second stop member, a second counter-stop, and a key coöperative with said second stop member and second counter-stop, for effecting an auxiliary movement of said carriage and rendering the first said stop member and counter-stop and plurality of keys ineffective.

579. The combination of a track; a power driven and step-by-step movable carriage; a main stop member for arresting said carriage in its step-by-step movement along said track; a plurality of keys, coöperative with said main stop member, for effecting said step-by-step movement of said carriage; an auxiliary stop bar for temporary use in arresting said carriage and which extends in the direction of the said movement of the carriage and which has stops thereon for arresting the carriage at different positions in its said movement, said auxiliary stop bar being ineffective during the normal step-by-step movement of said car-

riage; a counter-stop for coöperating with said auxiliary stop bar; an auxiliary key; and means operable by said auxiliary key, independently of said plurality of keys; for rendering said auxiliary stop bar and counter-stop effective, thereby rendering said main stop member ineffective.

580. In a machine, the combination of a carriage; an escapement member, supported independently of the carriage, for controlling movement of the carriage; a stop mounted on the carriage; a second stop supported independently of the carriage; and a key, supported independently of the carriage, and being operable for effecting movement of said second stop without operating said escapement member, said stops being arranged in such coöperative relation as to effect an auxiliary control of the movement of said carriage independently of the control of the escapement member.

581. The combination with a carriage adapted to be fed step-by-step; and a stop member comprising a plurality of stops capable of arresting said carriage in its step-by-step-movements, of an auxiliary stop bar for temporary use in arresting said carriage and which extends in the direction of said movements of the carriage and which is provided with stops for arresting the carriage at different positions between its limits of movement, said auxiliary stop bar being ineffective in the normal step-by-step movements of said carriage; counter-stop means for coöperation with said stop member and with said auxiliary stop bar; means for enabling said stop member to coöperate with the counter-stop means for effecting normal step-by-step movements of the carriage, and means independent of the second said means, for effecting coöperation of said auxiliary stop bar with the counter-stop means, for temporarily disabling the step-by-step feed of the carriage and effecting the arrest of the carriage.

582. In a machine, the combination of a driven carriage; an escapement member for controlling movement of said carriage; a plurality of keys; connections operable by any of said keys and coöoperative with said escapement member to effect step-by-step movement of said carriage; an auxiliary stop member supported independently of the carriage and being movable independently of said escapement member; an auxiliary key; and means independent of the first said keys and their connections, through the medium of which means said auxiliary key operates to release said carriage from the control of said escapement member and to move said auxiliary stop member for arresting said carriage.

583. A machine comprising a track; a carriage; a main stop member for controlling step-by-step movement of the carriage

along said track; an auxiliary stop member normally out of carriage-arresting position and movable into position for arresting movement of said carriage along said track; and means comprising a contact portion for connecting said main stop member with the carriage and also comprising another contact portion for connecting the auxiliary stop member with the carriage.

584. The combination of a track, a carriage movable along said track step-by-step, a stop element for controlling the step-by-step movements of said carriage, an auxiliary stop element out of use during the normal step-by-step movements of said carriage, and a counter-stop for coöperation with said auxiliary stop element for temporarily arresting the carriage.

585. A machine comprising a track, a carriage, an escapement device for effecting step-by-step movement of said carriage along said track, a normally inoperative stop, and exclusive means operable solely for moving said stop in a plane at right angles to the movement of the carriage, from its inoperative position to its carriage-arresting position.

586. A machine comprising a movable carriage, a stop-bar mounted in an ineffective position relative to said movable carriage and adapted for movement at right angles to its length, and exclusive means operable solely for moving said stop-bar from its ineffective to its carriage-arresting position.

587. A machine comprising a movable carriage; a plurality of escapement stops therefor; a secondary stop arranged to arrest the movement of said carriage independently of said escapement stops and being mounted for movement at right angles to the direction of movement of said movable carriage; and means constructed and arranged solely for moving said secondary stop from its inoperative position to its operative position.

588. The combination with a carriage movable step-by-step; of a stop element which is ineffective during the normal step-by-step movement of said carriage, said stop element being mounted for sliding movement at substantially right angles to the direction of said movement of the carriage; a counter-stop constructed and arranged to coöperate with said element to a position to coöperate with said counter-stop.

589. A machine comprising a movable carriage adapted to be stopped; a movable mainstop therefor; means for operating said main stop; an auxiliary stop for said movable carriage, said auxiliary stop being mounted for movement at right angles to the line of movement of said movable carriage; and means separate from and independent of the first said means, for moving said auxiliary stop from its inoperative to its operative position.

590. A machine comprising a movable carriage adapted to be stopped; a movable mainstop therefor; means for operating said main stop; a stop-bar carrying an auxiliary stop for said movable carriage and mounted for movement into operative position in such manner that all points therein are mounted for movement at right angles to its length; and means, separate from and independent of the first said means, for moving said stop-bar from its inoperative to its operative position.

591. A machine comprising a driven carriage; a main stop device for arresting movement of said carriage; a plurality of keys; intermediate mechanism through the medium of which any one of said keys may actuate said main stop device, for controlling step-by-step movement of said carriage; a bar mounted for movement so that all points in a straight line throughout its length have equal movement; an auxiliary stop carried by said bar; an auxiliary key; and means connecting said auxiliary key with said bar, said key and its connecting means being separate from and independent of the first said keys and their intermediate mechanism, for moving said bar and auxiliary stop into operative position.

592. In a machine, the combination of a carriage, an escapement member for controlling movement of the carriage, a stop movable with said carriage, and a second stop non-controllable by said carriage and being mounted for movement relative to the other of said stops in a plane at right angles to the direction of movement of said carriage, said stops being arranged in such co-operative relation as to effect an auxiliary control of the movement of said carriage independently of the control of said escapement member.

593. In a machine, the combination of a carriage; an escapement member for controlling movement of the carriage; a stop movable with the carriage; a plurality of stops supported independently of the carriage, said plurality of stops being movable relatively to the stop on the carriage and each mounted for movement in a respective plane at right angles to the direction of movement of said carriage; and means for causing said plurality of stops to have uniform movements regardless of the position of the carriage, said stops being arranged in such co-operative relation as to effect an auxiliary control of the movement of said carriage independently of the control of the escapement member.

594. In a machine, the combination of a driven carriage; an escapement member for controlling movement of said carriage; a plurality of keys; intermediate mechanism through the medium of which any one of said keys may actuate said escapement member, to control step-by-step movement of

said carriage; a stop controllable by the carriage; a second stop non-controllable by the carriage, one of said stops being movable relatively to the other in a plane at right angles to the direction of movement of said carriage, said stops being arranged in such co-operative relation as to effect an auxiliary control of the movement of said carriage independently of the control of said escapement member; an auxiliary key; and means, separate from and independent of the first said keys and their intermediate mechanism, through the medium of which means said auxiliary key operates one of said stops, to permit movement of said carriage.

595. In a machine comprising a carriage, and an escapement member for controlling step-by-step movement of the carriage; an auxiliary escapement mechanism which is ineffective during said step-by-step movement of the carriage and which comprises a stop bar which is constantly parallel with the path of movement of said carriage; and has thereon a plurality of carriage-arresting stops; and a counter stop correlated with said carriage, said stop bar being operable to be shifted transversely of its length with a movement that is uniform throughout the length of said bar, so that all of its stops move equal distances into co-operative relation to said counter-stop and into effective position for arresting movement of the carriage.

596. In a machine comprising a carriage, and a feeding device for effecting the normal step-by-step movement of the carriage; an auxiliary device for controlling movement of the carriage and which is ineffective during said normal step-by-step feeding movement and which comprises a bar which is constantly parallel with the path of said movements of said carriage; an element movable with said carriage and correlated with said bar; and means for moving said bar to co-operate with said element to obstruct, at different positions along said bar, the movement of said carriage in said direction.

597. A machine, comprising a driven carriage; a main stop device for controlling movement of the carriage; a plurality of stops separate from said main stop device and normally arranged out of carriage-arresting position in a common plane parallel to the movement of said carriage and mounted for movement to carriage-arresting position in a different common plane which is also parallel to the path of movement of said carriage.

598. In a key controlled machine, the combination of a carriage; a track; a spring; a plurality of escapement stops; a universal bar; a plurality of keys any one of which may be operated to actuate said universal bar, to cause said escapement stops to con-

trol step-by-step movement of said carriage along said track; a counter-stop member; an auxiliary stop member comprising a plurality of auxiliary stops; and an auxiliary 5 key coöperative with said counter-stop member and said auxiliary stop member and arranged to move, independently of said universal bar, one of said members relative to the other the same distance in different 10 positions of said carriage along said track, for effecting movement of said carriage.

599. In a key-controlled machine, the combination of a carriage; a plurality of pivotally mounted members coöperative 15 with said carriage; a track; a spring; a plurality of escapement stops; a universal bar; a plurality of keys any one of which may be operated to actuate said universal bar, to cause said escapement stops to control 20 step-by-step movement of said carriage along said track and to actuate one of said pivotally mounted members; a counter-stop member; an auxiliary stop member comprising a plurality of auxiliary stops; and an auxiliary 25 key coöperative with said counter-stop member and said auxiliary stop member and arranged to move, independently of said universal bar, one of said members relative to the other the same distance in different 30 positions of said carriage along said track, for effecting movement of said carriage without actuating said pivotally mounted members.

600. A machine comprising a movable 35 carriage; a spring; a main stop device; a plurality of keys; universal connecting means between said keys and said main stop device, whereby any of said keys may actuate said stop device, to effect step-by-step 40 movement of said carriage by said spring; a plurality of stops separate from said stop device and normally arranged out of carriage-arresting position in common plane parallel to the path of movement of said 45 carriage and mounted for movement to carriage-arresting position in a different common plane which is also parallel to the path of movement of said carriage; a key; and connections coöperative with said key and 50 independent of said universal connecting means, for effecting, through the medium of said stops, a secondary control of the movement of said carriage by said spring.

601. The combination of a carriage; a 55 spring for effecting movement of said carriage in one direction; a plurality of main stops for arresting said movement of the carriage; a plurality of auxiliary stops independent of said main stops and arranged 60 in a common plane parallel to the path of movement of said carriage and mounted to be moved, for arresting movement of said carriage, to a different common plane which is also parallel to the path of movement of said carriage.

602. A machine comprising a movable carriage; a main stop device, comprising a series of stops, mounted separately from the carriage, for arresting movement of said carriage; an auxiliary stop device for arresting movement of said carriage; and means comprising a contact portion for connecting said main stop device with the carriage and comprising a separate contact portion for connecting the auxiliary stop 75 device with the carriage.

603. A machine comprising a driven carriage; a series of escapement stops; manually operable means coöperative with said escapement stops for controlling movement 80 of said carriage; a graduated scale; a pointer coöperative with said scale for indicating the different positions of said carriage in its path of movement; said scale having its graduations corresponding with 85 the respective stops of said series; a plurality of auxiliary stops which are normally inoperative and each of which when in its operative position always corresponds with one of the graduations of said scale; and means independent of the first said means, for moving said auxiliary stops from inoperative to operative position.

604. The combination of a movable carriage; a spring for moving said carriage; a 95 plurality of main stops for arresting the normal feeding movements of said carriage; a plurality of actuating keys; means whereby the operation of any one of said actuating 100 keys permits said spring to move said carriage from one stop to another of said main stops; a plurality of auxiliary stops for temporarily arresting movement of said carriage; an auxiliary key; and means separate from and independent of the first said 105 means, and operatively connecting said auxiliary key with said auxiliary stops, for releasing said carriage from the control of one of said main stops and allowing the carriage to be moved by its spring until arrested 110 by one of said auxiliary stops and to thereafter release said carriage to be again arrested by one of said main stops.

605. The combination with a plurality of actuating keys, a carriage, a track upon 115 which said carriage is mounted to move back and forth, a spring for driving said carriage in one direction, a detent escapement device, a universal element whereby said escapement device is actuated to allow said 120 spring to move said carriage a step whenever any one of said actuating keys is operated, of a key, and a member controllable by the last said key independent of said actuating keys and their universal element to said escapement device, for effecting 125 an auxiliary movement of said carriage.

606. The combination with a plurality of actuating keys; a carriage; a track upon 130 which said carriage is mounted to move

back and forth; a spring for driving said carriage in one direction; a detent escapement device comprising a pawl member and a main stop member; a universal element 5 whereby said escapement device is actuated, to allow said spring to move said carriage a step whenever any one of said actuating keys is operated; a secondary key; and secondary stops coöperative with said secondary 10 key independently of said universal element, whereby said pawl member is temporarily freed from said main stop member, for allowing said carriage to move under the power of its spring until arrested by one 15 of said secondary stops and whereby said pawl member is again allowed to coöperate with the main stop member.

607. The combination of a movable carriage, a spring for moving said carriage, a 20 main stop device for arresting the movement of said carriage, with an auxiliary stop member for arresting the movement of said carriage, and means for moving said auxiliary stop member from an inoperative to an 25 operative relationship with said carriage.

608. The combination of a movable carriage; a spring for moving said carriage; a main stop device for arresting the movement of said carriage; and an auxiliary stop 30 member for temporarily arresting the movement of said carriage, said auxiliary stop member being movable from an inoperative to an operative relationship with said carriage, whereupon said carriage is disengaged from said main stop device and engaged with said auxiliary stop member, so that said carriage is permitted to be moved by the power of its spring until arrested by said auxiliary stop member.

609. A machine comprising a movable carriage; a plurality of stops normally mounted in an inoperative position relative to said movable carriage, and means for simultaneously moving all of said stops the 45 same distance into an operative position for stopping said movable carriage.

610. The combination of a carriage; an escapement mechanism for normally effecting step-by-step movement of said carriage; 50 a stop member which is ineffective during the normal step-by-step movement of said carriage; a key; and mechanism, solely controllable by said key, for releasing the carriage from said escapement mechanism and giving said stop member a movement of 55 fixed extent to a definite predetermined operative position prior to the advanced movement of the released carriage which advanced movement results from the release of 60 said carriage.

611. The combination of a carriage; means for effecting step-by-step movement of said carriage; a stop which is ineffective during the step-by-step movement of said carriage; 65 a key; and mechanism, solely controllable by

said key, for giving said stop a movement to a definite predetermined carriage-stopping position regardless of the position of said stop relative to the limits of movement of said carriage.

612. The combination of a power driven carriage; mechanism for controlling step-by-step movement of said carriage, said carriage being releasable from the control of said mechanism; a stop which is ineffective 70 during the normal step-by-step movement of said carriage; a key; and mechanism solely controllable by said key, for releasing the carriage from the control of the first said mechanism and giving said stop a movement 75 of fixed extent to a definite predetermined operative position regardless of the position of the carriage.

613. The combination of a carriage, means for effecting step-by-step movement of said carriage, a set of stops which is ineffective 80 during the normal step-by-step movement of said carriage, a key, and mechanism solely controllable by said key, for giving said set of stops a movement to a definite predetermined carriage-stopping position regardless 85 of the position of the stop of said set relative to the limits of movement of said carriage.

614. The combination of a power-driven carriage; mechanism for controlling step-by-step movement of said carriage, said carriage being releasable from the control of said mechanism; a set of stops which is ineffective 90 during the normal step-by-step movement of said carriage, a key; and mechanism solely controllable by said key, for releasing the carriage from the control of the first said mechanism and giving said 95 set of stops a movement of fixed extent to 100 a definite predetermined operative position regardless of the position of the carriage.

615. The combination of a power-driven, step-by-step moving carriage; keys; stops correlated with said keys for controlling the 110 step-by-step movement of said carriage; a plurality of auxiliary stops normally out of carriage-arresting position; a counter stop movable with said carriage; and an auxiliary key operable for simultaneously 115 moving all of said stops equal distances relative to the path of movement of said counter-stop, for arresting said carriage, said auxiliary key also being operable to release the carriage from the control of the 120 first said keys.

616. The combination of a power-driven, step-by-step moving carriage; keys; stops correlated with said keys, for controlling the step-by-step movement of said carriage; 125 a plurality of auxiliary stops normally out of carriage-arresting position; a counter-stop movable with said carriage; and a plurality of auxiliary keys each operable for simultaneously moving a plurality of said 130

stops equal distances relative to the path of movement of said counter-stop, for arresting said carriage, each of said auxiliary keys also being operable to release the carriage from the control of the first said keys.

617. The combination of a carriage movable step-by-step, keys for controlling step-by-step movement of said carriage, auxiliary stops which are ineffective during the 10 normal step-by-step feeding movement of the carriage, an auxiliary key, means controllable by said auxiliary key for both releasing the carriage from the control of said keys and effecting setting movement of said auxiliary stops, and fixed means for limiting said setting movement of said auxiliary stops, whereby the latter are always brought to a predetermined position by the working stroke of the auxiliary key.

618. The combination of a carriage, a spring for moving said carriage, a main stop device for arresting said carriage in different positions against movement by said spring, an auxiliary stop independent of 25 said main stop device and normally inoperative with relation to said carriage, and key-operated means for positioning said stop in operative relation to said carriage.

619. The combination of a carriage, a 30 spring for moving said carriage, a main stop device for arresting said carriage in different positions against movement by said spring, a plurality of auxiliary stops independent of said main stop device and normally inoperative with relation to said carriage, and a plurality of keys for moving said stops into operative relation to said carriage.

620. The combination of a carriage, a 40 spring for moving said carriage, a main stop device for arresting said carriage in different positions against movement by said spring, a plurality of auxiliary stops independent of said main stop device and normally inoperative with relation to said carriage, and key operated means for simultaneously moving said stops an equal distance into operative relation with said carriage.

621. The combination of a carriage; a track upon which said carriage is mounted to move; a spring for driving said carriage; a main detent escapement mechanism comprising stops for controlling the movement 55 of said carriage under the driving power of said spring and normally in operative relation to said carriage; a plurality of actuating keys; universal connecting means, between said actuating keys and said escapement mechanism, whereby the latter is actuated upon the operation of any one of said keys, to permit step-by-step movement of said carriage under the propelling power of said spring; an auxiliary stop independent 60 of said actuating keys and said main stops

and normally in an ineffective position with relation to said carriage; and a key independent of said actuating keys, for positioning said auxiliary stop in an effective position with relation to said carriage.

70

622. In a key controlled machine, the combination of a movable carriage; an escapement device; a set of keys and a universal intermediate connection co-operatively connected with said escapement, for controlling movement of said carriage; a supplemental key and an intermediate connection, independent of and separate from the said set of keys and its universal connection, co-operatively connected with the escapement 75 device, for effecting a supplemental control of the carriage; and means for rendering said supplemental key ineffective with relation to said escapement.

80

623. The combination with a carriage, of 85 a step-by-step feeding mechanism comprising a set of stops and a co-operative dog or stop device, a key-mechanism for advancing the carriage by means of said step-by-step feeding mechanism, a second key-mechanism independent of the first said key-mechanism, and means comprising a separate set of stops arranged to be controlled by said second key-mechanism exclusively, for also controlling the advancing movements of said 90 carriage.

95

624. In a key controlled machine, the combination of a carriage, a spring for moving said carriage, a main stop device comprising a pawl device for arresting the movement of said carriage, a plurality of controlling keys, means common to all of said controlling keys for actuating said main stop device to permit step-by-step movement of said carriage by said spring, an auxiliary stop for arresting the movement of said carriage, an auxiliary controlling-key, and connections between said auxiliary controlling key and said auxiliary stop which are constructed and arranged independent 100 of the first said means, whereby the carriage may be released from control of the main stop device and allowed to move until its movement is arrested by the auxiliary stop.

105

625. The combination with a movable carriage, of an escapement mechanism for controlling normal step-by-step movements of said carriage, a plurality of auxiliary stops for temporary use in arresting said carriage and being ineffective during the normal step-by-step movements of the said carriage under the control of said escapement mechanism, and a plurality of manually movable devices operable independently of one another for moving said auxiliary stops from 110 ineffective position to carriage arresting position.

115

626. A machine comprising a track; a carriage on said track; an escapement device; a plurality of actuating keys; universal 120

125

130

means for operatively connecting said actuating keys with said escapement device, for effecting step-by-step movement of said carriage along said track; a plurality of spacing keys, and means operatively connected with said spacing keys, separate from and independent of said universal means, for effecting auxiliary movement of the carriage along said track.

10 627. The combination of a movable carriage; a set of keys; a plurality of stops controllable by said keys, for effecting a control of the movement of said carriage; a second set of keys; and a second set of stops controllable by said second set of keys, for effecting an auxiliary control of the movement of said carriage.

15 628. The combination with a movable carriage, of a stop-device comprising a bar which extends in the direction of the movement of the carriage and is provided with means for temporarily arresting movement of the carriage at different points between its limits of movement and being normally ineffective, and a plurality of manually movable devices operable independently of one another, for moving said stop device from ineffective position to carriage arresting position.

20 629. The combination with a carriage, of movable stops for temporary use in arresting said carriage and being normally ineffective and mounted for movement to carriage arresting positions; and a plurality of trains of connections operatively related to said stops, for moving the latter from ineffective to carriage arresting positions, each of said trains comprising a manually operable device, and each train being operable independently of the other of said trains.

25 630. A machine comprising a track; a carriage on said track; an escapement device; a plurality of actuating keys; a universal device operatively connecting said keys with said escapement device, for effecting step-by-step movement of said carriage along said track; a spacing key; means separate from and independent of said universal device, and operatively connected to said spacing key, for effecting a supplemental control of the carriage along said track; an auxiliary spacing key; and means separate from and independent of said universal device and operatively connected with said auxiliary spacing key, for effecting an auxiliary control of the carriage independently of said actuating keys and said spacing key.

30 631. The combination of a carriage; a spring for driving said carriage; an escapement mechanism for controlling movement of said carriage; a plurality of actuating keys; universal connecting means, for connecting said keys with said escapement mechanism, to actuate the latter, whereby the carriage is permitted to move upon the

actuation of any of said keys; a plurality of auxiliary stops; an auxiliary key; and connections between said auxiliary key and said auxiliary stops, which connections are separate from and independent of the connections between said escapement and said actuating keys and which connections are constructed and arranged to cause simultaneous equal movement of said auxiliary stops when said auxiliary key is depressed.

35 632. A machine comprising a movable carriage; a set of stops; a plurality of actuating keys; mechanism for connecting said stops with said keys, for controlling movements of said carriage; a second set of stops independent of the first said set; a skipping key independent of said actuating keys; and mechanism independent of the first said mechanism, for connecting said skipping key with the second said stops and for rendering a predetermined stop of the first said set ineffective and rendering a succeeding stop of the first said set effective, thereby effecting an auxiliary control of said carriage.

40 633. In combination with a carriage, a plurality of actuating keys, connections operable thereby for effecting movement of the carriage, a plurality of spacing keys independent of each other and of said actuating keys and connections independent of the connections of said actuating keys, the last said connections correlating said spacing keys with said carriage.

45 634. The combination of a carriage; a plurality of keys; means controllable by said keys for effecting spacing movement of said carriage; a plurality of auxiliary keys, one operable independently of the other; and mechanism controllable by said auxiliary keys only, for effecting spacing movement of said carriage by releasing the carriage from the control of the first said keys and subjecting it to the control of the auxiliary keys, and thereafter restoring the carriage to the control of the first said keys.

50 635. The combination of an escapement mechanism comprising a pawl device and stop teeth, operating means therefor, a plurality of auxiliary stops independent of the stop teeth of said escapement mechanism and normally out of carriage-arresting position, and operating means for said auxiliary stops, whereby the latter are moved into carriage-arresting position, said operating means being independent of the operating means of said escapement mechanism.

55 636. The combination of a movable carriage, a spring for moving said carriage, a main escapement stop mechanism for normally holding said carriage against movement by said spring, operating means whereby said escapement stop mechanism may be operated to allow step-by-step movement of said carriage under the propelling

power of said spring, a plurality of normally inoperative auxiliary stops, and auxiliary operating means independent of said operating means for said escapement stop mechanism, whereby said auxiliary stops are operated to release said carriage from the control of said escapement stop mechanism and allow it to be moved by the propelling power of said spring until arrested by said auxiliary stops.

637. In a key-controlled machine; the combination of a carriage movable step-by-step; a stop member movable concomitant with the step-by-step movement of said carriage and instrumental in stopping said carriage; a key supported independently of said carriage; connecting means from said key to said stop member, for effecting a spacing movement of said carriage; a second key supported independently of said carriage; and connecting means from said second key to said stop member, for effecting a spacing movement of said carriage, the last said connecting means being independent of the first said connecting means.

638. In a key-controlled machine the combination of a carriage movable step-by-step; a plurality of stops movable concomitant with the step-by-step movement of said carriage and instrumental in stopping said carriage; a key supported independently of said carriage; connecting means from said key to one of said stops, for effecting a spacing movement of said carriage; a second key supported independently of said carriage; and connecting means from said second key to one of said stops for, effecting a spacing movement of said carriage, the last said connecting means being independent of the first said connecting means.

639. In a key-controlled machine, the combination of a carriage; means for moving said carriage; keys; a main stop mechanism common to all of said keys and cooperative therewith for causing the carriage to move a definite space at each stroke of any one of said keys; a supplemental spacing key; and a supplemental stop mechanism independent of said main stop mechanism, for controlling secondary movement of said carriage, operable by said supplemental spacing key for releasing the carriage from the main stop mechanism and simultaneously interposing a supplemental stop to arrest said secondary movement of said carriage.

640. A machine comprising a carriage, means for moving the carriage, a main stop device for arresting movement of the carriage, operating means for said main stop device, a secondary stop element normally out of carriage-arresting position and movable relative to said main stop device, and

operating means for said secondary stop element separate from and independent of the operating means of the main stop device, and whereby said secondary stop element is moved into carriage-arresting position.

641. The combination of a carriage; a step-by-step feeding rack therefor; an auxiliary stop device comprising a bar extending in the direction of the transverse movement of the carriage and having means for arresting the carriage at different positions; a counter-stop device common to said rack and to said auxiliary stop bar; means to effect co-operation between said counter-stop device and said rack, for effecting step-by-step movements of said carriage; and means independent of the first said means, for effecting co-operation between said counter-stop device and said auxiliary bar, for arresting said carriage independently of said rack.

642. In a machine, the combination of a carriage; a spring for moving said carriage in one direction; a plurality of series of main stops for arresting the movement of said carriage by said spring, each series comprising more than two stops; a plurality of actuating keys; universal means operatively connecting said plurality of keys with said main stops, whereby any of said keys may cause said carriage to move step-by-step by power of said spring; an auxiliary stop; an auxiliary key; and means independent of said universal means, for connecting said auxiliary key with said auxiliary stop, to effect an auxiliary control of said carriage.

643. The combination of a driven carriage; means, comprising a plurality of keys and two sets of stops and a universal connection between said keys and stops, for controlling movement of the carriage by the depression and release of any one of said keys, each of said sets comprising stop-teeth fixed with relation to each other; an auxiliary stop member mounted independently of the said two sets of stops; and means comprising a key, for releasing the carriage from the control of the said two sets of stops and for effecting an auxiliary control of the carriage independently of the said universal connection.

644. A machine comprising a carriage; two sets of primary stops supported independently of said carriage; means co-acting with said stops for controlling movement of the carriage; a secondary set of stops; and means co-acting with said secondary set of stops, for releasing said carriage from the control of said primary stops and effecting an auxiliary control of the movement of said carriage.

645. The combination of a carriage mounted for key-controlled horizontal and verti-

cal movements; a track; means for moving the carriage in a horizontal direction along said track; a set of pivotally mounted members; two sets of primary escapement stops supported independently of said carriage, for controlling movement of said carriage in said horizontal direction; a plurality of keys for actuating said pivotally mounted members and coöperative with said stops for controlling movement of said carriage; a secondary set of stops; and means coöperative with said secondary set of stops, for releasing said carriage from the said primary escapement stops and effecting a supplemental control of the carriage.

646. The combination of a main frame; a carriage mounted for key-controlled horizontal and vertical movement; a track; means for moving the carriage in a horizontal direction along said track; a set of pivotally mounted members; two sets of primary escapement stops supported independently of said carriage, for controlling movement of said carriage in said horizontal direction; a plurality of keys for actuating said pivotally mounted members and coöperating with said stops, for controlling movement of said carriage; a secondary set of stops; and means coöperating with said secondary set of stops, for releasing said carriage from the said primary escapement stops and effecting a supplemental control of the carriage; and means, comprising a key supported independently of said carriage, for moving the said carriage in the opposite horizontal direction.

647. In combination, a set of pivotally mounted members; a track; a carriage movable vertically relatively to said pivotally mounted members; means for moving the carriage along said track in one direction; two sets of primary escapement stops, supported independently of said carriage, for effecting step-by-step movement of the carriage, said sets of stops being arranged with the teeth of one set normally in advance of corresponding teeth of the other set, one set being movable relatively to the other so as to position the normally advanced teeth rearward of the teeth of the other set; a plurality of keys for actuating said pivotally mounted members and coöperating with said stops for controlling movement of said carriage; a set of secondary stops; and means coöperative with said set of secondary stops, for releasing said carriage from control of said primary escapement stops and effecting a supplemental control of the carriage.

648. In combination, a set of pivotally mounted members; a track; a carriage movable vertically relatively to said pivotally mounted members; means for moving the carriage along said track in one direction;

two sets of primary escapement stops supported independently of said carriage, for effecting step-by-step movement of said carriage, said sets of stops being arranged with the teeth of one set normally in advance of corresponding teeth of the other set, one set being movable relatively to the other; a plurality of keys for actuating said pivotally mounted members and coöperating with said stops, for controlling movement of said carriage; a set of secondary stops; and means coöperative with the said set of secondary stops, for releasing said carriage from control of the said primary escapement stops and effecting a supplemental control of the carriage.

649. In a machine, the combination of a carriage, a track upon which said carriage is mounted, a spring for moving said carriage along said track in one direction, a plurality of pivotally mounted members, a detent escapement mechanism for controlling said moving of said carriage, a plurality of actuating keys for actuating said escapement mechanism and said members, a space-key coöperative with said escapement to effect movement of said carriage without actuating any of said members, a space-bar, a supplemental space-key coöperative with said escapement, for freeing said carriage from said escapement and for moving said space-bar to exert a supplemental control of said moving of said carriage.

650. In a machine, the combination of a carriage, a track upon which said carriage is mounted, a spring for moving said carriage along said track in one direction, a plurality of pivotally mounted members, a detent-escapement mechanism for controlling said moving of said carriage, a plurality of actuating keys connected to for actuating said escapement mechanism and said members, a space-key coöperative with said escapement to effect movement of said carriage without actuating any of said members, a space-bar, a supplemental space key coöperative with said escapement for freeing the said carriage from said escapement and for moving said space-bar to exert a supplemental control of said moving of said carriage, and connections between said space-bar and said supplemental space key, said connections being separate from and independent of the connections between said actuating keys and said escapement mechanism and said members.

651. The combination of a movable carriage, a spring for moving said carriage, a main stop member for controlling said moving of said carriage, a plurality of auxiliary stops, a controlling key coöperative with said auxiliary stops for controlling said moving of said carriage, and key-controlled means for rendering said auxiliary

stops operative and inoperative with relation to said controlling key.

652. The combination of a movable carriage, a spring for moving said carriage, a main stop member for controlling said moving of said carriage, a plurality of auxiliary stops, a controlling key coöperative with said auxiliary stops for controlling said moving of said carriage, a key for rendering said auxiliary stops operative with relation to said controlling key, and a key for rendering said auxiliary stops inoperative with relation to said controlling key.

653. In a key-controlled machine the combination with a movable carriage; of mechanism for moving said carriage step-by-step in a horizontal direction and for moving said carriage in the opposite direction and for moving said carriage vertically; and a key, supported independently of said carriage, for controlling said mechanism.

654. The combination of a movable carriage, a series of controlling keys, an escapement device coöperatively connected with the controlling-keys for controlling movement of said carriage, and locking means arranged for rendering said escapement device inactive until one of said controlling keys is depressed a predetermined distance.

655. In combination, a movable carriage, an escapement device for controlling movement of said carriage, locking-means for holding the escapement device in a temporarily fixed position, and operating means for first freeing said escapement device from said locking-means and thereafter actuating said escapement device and thereby allowing movement of said carriage.

656. The combination with a power driven carriage, and an escapement mechanism therefor, of a lock normally holding the escapement mechanism against actuation, a series of keys for operating said escapement mechanism, and means to enable any of said keys to release said lock, for permitting the escapement mechanism to be operated.

657. The combination of a carriage frame, a transverse bar provided with a locking mechanism whereby the frame is locked in a depressed position, and a key lever for connecting with said transverse bar, whereby the carriage frame is released upon depressing the key lever.

658. The combination of a carriage frame having side arms, a transverse bar connecting the side arms of said frame and provided with a pivoted locking lever whereby the carriage frame is locked in a depressed position, and a key lever operable to connect with said transverse bar so as to release the carriage frame upon depressing the key lever.

659. The combination of a carriage frame,

locking means whereby the frame is locked in a depressed position, a key, and means controllable by said key and which operates to unlock said frame when said key is actuated.

660. The combination of a movable carriage; means for moving said carriage; an escapement mechanism comprising a universal member, for controlling movement of said carriage; a plurality of pivotally mounted members; and a plurality of actuating keys, one for each of said pivotally mounted members and connected therewith for moving said pivotally mounted members, and each of said keys being arranged to begin to actuate said universal member nearer the completion than the beginning of the movement, of the respective pivotally mounted member, effected during the down-stroke of the actuated key.

661. The combination of a movable carriage, a spring for moving said carriage in one direction, a detent escapement mechanism for controlling step-by-step movement of said carriage, a plurality of controlling keys for actuating said escapement mechanism, and a locking device arranged to prevent said controlling keys from actuating said escapement mechanism unless said controlling keys have been depressed a predetermined distance.

662. The combination of a movable carriage, a series of controlling keys, key-actuated mechanism for effecting step-by-step movement of said carriage, locking means effective to prevent relative movement of said carriage unless one of said controlling keys is depressed a predetermined distance, and hand operated mechanism independent of said controlling keys and said locking means, for controlling movement of said carriage.

663. A key controlled machine comprising a movable carriage, a carriage-stop device having relatively movable members certain of which being normally locked against movement, and a member mounted in operative relation to said stop device, for first unlocking and thereafter operating said stop device.

664. A key-controlled machine comprising a rectilinear track, a carriage mounted to travel along said track, a carriage-stop device comprising relatively movable members certain of which being normally locked against movement, and a key-lever mounted in operative relation to said stop device for first unlocking said stop device and thereafter controlling movement of the latter.

665. A machine comprising a carriage; means for moving said carriage in one direction; a plurality of actuating keys; and an escapement mechanism, for said carriage, comprising a universal member arranged to

- be actuated by any one of said actuating keys, only after the key has been moved a considerable portion of its stroke.
666. A machine comprising a movable carriage, a stop-device for controlling movements of said carriage, and a key lever for controlling the stop-device, said key lever having different effective points of fulcrum during different parts of its movement.
667. A machine comprising a movable carriage; driving means for said carriage; an escapement device for controlling movements of said carriage; and a series of key-levers for controlling said escapement device, each of said key-levers having different effective points of fulcrum during different portions of its movement.
668. The combination of a movable carriage, a key-lever having different effective points of fulcrum during different portions of its stroke and which key-lever is operative for controlling movement of the carriage, and a key-lever having a single point of fulcrum and being operative for effecting an auxiliary control of the movement of the carriage, both said key-levers being supported independently of said carriage.
669. The combination of a carriage, a key-lever having different effective points of fulcrum during different portions of its stroke and which key lever is operative for controlling forward movement of said carriage, a key-lever having a single point of fulcrum and being operative for exerting an auxiliary control of said forward movement of the carriage, and a key-lever for controlling backward movement of said carriage, all of said key-levers being supported independently of the carriage.
670. The combination with the main frame, of a movable carriage, two frames movably supported on the main frame, and a connecting device pivotally secured to each of the said two frames, for controlling movement of said carriage.
671. The combination with a movable carriage, of a frame upon which said carriage is mounted, a second frame comprising a rock shaft provided with arms, and a plurality of links immediately connecting said arms with the first said frame, said frames being coöperative for guiding and shifting said carriage.
672. The combination with a main frame; of a movable carriage; a movable frame upon which said carriage is mounted for step-by-step movement; a frame coöperative with said movable frame, for guiding and shifting said carriage; and keys for controlling step-by-step movement of said carriage.
673. The combination with a main frame; of a movable carriage; a movable frame upon which said carriage is mounted for step-by-step movement; a frame comprising a rock shaft and arms; links connecting said arms with said movable frame, said frames being coöperative for guiding and shifting said carriage; and means for causing step-by-step movement of said carriage.
674. The combination with a main frame, of a movable carriage, a guiding and shifting device comprising two frames, connecting means pivotally secured to each of the said two frames, and a spring for propelling said carriage along said guiding and shifting device.
675. The combination of a reciprocatory member, and a pivotally mounted member having two elements rigid with relation to each other and pivotally and permanently connected to said reciprocatory member by means comprising axially alined pivot-bearings spaced apart so that each of said pivot-bearings reciprocates through a distance equal to the distance through which the other of said pivot-bearings reciprocates, the pivotal axis of said reciprocatory member being parallel with the axial line of said pivot-bearings.
676. The combination of a reciprocatory member, and a pivotally mounted member having two elements rigid with relation to each other and pivotally connected to said reciprocatory member by means comprising axially alined pivot-bearings spaced apart so that each of said pivot-bearings reciprocates through a distance equal to the distance through which the other of said pivot-bearings reciprocates, the pivotal axis of said reciprocatory member being parallel with the axial line of said pivot-bearings, said reciprocatory and pivotally mounted members being relatively substantially immovable longitudinally of their axes.
677. The combination with a movable carriage, of two hingedly mounted frames, and a connecting device movably secured to each of said frames, for securing said frames together, said frames being coöperative for supporting said carriage and for guiding and shifting the latter.
678. The combination with a movable carriage; of two hingedly mounted frames; a connecting device movably secured to each of said frames, for securing said frames together, said frames being coöperative for supporting said carriage and for guiding and shifting the latter, a spring for driving the carriage; keys; and means controllable by said keys, for permitting said carriage to advance step-by-step under the impulse of said spring.
679. The combination with a main framework, of a hingedly mounted frame comprising a track extending crosswise of the machine, a rock shaft mounted on the main framework, arms on said rock shaft connected to said hingedly mounted frame, a car-

riage supported on said track, and mechanism for causing said carriage to advance step-by-step along said track.

680. In a key-controlled machine, the combination of a horizontal rock shaft extending crosswise of the machine, arms extending from said rock shaft, links extending from said arms, a shifting-frame immediately joined to said links, a carriage mounted on said shifting-frame, keys, and mechanism under the control of said key, whereby horizontal step-by-step movement of said carriage is effected.

681. The combination of a carriage, a pivotally mounted frame on which said carriage is supported to move horizontally with relation to said pivotally mounted frame, and a key-lever supported independently of said carriage and coöperative with said frame, for raising said carriage.

682. The combination in a key controlled machine, of a horizontal rock-shaft extending crosswise of the machine; arms rigid with said rock-shaft; links extending from said arms; a carriage; a track; and means for moving said carriage step-by-step along said track, said track being connected to said links and extending crosswise of the machine, for guiding said carriage crosswise of the machine and shifting said carriage in a direction transverse to the direction of its step-by-step movement.

683. The combination of a carriage, a pivotally mounted frame on which said carriage is supported to move horizontally with relation to said pivotally mounted frame, a key-lever supported independently of said carriage and coöperative with said frame for raising said carriage, and an equalizing device for controlling said raising of said carriage.

684. The combination with a main frame, of a horizontal rock shaft extending crosswise of the machine, arms rigid with the said rock shaft, links extending from said arms, a horizontal track extending crosswise of the machine and connected at its ends with said links, a carriage mounted on said track to travel therealong step-by-step and to be shifted up and down thereby, and feeding devices for controlling step-by-step movements of said carriage.

685. The combination with a main frame, of a horizontal rock shaft extending crosswise of the machine, arms rigid with said rock shaft, links extending from said arms, a horizontal track extending crosswise of the machine and connected at its ends with said links, a carriage mounted on said track to travel therealong step-by-step and to be shifted up and down thereby, and feeding devices for controlling the step-by-step movements of said carriage, said feeding devices including elements shiftable up and down with said track.

686. In a machine, the combination of a horizontal track extending crosswise of the machine; a carriage wholly supported on said track; a frame whereon said track is mounted, said frame and track being bodily shiftable; and keys for causing feeding of the carriage along said track.

687. In a machine, the combination of a rock shaft, arms extending therefrom, a horizontal track extending crosswise of the machine, means linking said arms to said track, and a carriage mounted on said track to travel step-by-step therealong and be shifted thereby in a direction transverse thereof.

688. The combination with a carriage arranged for step-by-step movement, and a shiftable support therefor comprising a hinged frame, of a rock shaft, links connecting the rock shaft with the hinged frame, and key controlled means for shifting said hinged frame.

689. The combination with a main framework, of a track device connected thereto, a rock shaft supported on the main framework independently of said track device, means connecting said rock shaft to the opposite ends of the track device, and a carriage mounted to travel step-by-step on said track device and shiftable transversely thereby.

690. The combination with a main framework, of a track device connected thereto, a rock shaft supported on the main framework independently of said track device, means connecting said rock shaft to the opposite ends of the track device, a carriage mounted to travel step-by-step on said track device and shiftable transversely thereby, a spring connected to said carriage to propel the same, and key-controlled devices for controlling the step-by-step travel of said carriage effected by said spring.

691. In combination, a main frame, a light and primarily yieldable frame pivotally connected to said main frame, a relatively rigid member pivotally connected to the main frame, and rigid connecting means pivoted to said relatively rigid member and to said primarily yieldable frame for bracing the latter while allowing free movement thereof, on its pivotal connection.

692. The combination in a key-controlled machine, of a light and primarily yieldable frame pivotally supported at a considerable distance from its free end, keys for easily raising the said free end, a relatively rigid member pivotally supported near said primarily yieldable frame, and rigid bracing means pivotally connecting opposite sides of said frame with said relatively rigid member.

693. An escapement mechanism comprising two sets of stops, a detent in position to be engaged with said stops alternately, and means for changing the relative positions

of said sets of stops to render said escape-
ment inoperative.

694. In combination, a carriage; a stop device; a controlling key coöperative with said stop device, for controlling intermittent movement of said carriage; and a hand-operated device correlated with said stop device, for modifying said intermittent movement of said carriage.

10. 695. The combination of a step-by-step movable carriage; two sets of stops for controlling the step-by-step movements of said carriage, one of said sets being movable relative to the other in a path in which all relative movements between said sets of stops are solely for the purpose of modifying the controlling effect of said stops relative to said carriage; and means for retaining said sets of stops in said relative position.

20. 696. In an escapement mechanism, the combination of a stop member comprising a plurality of stops, a coöperative counter-stop member, means for moving one of said members relatively to the other for rendering said escapement mechanism inoperative, and means for retaining the moved member in moved position.

30. 697. An escapement mechanism comprising two sets of controlling stops, one of said sets being movable relative to the other in a path in which all relative movements between said sets of stops are solely for the purpose of modifying the controlling effect of said stops, in combination with means for retaining the moved set of stops in moved position.

40. 698. In an escapement mechanism, the combination of two sets of stop teeth, one of said sets being adjustable relative to the other set; and means for detaining the adjusted set in adjusted position.

45. 699. The combination of a movable carriage; an escapement mechanism for controlling movement of said carriage; a plurality of keys; connections operable by said keys, for controlling said escapement mechanism; and means supported independently of said carriage and operable independently of said keys and said connections, for rendering said escapement mechanism inoperative.

50. 700. The combination of a carriage, a set of stops, a second set of stops, a dog for co-operation with said stops, keys for causing the dog to shift from a stop in one set to a stop in the other set for feeding the carriage, and means for causing a relative shifting between said sets of stops, for preventing the shifting of said dog from one set of stops to the other, whereby feeding of the carriage upon the operation of said keys is prevented.

55. 701. The combination of a power-driven carriage; a pair of feed members; a third feed member coöperative with said pair by escaping from one member to the other

thereof; a key for causing coöperation of said feed member, for feeding said carriage; and means for causing relative shifting between the members of said pair, for preventing the normal escaping action of said third feed member.

702. The combination of a movable carriage, an escapement device therefor, an actuating member operatively connected with said escapement device and adapted to contact therewith for effecting step-by-step movements of said movable carriage, and means for rendering said escapement device inoperative, whereby the carriage is retained in a fixed position by the escapement device during the operation of said actuating member.

703. The combination of a carriage; a support upon which said carriage is mounted to move; a spring for moving said carriage; a detent escapement mechanism for controlling said moving of said carriage; a plurality of actuating keys; universal connecting means, between said actuating keys and said escapement mechanism, whereby the latter is actuated to permit a step-by-step movement of said carriage, under the propelling power of its spring, at each operation of any one of said actuating keys; and means for rendering said escapement mechanism inoperative, whereby the carriage is retained in a fixed position during the successive operations of said actuating keys.

704. The combination of a machine frame; a carriage movable transversely with relation thereto; a spring for driving said carriage in one direction; an escapement device coöperative with said spring, for effecting step-by-step movement of said carriage; a plurality of actuating keys; universal connecting means, between said keys and said escapement stop device, whereby the depression of any one of said keys causes said escapement device to permit said step-by-step movement of said carriage; and a device independent of said actuating keys and said universal connecting means and supported independently of said carriage, for releasing said carriage from said escapement device.

705. The combination of a machine frame; a carriage movable transversely with relation thereto; a spring for driving said carriage in one direction; an escapement device, coöperative with said spring, for effecting step-by-step movement of said carriage; a plurality of actuating keys; universal connecting means, between said keys and said escapement device, whereby the depression of any one of said keys causes said escapement device to permit said step-by-step movement of said carriage; a controlling device independent of said actuating keys and said universal connecting means and supported

independently of said carriage, for releasing said carriage from said escapement device; and a key, supported independently of said carriage, for actuating said controlling device.

706. A machine comprising a carriage; means for moving said carriage in one direction; two series of stops supported independently of said carriage, one of said series being arranged in a plane different from the plane of the other series; a pawl device coöoperative with both said series of stops, for controlling movements of said carriage; a plurality of actuating keys; and means coöoperative with said keys and said stops and said pawl device, for causing step-by-step movement of said carriage.

707. A machine comprising a carriage; a track; a spring for moving said carriage along said track in one direction; a plurality of actuating keys; two series of stops supported independently of said carriage and arranged in different planes, the stops of one series being arranged in advance of the corresponding stops of the other series; and a pawl-device operatively connected with said stops; said keys being operable for causing relative movement of said stops and pawl-device, and thereby coöoperating with said spring, for effecting step-by-step movement of said carriage.

708. A machine comprising a carriage; means for moving said carriage in one direction; a plurality of stops supported independently of said carriage; a double-pawl device having separate stop surfaces fixed with relation to each other, for engaging alternately with said stops, for controlling said moving of said carriage; and a plurality of actuating keys any one of which may actuate said stops to permit step-by-step movement of said carriage.

709. The combination of a machine frame; a carriage mounted to move transversely with relation thereto; a spring for driving said carriage to move in one direction; a stop device comprising a set of escapement teeth which extend respectively along lines which lie wholly in a common plane, and a second set of escapement teeth which extends respectively along lines which lie wholly in a common plane parallel with the first said plane; and a pawl device having two detent fingers fixed with relation to each other and adapted to alternately engage with the teeth of said sets, whereby the carriage is permitted to move step-by-step under the propelling power of said spring.

710. The combination of a machine frame; a carriage mounted to move transversely with relation thereto; a spring for driving said carriage to move in one direction; a stop device having two sets of stop teeth, the

teeth of one set pointing in like directions 65 with corresponding teeth of the other set and arranged in parallel planes adjacent to each other, each tooth of one set being normally in advance of the corresponding tooth of the other set; and a pawl-device having 70 two detent fingers fixed with relation to each other and adapted to alternately engage the teeth of said sets, whereby the carriage is permitted to move step-by-step under the propelling power of said spring. 75

711. The escapement mechanism comprising two sets of stop teeth, the teeth of one set pointing in like directions with the corresponding teeth of the other set and arranged in parallel planes adjacent to each other, each tooth of one set being in advance of the corresponding tooth of the other set; and a pawl-device having two detent fingers fixed with relation to each other and adapted to alternately engage with the teeth of 85 said sets.

712. A machine comprising a movable carriage two series of stop teeth arranged with the teeth of one series pointing substantially in the same direction as those of the other 90 series and mounted for movement of one series relative to the other series in a line of direction substantially parallel to the stopping faces of said teeth; and means coöoperative with both of said series of teeth, 95 for effecting step-by-step movement of said movable carriage.

713. A machine comprising a movable carriage; two series of stop teeth arranged with the teeth of one series pointing substantially 100 in the same direction as those of the other series and mounted for movement of one series relative to the other series along a line of direction substantially parallel to the stopping faces of said teeth; said series also 105 being movable one relative to the other along a line of direction at an angle to the line of the first said movement; and means coöoperative with both of said series of teeth, for effecting step-by-step movement of said movable 110 carriage.

714. In a key-controlled machine, the combination of a movable carriage; a spring for driving said carriage; a pawl device; two sets of stop teeth supported independently 115 of said carriage, one of said sets being arranged in a plane adjacent to the other set so that two adjacent teeth, one of each set, constitute a pair, the teeth of each pair pointing in similar directions along lines 120 that are nearly parallel, one tooth of each pair being positioned in advance of its companion tooth; and keys for causing successive engagement of said pawl device with the successive teeth of alternate sets, for 125 controlling said driving of said carriage.

715. In an escapement mechanism, the combination of a pawl-device; two sets of

stop teeth each set comprising a plurality of stop teeth, and arranged in a plane adjacent to the other set, each tooth of one set positioned in advance of its companion tooth of the other set; and means for successively engaging said pawl device with the teeth of alternate sets.

716. In a key-controlled machine, the combination of a movable carriage; a spring for driving said carriage; two sets of stop teeth, each set comprising a series of stop teeth arranged in parallel relation with its companion set, each tooth of one set being positioned normally in advance of its companion tooth of the other set; a pawl device operatively connected with the two sets, for alternately engaging with their teeth; keys cooperative with said teeth and said pawl, for controlling said driving of said carriage, one of said sets being shiftable with relation to the other set, so that the teeth which are normally in advance assume a rearward position relative to their companion teeth of the other set.

717. In an escapement mechanism, the combination of two sets of stop teeth, each set comprising a series of stop-teeth arranged in parallel relation with its companion set, each tooth of one set being positioned normally in advance of its companion tooth of the other set, one of said sets being shiftable with relation to the other set, so that the teeth which are normally in advance assume a rearward position relative to their companion teeth of the other set; and a pawl-device operatively connected with the two sets, for alternately engaging with their teeth.

718. In an escapement mechanism, the combination of a pawl-device having two separate contact surfaces; two sets of stop teeth, the teeth of one set extending respectively in lines which lie wholly in a common plane, and the teeth of the other set extending respectively in lines which lie wholly in a common plane parallel with the first said plane, each tooth of one set being positioned in advance of its companion tooth of the other set; and means whereby the separate surfaces of said pawl-device may be caused to engage with successive teeth of said sets alternately.

719. In an escapement mechanism, the combination of a pawl-device; and two sets of stop teeth, the teeth of one of said sets extending respectively along lines which lie wholly in a common plane, and the teeth of the other of said sets extending respectively along lines which lie wholly in a common plane parallel with the first said plane, said pawl-device being movable along a line of direction which lies either in one of said planes or in a plane parallel thereto.

720. In an escapement mechanism, the

combination of a pawl-device; two sets of 65 stop teeth, each set comprising a plurality of stop teeth; and means whereby said pawl-device may be engaged with successive teeth of said sets alternately, one of said sets of teeth being shiftable independently of said 70 pawl device, with relation to the other set of teeth.

721. A machine comprising a carriage, means for moving the carriage, two sets of stop teeth supported independently of said 75 carriage, and a pawl-device for alternately engaging successive teeth of said sets of stop teeth, for controlling movement of said carriage, one of said sets of stop teeth being adjustable with relation to the other set of 80 stop teeth, for varying the normal positions of the two sets relative to one another.

722. A machine comprising a carriage, means for moving the carriage, two sets of stop teeth supported independently of said 85 carriage, a pawl-device for alternately engaging successive teeth of said sets of stop teeth, for controlling movement of said carriage, one of said sets of stop teeth being adjustable with relation to the other set of 90 stop teeth, for varying the normal positions of the two sets relative to one another, and means for securing the adjusted set of stop teeth in adjusted position.

723. In an escapement mechanism; the 95 combination of a pawl-device; two sets of stop teeth, each set comprising a plurality of stop teeth, the stop teeth of each set being positioned to point in parallel and in other than opposite directions, each tooth of 100 one set being positioned in advance of its companion tooth of the other set, said sets being arranged in adjacent parallel planes; and means, independent of the pawl-device, for moving one of said sets of teeth with 105 relation to the other set, to successively disengage said pawl-device from the stop teeth of one of said sets and engage it with the stop teeth of the other set.

724. In a key-controlled machine, the combination with a movable carriage; of a track supporting said carriage; a spring for effecting horizontal movement of said carriage along said track; an escapement mechanism; a key for controlling said escapement mechanism, to permit said horizontal movement of said carriage step-by-step; a key supported independently of said carriage, for moving said carriage along said track in the direction opposite to the first said horizontal 120 movement, against the power of said spring; a pivotally mounted equalizing frame connected with opposite ends of said track; and a key supported independently of said carriage, for moving said carriage and track 125 vertically.

725. In a machine, the combination of a plurality of actuating members, a carriage

operable to engage for actuating each of said members, and means for moving said carriage step-by-step to position said carriage for engagement with said members successively.

5 726. In a machine, the combination of a carriage; a spring for moving said carriage step-by-step in one direction; a member so connected as to move concomitantly with the movement of said carriage; and an actuating 10 device constantly in operative relation with said member and non-dependent on friction, for moving said carriage, and comprising a key for the sole purpose of moving said carriage in the direction opposite to the first 15 said direction.

727. The combination of a carriage, a spring, an escapement mechanism co-operative with said spring for moving said carriage step-by-step in one direction, an element 20 mounted for movement concomitant with movement of the carriage, and key-controlled means co-operative with said element and non-dependent on friction for moving the carriage in the direction opposite to the 25 first said direction, said escapement mechanism being incapable of rendering said means ineffective.

728. In a calculating machine, the combination of a carriage, a spring, an escapement 30 co-operative with said spring, for effecting movement of said carriage step-by-step in one direction, a finger-piece supported independently of said carriage, and a connection between said finger-piece and carriage, said 35 connection being operable by said finger-piece, for moving said carriage in the direction opposite to the direction of its step-by-step movement, said connection being non-dependent on friction and non-affected by 40 said escapement.

729. The combination of a carriage; a spring; a finger-piece movable relatively to the carriage for the purpose of moving the carriage against the tension of said spring, 45 the movement of said carriage by said finger-piece being non-dependent on friction, and a pawl-device co-operative with said carriage, for effecting step-by-step movement of the latter under the impulse of said 50 spring; said pawl-device being incapable of rendering said finger piece ineffective.

730. The combination of a carriage, a spring, a pawl device co-operative with the carriage for effecting step-by-step movement 55 of the latter under the impulse of said spring, and a key mounted for movement concomitant with the step-by-step movement of said carriage and for movement relative to said carriage, so that the relative movement of said key effects movement of said carriage in the direction opposite to that of the step-by-step movement.

731. The combination of a carriage mounted for movement in opposite directions, a

spring for moving said carriage in one of 65 said directions, and a finger-piece connected to for moving the carriage in the other of said directions and being operable for horizontal movement relative to said carriage substantially in the directions of movement 70 of the carriage, said finger-piece being pivotally supported independently of said carriage.

732. A machine comprising a carriage; operating means, supported independently 75 of said carriage, for controlling forward and return movements of the carriage; and auxiliary operating means for effecting an auxiliary control of the carriage, said auxiliary operating means being supported independently 80 of said carriage, and being separate from and independent of the first said operating means.

733. A machine comprising a carriage; hand controlled operating-means supported 85 independently of said carriage, for controlling the forward and return movements of the carriage; and hand controlled auxiliary operating-means independent of the first 90 said operating-means, for controlling movements of said carriage.

734. The combination with a movable carriage; a spring for moving said carriage; controlling means for said carriage, comprising an escapement mechanism; a plurality of actuating keys; connections from 95 said actuating keys to said escapement mechanism, whereby the carriage is permitted to move step-by-step upon the operation of any one of said actuating keys; and a manually 100 operable device pivotally supported independently of said carriage, for moving said carriage in the direction opposite to the first said direction, against the power of said spring; of a secondary stop-device independent 105 of said controlling means, for effecting control of said carriage; and a key separate from and independent of the said actuating keys, for controlling said secondary stop-device.

735. The combination in a key-controlled machine; of a carriage; a spring for moving said carriage; an escapement device; a plurality of controlling keys; a universal device correlated with said escapement device and with said keys and being co-operative 115 with said spring, for effecting step-by-step forward movement of said carriage; means comprising a return-key, supported independently of said carriage, for moving the carriage backward; and means comprising a plurality of keys, supported independently of the carriage, for effecting an auxiliary control of the carriage independently of 120 said universal device.

736. In a machine, the combination of a movable carriage; a spring for moving said carriage in one direction; an escapement

- device for permitting said carriage to move step-by-step, under the propelling power of said spring; a plurality of actuating keys, universal connecting means coöperative with 5 said keys and said escapement device, whereby said escapement device is actuated upon the operation of any of said keys; a return-key; means operable by said return-key for causing the carriage to move in the direction 10 opposite to the first said direction, against the power of said spring; an auxiliary key; and means operable by said auxiliary key, for permitting said carriage to be moved by said spring independently of said escape- 15 ment device.
737. In a machine, the combination of a movable carriage; a spring for moving said carriage in one direction; a plurality of stops for arresting said moving of said carriage; a plurality of actuating keys; universal means operable by any one of said keys, for permitting said carriage to be moved by said spring from one to another of said stops; a return-key; means operable 25 by said return-key, for causing said carriage to move in the direction opposite to the first said direction, against the power of said spring; a plurality of auxiliary keys; and a plurality of stops separate from the first said 30 stops and operable by said auxiliary keys, for permitting said carriage to be moved by said spring independently of said universal means.
738. In a machine, the combination of a movable carriage; a spring for moving said carriage in one direction; a stop-device supported independently of said carriage and comprising a plurality of stops, for arresting said moving of said carriage; a plurality 35 of actuating keys; universal means operable by any of said keys, for permitting said carriage to be moved by said spring from one to another of said stops; a return-key; means operable by said return-key for, 40 causing said carriage to move in the direction opposite to the first said direction, against the power of said spring; a plurality of auxiliary keys; and a plurality of stops separate from the first said stops and 45 operable by said auxiliary keys, for permitting said carriage to be moved by said spring independently of said universal means.
739. The combination with a movable carriage; a spring for moving said carriage in one direction; controlling means, for said carriage, comprising an escapement mechanism; a plurality of actuating keys; connections from said actuating-keys to said 50 escapement mechanism, whereby the carriage is permitted to move step-by-step upon the operation of any one of said actuating-keys; and a manually operable device pivotally supported independently of said car- 55
- riage, for moving said carriage in the direction opposite to the first said direction, against the power of the said spring; of a carriage-releasing-and-arresting device separate from said controlling means; and means separate from and independent of said controlling means, for operating said carriage-releasing-and-arresting device. 65
740. A machine comprising a horizontal track, a carriage on said track, and a key-lever pivotally secured to a stationary part 75 of the machine and being connected to a fixed part of the carriage and operable for moving the latter along said track.
741. The combination of a carriage; a frame movable up and down and on which 80 said carriage is supported to move horizontally with relation to said frame; an equalizing device comprising a pivotally mounted frame and correlated with the first said frame, for controlling the up and down 85 movements of the first said frame; and a key coöperative with said frames, for moving said carriage up and down.
742. The combination of a carriage shiftable up and down, a pivotally mounted 90 frame on which said carriage is supported to move horizontally with relation thereto and which frame is operable for imparting up and down movement to said carriage, an equalizing device comprising a second pivotally mounted frame which is correlated 95 with said carriage for controlling the up and down movement of the carriage, and a key coöperative with said frames for moving said carriage. 100
743. The combination of a carriage movable vertically, a pivotally mounted frame on which said carriage is supported for horizontal step-by-step movement with relation thereto, a key for controlling step-by-step 105 horizontal movement of said carriage, a key for operating said frame for imparting up and down movements to said carriage, and an equalizing device comprising a second pivotally mounted frame correlated with for 110 controlling the up and down movement of said carriage.
744. In a machine, the combination with a frame movable up and down; and a carriage supported upon said frame; of a shifting-lever supported independently of said carriage and operable to move the carriage transversely upon the supporting frame; and a lever movably secured to a part of the machine other than the carriage and supported independently of said carriage and operatively related to said movable frame, for raising the latter. 115
745. The combination of a carriage; means comprising an escapement, for effecting movement of the carriage in one direction; means movably supported independently of said carriage, for effecting 120
- 125

movement of the carriage in the opposite direction; and key-controlled means supported independently of said carriage, for raising the carriage.

746. The combination of a carriage; means comprising an escapement, for effecting movement of the carriage in one direction; means movably supported independently of said carriage, for effecting movement of the carriage in the direction opposite to the first said direction; and means comprising a lever for raising the carriage.

747. The combination of a carriage mounted for horizontal and up-and-down movements; means comprising an escapement, for controlling step-by-step movement of the carriage in one horizontal direction; means supported independently of said carriage, for controlling movement of the carriage in the opposite horizontal direction; and key-controlled means supported independently of said carriage, for controlling up-and-down movements of the carriage.

748. The combination of a carriage, means comprising a plurality of keys and an escapement mechanism for effecting horizontal movement of the carriage in one direction, a key supported independently of the carriage, for effecting movement of the carriage in the opposite direction, and key-operated means supported independently of said carriage, for raising the carriage.

749. The combination of a carriage, a pivotally mounted frame supporting said carriage, means for controlling movement of said frame so as to raise and lower said carriage, and means for causing said carriage to move step-by-step horizontally with relation to said frame.

750. The combination in a machine, of a carriage mounted to be fed step-by-step and guided for horizontal movements across the machine, a plurality of separately operable keys supported independently of said carriage, and means controllable by said keys for causing vertical movement of the carriage.

751. The combination of a carriage; means comprising an escapement, for effecting movement of the carriage in a horizontal direction; and a plurality of differently designated keys supported independently of said carriage, for raising the carriage.

752. In combination, a carriage, an element for moving the carriage in a horizontal direction, means for reversing the action of said element and thereby moving the carriage in the opposite horizontal direction, and means supported independently of said carriage, for raising the carriage.

753. In combination, a carriage, an element for moving the carriage in a horizontal direction, hand-controlled means supported independently of said carriage, for reversing the action of said element and

thereby moving the carriage in the opposite horizontal direction, and key operated means supported independently of said carriage, for raising the carriage.

754. In combination, a horizontally movable carriage; means for moving said carriage in one direction; an escapement device for controlling said moving of said carriage, a plurality of pivotally mounted arms supported in position for intermittently contacting with said carriage, said carriage and the support of said arms being constructed and arranged for relative up-and-down movement of one with respect to the other; a key movably supported independently of said carriage, for effecting said up-and-down movement; and means, comprising a key supported independently of said carriage, for releasing the carriage from said escapement and stopping said carriage between its limits of horizontal movement.

755. In combination, a horizontally movable carriage; means for moving said carriage in one direction; an escapement for controlling said moving of said carriage; a plurality of pivotally mounted arms supported in position for intermittently contacting with said carriage, said carriage and the support of said arms being constructed and arranged for relative up-and-down movement of one with respect to the other; a key movably supported independently of said carriage, for causing said up-and-down movement; means, comprising a key supported independently of said carriage, for releasing the carriage from said escapement and stopping said carriage between its limits of horizontal movement; and a finger-piece supported independently of said carriage, for moving the carriage against the action of the first said means.

756. In combination, a carriage, movable horizontally, an escapement device for controlling the horizontal movement of the carriage, a shifting device for moving the carriage in a direction other than horizontal, and operating means common to and co-operative with both the escapement device and the said shifting device, for effecting both of said movements of the carriage.

757. In combination, a horizontally movable carriage; mechanism comprising a plurality of arms pivotally mounted on a common support, each of said arms being in position for intermittently contacting with said carriage, said carriage and said support of the pivoted arms being mounted for relative up-and-down movement of one with respect to the other; and a key movably supported independently of said carriage, for causing said up-and-down movement.

758. The combination of a movable member supported by pivot-bearings spaced apart, and a second movable member supported by pivot-bearings spaced apart and

having their axial lines parallel with those of the first said movable member, said movable members being relatively immovable longitudinally of their axes, and being connected together for the purpose of equalizing the movements of one of said movable members by means of the other of said movable members.

759. The combination of a carriage, a track mounted for reciprocatory movement transversely of its length and on which track said carriage is mounted, driving and stopping elements for effecting step-by-step movement of said carriage along said track, and a pivotally mounted member connected with said track for rendering the reciprocatory movement at one end equal to that at the other end of said track.

760. The combination of a carriage; a pivotally mounted frame comprising a track on which said carriage is mounted to travel; a spring; and an escapement element coöperative with said spring, for effecting step-by-step movement of said carriage along said track.

761. The combination with a main framework; of a frame comprising a horizontal track extending crosswise of the machine, and also comprising arms extending from said track and hinged to the main framework, whereby said track may be shifted up and down; keys; a carriage on said track; and means controllable by said keys, for advancing the carriage step-by-step along said track.

762. The combination with a main framework of a machine, of a frame movably mounted on said framework and comprising a track extending horizontally crosswise of the machine, a carriage mounted to travel step-by-step along said track and being shiftable up and down by said track, a spring for propelling said carriage along said track, keys, and means under the control of said keys, for controlling the step-by-step movement of said carriage effected by said spring.

763. The combination with a main framework of a machine, of a horizontal track extending crosswise of the machine and being shiftable up and down, a carriage mounted on said track, means for limiting the up-and-down shifting movements of said track and carriage, a spring for propelling said carriage along said track, keys, and an escapement mechanism controllable by said spring and coöperative with said spring, for causing said carriage to advance step-by-step along said track.

764. The combination of a carriage, a motor spring therefor, a key, a plurality of escapement elements, a pivotally mounted frame comprising a track on which said carriage is supported and is controllable by said spring and said escapement elements

and said key so as to move step-by-step along said track, a key for moving said pivotally mounted frame up and down, and an equalizing device for controlling the up and down movement of said carriage.

765. In a key-controlled machine, the combination of a carriage, means for moving said carriage transversely step-by-step, a key for moving said carriage vertically, and means for preventing said carriage from moving vertically unless said key is operated.

766. The combination of a pivotally mounted frame comprising a track-bar, a carriage mounted to travel longitudinally of said track-bar and held against lateral movement relative to said track-bar, a locking element for normally detaining said track-bar and carriage in depressed position, and a key-lever operable for releasing said track-bar and carriage from the control of said locking element and raising said track-bar and carriage.

767. In a key-controlled machine, the combination of a carriage which is movable up and down; a key supported independently of the carriage, for effecting up-and-down movement of said carriage from one position to another position; and an element for locking said carriage in one of said positions.

768. In a key controlled machine, the combination of a carriage; a spring for moving said carriage substantially horizontally; an escapement mechanism coöperative with said spring for controlling step-by-step movement of said carriage; means for moving said carriage up and down from one position to another position and comprising a key supported independently of said carriage; and an element for locking said carriage in one of the said positions.

769. In a key controlled machine, the combination of a carriage; a spring for moving said carriage substantially horizontally; an escapement mechanism coöperative with said spring for controlling step-by-step movement of said carriage; a key for moving said carriage up and down from one position to another position and supported independently of said carriage; an element for locking said carriage in one of the said positions; and an element for operating the locking element, for releasing the carriage therefrom.

770. In a key-controlled machine, the combination of a carriage movable up and down; a key supported independently of said carriage, for moving said carriage up and down from one position to another position; and an element for locking said carriage in one of said positions, said key being operable for releasing said carriage from the control of said element.

771. In a key - controlled machine, the combination of a carriage, a movable frame

on which said carriage is mounted to travel, a locking device whereby the said frame is temporarily held in a lower position, and a key operative to release said locking device and to effect the raising of the said frame and carriage.

772. In a calculating machine, the combination of a totalizer, actuators for actuating said totalizer, a stationary field of 10 stops for controlling said actuators, a movable carrier, and a series of vertically disposed horizontally adjustable setting-up pins arranged in said carrier.

773. In a calculating machine, the combination of a totalizer, actuators therefor, 15 a field of stops for controlling the movement of said actuators, a movable carrier, a series of horizontally adjustable setting-up pins mounted in said carrier, and means 20 for moving said setting-up pins to position the stops.

774. In a calculating machine, the combination with the carriage frame, of a transverse bar connecting the side arms of said 25 frame and provided with a pivoted locking lever whereby the carriage frame is locked in a depressed position, and a key lever engaging said transverse bar, whereby the carriage frame is released upon depressing 30 the key lever, substantially as set forth.

775. In a calculating machine, the combination with a registering wheel provided 35 with ratchet teeth and a key lever adapted to rotate said wheel, of a stop mechanism interposed between said key lever and registering wheel and actuated by said key lever, whereby the registering wheel is rotated a number of teeth corresponding with 40 the number on said key lever and any multiple thereof, substantially as set forth.

776. In a calculating machine, the combination with the registering wheels, and the key levers, and a movable carriage arranged between the key levers and registering 45 wheels, and provided with a pawl mechanism engaging against stops secured to the frame of the machine, and mechanism connecting said carriage with the key levers and registering wheels, of a space key lever, 50 and a space bar connected with said space key lever whereby the carriage is released upon depressing the space key lever.

777. In a calculating machine, the combination with a registering wheel provided 55 with ratchet teeth, of a pawl arm carrying a pawl engaging with the teeth of the registering wheel, a key whereby the pawl arm is actuated to rotate the registering wheel, a stop adapted to limit the movement of 60 the pawl arm in one direction, and a movable stop bar actuated by the key and adapted to arrest the movement of the pawl arm in the opposite direction.

778. In a calculating machine, the combination with a registering wheel provided 65

with ratchet teeth, and a pawl engaging with said teeth, of a key lever whereby said pawl and registering wheel are actuated, and a movable stop bar actuated by said key lever and adapted to bear against said pawl 70 and arrest the movement of the registering wheel.

779. The combination with a register, and an operating mechanism therefor, of a plurality of devices settable preparatory to performing the registering operation, and a locking device which is constructed to lock any one of the settable devices when the latter is shifted into an operative position and also to lock another one of said settable 80 devices which is subsequently shifted into an operative position and to release the previously shifted settable devices.

780. The combination with a register; and an operating mechanism therefor; of 85 a plurality of devices settable preparatory to performing the registering operation, each of said settable devices being provided with an incline and a shoulder; and a movable locking member capable of engaging 90 with the inclines and shoulders of said settable devices, said locking member, inclines and shoulders being so constructed that when one of the settable devices is shifted into its operative position, the shoulder of 95 the same will be engaged by said locking member and locked in this position, while upon subsequently shifting another one of said settable devices into its operative position, the incline thereof will engage said 100 locking member and cause the latter to disengage the previously shifted settable device and, in turn, the subsequently shifted settable device will be engaged with said member, for locking the last said settable 105 device in an operative position.

781. The combination of a series of registering wheels, a series of number keys, a carriage interposed between said wheels and keys, a spring for moving said carriage forwardly, means independent of said keys for straining said spring, an escapement mechanism operable by said keys and adapted to control the movement of the carriage by said spring for bringing the number keys 110 in operative relation to the registering wheels in succession upon the depression of any one of said number keys.

782. In a calculating machine, the combination with a series of registering devices, 115 of a key operable to propel for rotating any one of said registering devices, and a stop for each registering device, each said stop being adapted to be operated by said key for arresting the movement of its respective 120 registering device.

783. In a calculating machine, the combination with a series of registering devices; of a series of stops; and a key operable for controlling movement of said stops to con- 130

trol without causing actuation of said registering devices.

784. In a calculating machine, the combination with a series of registering devices; 5 of a series of stops for controlling without actuating said registering devices; and a key operable for controlling movement of said series of stops.

785. In a calculating machine; the combination of a plurality of movable registering members; a plurality of keys, any one of which is operable for controlling any one of said registering members; a plurality of sets of stops, for controlling said registering members; and connecting-means whereby each of said keys controls its respective stops.

786. In a calculating machine, the combination of a registering wheel having ratchet 20 teeth, a pawl engaging with the teeth of said registering wheel, a key whereby said pawl is actuated for rotating said registering

wheel, and a stop-member movable with relation to said wheel and operable by said key and adapted to limit movement of said 25 registering wheel.

787. In a calculating machine, the combination of a registering wheel constructed with engaging elements, an actuating device provided with an engaging member for engaging said engaging elements of said registering wheel, and a stop adapted to be moved to a position in which it is substantially unyielding with relation to said engaging member, whereby said engaging member is arrested in its forward movement and held in engagement with said registering wheel for preventing over-rotation thereof.

Witness my hand this 19th day of June 1889.

WILLIAM S. GABELMANN.
